SWITCH AND SIGNAL CONTROL SYSTEM
FOR RAILROADS

Neil D. Preston, Rochester, and Forest B. Hitchcock, Greece, N. Y., assignors to General Railway Signal Company, Rochester, N. Y.

Application April 9, 1940, Serial No. 328,712

35 Claims. (Cl. 246—134)

This invention relates to switch and signal control systems for railroads, and it more particularly pertains to a system where the manipulations by an operator are of the entrance-exit type for controlling the power operation of track switches and the indications of the signals of a track layout.

In the system of the entrance-exit type, it is preferable that a control panel be provided with a miniature track diagram located thereon with suitable control buttons, or the like, at points on the track diagram corresponding to the signal locations constituting the entrance and/or exit ends of the various routes. The desired operation of the various track switches to the positions required to set up the various routes through the track layout and the clearing of the signals is accomplished by actuating these manually operable buttons without individually controlling the several track switches involved.

More specifically, the operator may position all of the switches for a desired route and effect the clearing of a signal for train movement in one direction or the other over that route by merely operating a button belonging to the entrance end of the desired route followed by the actuation of a button at the exit end of that route. Such manipulation on the part of the operator causes the organization of relays and circuits to automatically effect the operation of all the track switches or cross-overs involved to proper positions to set up the desired route after which the signal at the entrance end of the route is cleared.

A switch and signal control system of this entrance-exit type is disclosed, for example, in the prior application of A. Langdon, Ser. No. 119,641, filed January 8, 1937; in the prior application of N. D. Preston, Ser. No. 183,499 filed January 5 1938; and also in the prior application of N. B. Coley, Ser. No. 272,319 filed May 8, 1939. The present invention is in the nature of an improvement in the means employed for accomplishing the desired functions and results in such a type of system; and no claim is made herein to anything disclosed in such prior applications.

One object of the present invention is to provide an improved organization of relays and circuits in a system of the entrance-exit type in which a single self-restoring control button is all that is needed for each signal location constituting the entrance and/or exit point for a route or routes emanating from or converging at that point. The same button acts at different times to designate its point as an entrance point or an exit point, as the case may be, dependent upon the se-

quence with which it is actuated with respect to some other button, and thereby governs the direction of train movement over the given route as determined by this sequence or order.

This feature of the present invention is in general accomplished by what has been conveniently termed a "bus interlock arrangement" which provides that the first button actuated performs the function of an entrance button and at the same time renders all other buttons ineffective to act as entrance buttons until a second button is actuated for the exit end of an available route emanating from the point corresponding to the first button actuated, which second button performs the function of an exit button, whereupon the "bus interlock arrangement" is restored to its normal condition ready for the next sequential actuation of two buttons belonging to the entrance and exit ends of an available route.

Another object of the present invention is to provide an improved route establishing means using a minimum number of relays and governed by single control buttons located at the ends of the routes. This route establishing circuit means according to the present invention comprises a normal and a reverse switch control relay for each track switch, except in the case of a cross-over where the opposite ends of the cross-over are operated together, in which case both track switches have a common reverse relay. In other words, two relays are employed for each single switch and three relays are employed for each crossover.

These normal and reverse switch control relays are so included in the circuits of the route establishing means that the designation of any given signal location as an entrance point causes the switches in each of the available routes emanating from that point to be preselected by energizing selected switch control relays, and the designation of the exit end of a given one of such available routes completes the energization of the switch control relays for any remaining track switches in that route and causes that given route to be established and the signal at the entrance end to be cleared.

In a system of this character, where the designation of an entering signal location preselects the positions of those switches in all the various available routes originating at such entrance point, it is essential that such manipulation for an entrance point be directly followed by the designation of the exit end of a particular one of those available routes before another entrance signal location is designated. Otherwise, the des-

ignation of two entrance signal locations followed by the designation of an exit signal location might result in the establishment of an undesired and unanticipated route. The present invention embodies both the principles of preselection and the enforced sequence of entrance and exit manipulations by the "bus interlock arrangement" and thereby avoids any undesired results mentioned above.

The route establishing means through the provision of the principle of preselection is so organized as to give a predetermined preference between several optional or alternative routes afforded by the track layout between the same entrance and exit points. More specifically, the designation of entrance and exit points between which there are optional routes, results in the establishment of a predetermined one of such routes with the circuit arrangement so organized that, if the preferred route is not available for use by reason of the establishment or occupancy of another route in conflict therewith, the inferior route will be automatically established and allow the passage of a train. However, it is also contemplated that this automatic selection between optional routes will be under the manual control of the operator, and may be modified or changed by the operation of auxiliary switch control levers.

Another feature of the present invention resides in the manner in which the power operation of the several track switches in any route being established are caused to be initiated in cascade relationship, irrespective of the time of response of the route establishing circuit means. It will of course be understood that the use of quick acting type primary switch control relays in the route establishing circuit means would render such means so rapidly responsive to the designations of the opposite ends of a route that the several power-operated track switches in the route would receive starting energy at substantially the same time. According to the present invention, additional means is provided for causing the cascade or sequential starting of the several switch machines in any route being set up irrespective of whether or not the primary switch control relays of such route are actuated in sequence or at the same time.

Any group of track switches and crossovers in a terminal or interlocking plant, which provide inter-related routes, and which are located between or bounded by their governing signals, are conveniently termed an "interlocked group."

A terminal or interlocking plant may include one or several of these interlocked groups dependent upon the arrangement of the track layout and the movements of traffic to be made thereover, and some of such interlocked groups may be located end-to-end so as to provide one or more "through routes" past the signals of one or more interlocked groups which signals are then considered as intermediate signals with respect to any given through route.

Thus, another object of the present invention is to so organize the route establishing circuit means that the operation of the control button for any given entrance signal location followed by the actuation of the control button for the exit end of any available route terminating either at the exit end of its interlocked group or any subsequent interlocked group, will cause either a route or a through route to be established. In other words, the present invention contemplates the provision of what has been

conveniently termed "through route control." It is proposed to provide for such "through route control" by suitable through route connections between the route establishing circuit means for the several interlocked groups so that the through route operation is effective for all routes which the track layout may afford. It is to be understood, however, that in those cases where certain through routes are not desired, such through route control may of course be eliminated.

It is an object of this invention to provide this through route control by means which prevents such through route control from establishing and clearing signals for through routes occupied by trains. Yet, the system is so organized as to permit the establishment of an occupied route in any single interlocked group and the clearing of a call-on signal therefor to effect the various switching operations required of the plant.

Other objects and characteristic features of the invention relate to a means employed to enable the operator to cancel a route partially set up by merely actuating a special cancel key; to cancel a route completely set up by merely actuating in a distinctive manner the control button at the entrance end of such route; to provide for individual operation of any switch by manipulation of an auxiliary switch control lever; and to make provision for the display of suitable desirable indications of the switch position and response, track occupancy, the route established, and the signals cleared, in a distinctive manner on the track diagram to furnish the operator with the necessary information for the proper and efficient manipulation of the system.

In connection with the display of indications, it is the object of the present invention to provide indications of route establishment in a simple and clear manner without including indications as to the response of individual switches except when such individual response becomes essential to the operator for further operation of the system. To accomplish this, a master key or button is provided for allowing the operator to obtain at will indications of the response of the switches to their individual controls.

The embodiment of the present invention also provides another feature which gives the system dual methods of manipulation. The usual and contemplated operation is of the entrance-exit type, as above explained, but under certain emergency conditions the track switches of a desired route can be controlled by their individual levers to establish that route, and the signal governing such route can then be cleared by the operation of its associated control button alone. It is the object of this invention to include such dual features of manipulation without added apparatus but with all other features of safety and facility of operation retained.

The nature of the invention and complexity of the structural organization and mode of operation makes it difficult to define the invention completely and yet briefly; and various other characteristic features, attributes, and advantages of the system embodying this invention will appear as the description progresses.

The accompanying drawings illustrate conventionally and diagrammatically certain specific embodiments of the invention applied to typical or representative track layouts, the parts and circuits being illustrated in a man-

ner to facilitate an explanation and an understanding of the invention, rather than to show specifically how the various relays and devices may be arranged and structurally organized in practice, various symbols and nomenclatures being employed to simplify the illustration.

Figs. 1A and 1B, when placed side by side, show diagrammatically a control panel with its track diagram and associated route establishing means for a relatively simple track layout typical of the various arrangements of signals and crossovers found in practice;

Fig. 2 shows a typical switch control circuit which illustrates how each of the track switches indicated in Figs. 1A and 1B may be controlled by the response of the route establishing means or by individual lever manipulation;

Fig. 3 shows the track layout in the field for which the miniature track diagram of Fig. 1A is provided, and also shows the signal selecting circuits provided to select and control the signals in accordance with the route establishing means and in accordance with traffic conditions;

Fig. 4 shows the directional stick relays and circuits to provide sectional release locking for the track switches of Fig. 3;

Figs. 5A and 5B show the arrangement of relays and circuits provided for indicating and displaying the desired information on the miniature track diagram of Fig. 1A;

Figs. 6A, 6B and 6C, when placed side by side, show the through route circuit connections necessary to interrelate the route establishing means for two adjacent interlocked groups at an intermediate signal location having signals governing traffic in both directions with only a single control button provided for such signal location;

Fig. 7 shows a track layout to which the through route features of the present invention may be applied together with certain typical signal control circuits;

Fig. 8 shows a modified arrangement of the circuits of Figs. 1A and 1B to change the relative superiority between the optional routes found in the track layout of Fig. 3;

Figs. 9A and 9B, when placed side by side, show diagrammatically a control panel with its track diagram and associated route establishing means for the track layout shown in Fig. 3, which route establishing means is a modified form of the route establishing circuit means shown in Figs. 1A and 1B;

Fig. 10 shows a typical switch control circuit which illustrates how each of the track switches of Fig. 3 may be controlled in response to control by the route establishing means of Figs. 9A and 9B, as well as by individual lever control.

Fig. 11 taken with Fig. 5B shows the arrangement of relays and circuits employed for indicating and displaying the desired information on the miniature track diagram of Figs. 9A and 9B using the typical switch control circuit of Fig. 10;

Fig. 12 shows a modified arrangement of the circuits of Figs. 9A and 9B to change the relative superiority between the optional routes provided by the track layout of Fig. 3;

Fig. 13 shows one arrangement of relays and circuits usable with the switch control of Fig. 10 to effect the sequential or cascade operation of switch machines in setting up routes in track layouts such as in Fig. 3;

Fig. 14 shows a circuit organization adapted for use with the route establishing means of Figs. 9A and 9B to effect the sequential or cas-

cade execution of switch controls in setting up a route in the track layout of Fig. 3; and

Fig. 15 shows a typical switch control circuit adapted for use with the route establishing means and cascade switch control execution of Fig. 14 in track layouts such as in Fig. 3.

For convenience in the consideration of the drawings and description of the invention, Figs. 1A, 1B, 2, 3, 4, 5A, 5B, 6A, 6B, 6C and 7 may be 10 considered to provide a first form of a switch and signal control system as contemplated by the present invention; while the Figs. 9A, 9B, 10, 3, 4, 11, 5B, 6A, 6B, 6C, 7 and 13 may be considered to provide a second form of a switch and 15 signal control system embodying the present invention. Fig. 8 is a modification of the route establishing means of the first form so as to provide that such form may be applied to the various track layouts found in practice and give 20 the desired flexibility of selection of relative degrees of superiority between optional routes. Fig. 12 is a modification of the route establishing means of the second form to provide the desired 25 flexibility in the application of such form of the present invention to the selection of optional routes in the various track layouts found in practice. Also, Figs. 14 and 15 considered together show a modified cascade switch control illustrated more particularly for the second form of 30 the invention although it may also be used with the first form of the invention.

Although it is convenient to refer to the drawings of the disclosure as a part of first or second forms of the embodiments of the present 35 invention, it will be readily appreciated that various sub-combinations in each of the forms may be substituted for corresponding sub-combinations in the other form, all of which is within the contemplated scope of the present invention. Certain of these substitutions and re-arrangements of the various elements of the embodiment will be mentioned as the description progresses.

In order to facilitate the disclosure of the 40 present invention, the various parts and circuits have been shown diagrammatically and certain conventional illustrations have been employed. Thus, the various devices, relays and their contacts are illustrated in a conventional manner; 45 certain circuit details well known to those familiar with the art are merely indicated by dotted lines; and symbols are used to indicate connections to the terminals of batteries, or other sources of electric current instead of showing all 50 of the wiring connections to these terminals.

The symbols (+) and (-) are employed to indicate the positive and negative terminals respectively of suitable batteries or other sources of direct current, and the circuits with which these 55 symbols are used always have current flowing in the same direction as graphically illustrated by the arrow heads and tails. If alternating current is used with the circuits having these symbols instead of direct current, the symbols shown are to be considered as representative of instantaneous relative polarities.

The symbols (B+) and (B-) are employed to indicate the positive and negative terminals respectively of suitable batteries or other sources 60 of direct current having a center or mid-tap indicated by the symbol (CN). The sources thus indicated are used to provide for the reversal of current flow in the circuits with which they are employed, and are used more particularly in connection with line circuits, and when so used it 65

is assumed that the mid-taps (CN) are connected over suitable common return line wires.

Certain of the indicating circuits are assumed to employ alternating current, and such circuits have associated therewith the symbols (BX) and (CX) to indicate the opposite terminals of a suitable alternating current source. Such alternating current is employed so that the degree of energization can be controlled by shifting transformer taps to change the degree of intensity of illumination of the indicator lamps without the consequent loss of power which would be present if direct current were employed and variable resistors used to change the degree of energization. However, it is to be understood that direct current can also be employed with such circuits.

General organization of the system.—It is of course well understood that the present switch and signal control system will govern the power operated switches and signals of the track layout in the field from a central tower or control office. The control office includes a control machine provided in accordance with the present invention which is directly connected to the various power switch machines and signals located in the field by suitable line wires. Inasmuch as the distribution of the control apparatus would vary in accordance with the different circumstances of application, no effort has been made to distinctly point out where the dividing line exists between the field apparatus and the control office apparatus. However, it is believed that it may be well to state that direct line wire control is contemplated and that most of the apparatus is located in the control office or a bungalow adjacent the field location so that the only line wires extending to the switches and signals are those which are for controlling the switch machine and signal mechanisms as well as those line wires which provide for the transmission of indications of the positions of the switches and signals. On the other hand, the present invention may well be used where some suitable code type of communication system is employed, such as shown in our prior Patent No. 2,129,183, dated September 6, 1938. The use of such a code type communication system would of course require either of two possible arrangements, namely, the location of the route establishing means in the control office or in the field. In the first instance, the switch and signal controls would then be transmitted over the code type communication system, while in the second instance the entrance-exit manipulations would be transmitted to the field for acting on the route establishing means. This has been pointed out for the purpose of having it understood that the features of the present invention may be applied to any switch and signal control system irrespective of the type of communication employed, and still be within the scope of the present invention.

Track layout (Fig. 3).—An interlocking plant may include one or several interlocked groups, it being understood that an interlocked group comprises one or more track switches for setting up or establishing different routes and having signals for governing traffic thereover. The track layout of Fig. 3 illustrates an interlocking plant having but a single interlocked group located on the main line of a double track railroad with automatic block signals assumed to be outside of the yard limits. It is of course to be understood that the present invention may

be practiced without the associated automatic signal system outside of the interlocking plant.

It is also to be understood that the present invention may be applied to a large terminal having several interlocked groups located end-to-end. When the invention is thus applied to such a track layout, the route establishing means (such as shown in Figs. 1A and 1B) for the adjacent interlocked groups are interconnected at the intermediate signal locations as shown in Figs. 6A, 6B and 6C. A track layout showing two interlocked groups has been indicated in Fig. 7, for which the control of a typical double intermediate signal has been shown in detail in Figs. 6A, 6B and 6C. The control for the other double intermediate signal may be assumed to be substantially the same as for the one shown.

With reference to the track layout of Fig. 3, it is contemplated that the various switches TS of the track layout will be equipped with power-operated switch machines in the usual manner, a switch machine of this character being disclosed, for example, in the patent to W. K. Howe, No. 1,466,903 dated September 4, 1923. Each switch machine SM is controlled in a manner suitable for remote control by a secondary switch control relay WZ (see Fig. 2) through suitable overload protection and the like, such as shown, for example, in the patent to W. H. Hoppe et al., Patent No. 1,877,876 dated September 20, 1932. It will be assumed for convenience, that any given relay WZ of the present disclosure is to be used for remotely controlling the relay CR illustrated in the Hoppe et al. patent, which relay CR is local to the switch machine.

Associated with each track switch TS (or crossover), is a suitable switch repeater or position indicating relay WP which is suitably controlled to one energized position or the other in the usual manner dependent upon the normal or reverse position and locked condition of its associated switch points. This control of each relay WP is preferably effected through the use of a suitable point detector contact mechanism such as disclosed, for example, in the patent to C. S. Bushnell, Patent No. 1,517,236 dated November 25, 1924. In the case of a crossover of the usual type, each end has its point detector mechanism and the circuit for the single switch position relay WP for that crossover is suitably selected through contacts of both mechanisms.

Wayside signals of a suitable type are provided at the various points constituting the entrance and/or exit ends of the various routes throughout the track layout, and these signals are governed in accordance with the usual practice to display appropriate indications for the type of traffic to be controlled. For the purpose of the present disclosure, the normal direction of traffic on the upper track is assumed to be from C to A, while on the lower track the normal direction of traffic is assumed to be from B to D. For this reason, signals BG and CG are provided with clear, caution and danger high speed signal aspects with automatic control. The remaining signals of the track layout are indicated as being of the low speed dwarf type without automatic control other than automatic restoration to provide stick signals.

The track layout is also assumed to be provided with suitable detector track sections having the usual track relays and track batteries. It is

contemplated that suitable detector, approach and sectional rear release route locking will be provided, such as common in the art and disclosed, for example, in the prior patent of C. F. Stoltz, Patent No. 2,115,511 dated April 26, 1938, and in the patent granted to Larry and Langdon, Patent No. 2,125,242 dated July 26, 1938. Typical sectional rear release locking has been shown for convenience in Fig. 4.

The arrangement of switches for various track layouts in terminals, junctions and the like, varies widely and it is of course understood that all such combinations cannot be illustrated in detail in the present disclosure, but it is believed that the principles of the present invention applied to the track switches and crossovers shown herein may also be applied to various other track layouts such as scissors crossovers, run-around sets of crossovers, ladder arrangements and the like. It is believed that the track layout selected to illustrate the present invention is sufficiently typical or representative of the problems encountered in practice that it would be obvious to any one skilled in the art how the means and principles constituting this invention may be adapted to apply to any form of track layout found in practice.

Also, the arrangement and location of signals varies in practice, depending upon the particular conditions surrounding the track layout; but the embodiments of the invention illustrated and described herein for single and double signal locations, together with the provision of through route operation are typical or representative of the conditions encountered in practice.

In the following discussion, the letters A, B, C, etc., are used for convenience to identify the signal locations constituting the ends of the various routes; and these letters are associated with other letters to appropriately designate certain of the devices, such as manually operable push buttons, relays and the like which are more directly associated with or belonging to the particular signal locations thus identified. Also, for the purpose of distinguishing between the opposite ends of a crossover, it is convenient to refer to track switch **1ATS** or track switch **1BTS**, for example, and in a similar manner the letters A and B are used to distinguish between the relays more directly related to the opposite ends of such crossover. For example, switch control relays **1AN** and **1BN** are respectively associated with the track switches **1ATS** and **1BTS**, and in a similar manner the track relays **1ATR** and **1BTR** are associated with the opposite ends of such crossover. Certain other letters used in the reference characters throughout the remaining parts of the specification which have been given particular significance will be mentioned as the description progresses.

CONTROL OFFICE APPARATUS

With reference to Figs. 1A and 1B, it is contemplated that the control machine includes a control panel having a track diagram located thereon, with the trackway represented by portions of cut-away panel having translucent strips of material inserted which are illuminated to outline the routes set up through the track layout. This track diagram also has signal symbols located at points on the diagram which correspond to the locations of the signals in the actual track layout. Adjacent such signal symbols are suitable control buttons of the self-restoring push button type, such as shown, for example, in the

prior application of J. F. Merkel, Ser. No. 158,720, filed August 12, 1937. Each such control button is assumed to be of the spring return type, capable of being pulled outwardly to an off normal position as well as capable of being depressed to an operated position. Certain of the buttons, where call-on signals are employed under manual control such as in Fig. 6B, are assumed to have right and left turned or rotated positions from which they must be manually returned to normal. These control buttons are suitably designated as **APB**, **BPB**, etc., corresponding to their respective signals **AG** and **BG**, etc. Each of these buttons is provided with signal indicator lamps which are illuminated under certain conditions more specifically described hereinafter.

In addition to the control buttons located at the points corresponding to signal locations, there is a cancel button **CANE**, a correspondence indication button **CRKB**, and suitable auxiliary switch control levers **1SML**, **2SML** and **3SML**.

The control panel also has the switches and signals suitably identified by letters and numbers, or other designations, which will provide a ready means of reference for the operator.

The control machine is provided with a "cancel bus" and an "entrance pick-up bus" which together with relays **NP**, **NPP** and **CAN** effect the control of the route establishing means on a sequence basis as hereinafter described in detail.

Each control button, such as **APB** has associated therewith certain relays which are more particularly identified with the corresponding signal location. For example, relays **ANR**, **AXL** and **AXS** are directly associated with the push button **APB**. The reference character **ANR** means that this relay is identified with signal location A, is an entrance relay governing traffic to the right, as contrasted with the reference character **CNL** for the relay associated with the button **CPB** which means that the relay **CNL** is associated with the signal C, and is an entrance relay governing traffic to the left.

The operation of each track switch or crossover is primarily governed by normal and reverse switch control relays, such as relays **1AN**, **1R**, and **1BN** associated with the track switches **1ATS** and **1BTS**. These primary switch control relays have associated therewith secondary switch control relays. In the first form of the invention (see Fig. 2), each track switch has associated therewith a secondary switch control relay such as relay **1AWZ** for the track switch **1ATS**, and such as relay **1BWZ** for track switch **1BTS**. In other words, each crossover is provided with two secondary switch control relays **WZ** while each single switch is, of course, provided with only a single secondary control relay **WZ**. In the second form of the invention (see Fig. 9), only a single secondary switch control relay, such as relay **1WZ**, is associated with both ends of the crossover **1ATS** and **1BTS**.

Route establishing means of Figs. 1A and 1B

Assuming that the operator desires to establish a route from A to C, he first depresses and releases the control button **APB** and then depresses and releases the control button **CPB**. This sequential actuation of two buttons at the opposite ends of a route causes the first operated control button to perform an entrance operation by picking up an entrance relay, such as relay **ANR**, while the second operated control button performs an exit operation by picking up an exit relay, such as relay **CXR**.

The energization of an entrance relay at one end of a route followed by the energization of an exit relay at the opposite end of such route causes the route establishing circuit means to properly select and establish a route connecting the two points corresponding to the operated control buttons. The route establishing circuit means is so organized as to prevent the establishment of a route already set up and to establish routes in the order of their superiority in the case of optional routes.

The route establishing circuit means comprises two conditioning circuit networks and a completion circuit network. One conditioning circuit network has feed points for each signal location at the left of the track layout and has circuit portions conforming to the track layout to the right from such signal locations, while the other conditioning circuit network has feed points for each signal location at the right end of the track layout and has circuit portions conforming to the track layout to the left from such signal locations. The completion circuit network also has circuit portions conforming to the track layout but has feed points for the signal locations at both ends of the track layout.

Upon the picking up of an entrance relay for one end of a desired route, energy is supplied to that conditioning circuit network having a feed point for the corresponding signal location, and this energization of such conditioning circuit network causes it to perform a preselecting operation for the switches and a conditioning operation for the exit relays with respect to all of the routes originating at such entrance signal location. This preselecting operation consists in the energization of the normal switch control relays for the switches in all routes originating at the designated entrance signal location, that would be trailed in normal positions, and the conditioning of the exit relays consists in preparing the exit relays for the exit ends of all such routes, which are available for use, to be energized by operation of their corresponding control buttons. The actuation of a control button for the exit end of a particular one of the available routes originating at the designated entrance signal location picks up the corresponding exit relay which applies energy to the conditioning circuit network having a feed point for that signal location, and such energization of that conditioning circuit network energizes the normal switch control relays for each of the track switches in that particular route which would be trailed in normal positions by a train traversing such route from the exit end, such operation being limited to that particular route by reason of the preselection effected by the prior energization of the other conditioning circuit network. Thus, the two conditioning circuit networks serve to energize the proper normal switch control relays to establish any given route, while the completion circuit network is energized only at the exit end of the designated route upon the picking up of the exit relay and thereby acts to energize the reverse switch control relays for any switches which require operation to their reverse positions for that given route. The switch controls as selected by the primary switch control relays N and R are executed to the secondary switch control relays WZ over circuits including in part the completion circuit network.

Following the operation of the track switches to proper positions in correspondence with their controls for the desired route, the signal at the

entrance end of such route, as defined by the picked-up condition of the entrance relay for such end, is caused to clear to allow the passage of a train.

5 We will now consider in detail the manner in which the system of the present invention responds to the sequential actuation of the buttons APB and CPB to effect the establishment of a route between the corresponding signal locations.

10 *Entrance storage.*—With the system in the normal condition illustrated in the drawings, the operation of the button APB (see Figs. 1A and 1B) closes a pick-up circuit for the entrance relay ANR from (+), through a circuit including the upper winding of relay NP, back contact 5 of relay NPP, "entrance pick-up bus," contact 6 of button APB in an actuated position, back contact 7 of relay AXL, lower winding of entrance relay ANR, to (-). The relays NP and ANR being energized in series have their contacts picked up at substantially the same time.

15 The picking up of the relay NP closes front contact 14 which applies positive energy (+) to the relay NPP through an obvious circuit. The response of relay NPP opens its back contact 5 and removes positive energy (+) from the "entrance pick-up bus" but connects such bus to negative potential (-), through front contact 5 of relay NPP. This removal of positive energy (+) from the "entrance pick-up bus" occurs only after an entrance relay, such as relay ANR, has had sufficient time to pick up and close a stick circuit. For example, relay ANR has a stick circuit closed from (+), through a circuit including normal contact 8 of button APB, front contact 9 of relay 1ATR, front contact 10 of relay ANR, upper winding of relay ANR, to (-). It is noted that this normal contact 8 of button APB is closed while such button is in its normal position or is in its depressed actuated position and is opened only when such button is pulled out for deenergizing an entrance relay, as will be hereinafter described.

20 Thus, when the operator releases the button APB, the relay ANR remains picked up and positive energy (+) has been removed from the "entrance pick-up bus" so that the actuation of the control button, CPB for example, cannot apply energy through its contact 19 to pick up the entrance relay CNL. This condition is indicated to the operator by the energization of the indicating lamp NPK which is energized through an obvious circuit including front contact 16 of relay NP.

25 It may be well to point out at this time that the actuation of the button APB under such normal conditions of the system cannot energize the exit relay AXL by closure of contact 22 in an actuated position because there is no energy being fed over the conditioning network to this exit relay.

30 *Preselecting and conditioning operations.*—The picking up of the relay ANR closes front contact 27 which applies positive potential (+) to the conditioning network having a feed point for signal AG. As this conditioning circuit network has circuit portions corresponding to the track layout for each of the possible routes emanating from the signal location A, conditioning energy is provided for the exit relay at the end of each of such possible routes which is then available for use, as well as effecting a preselecting operation for each of those track switches in such possible routes which would be trailed in a nor-

mal position by a train passing over any of those routes.

With reference to the track layout of Fig. 3, it will be seen that there are four possible routes emanating from the signal AG, namely, routes A to C, A to D via crossover 1, A to D via crossover 3, and A to E.

With reference to Figs. 1A and 1B, picked up relay ANR causes potential to be supplied from (+), through a circuit including front contact 27 of relay ANR, back contact 28 of relay 1R, wire 39, back contact 29 of relay 3R, back contact 530 of relay CNL, to the left-hand terminal of the exit relay CXR. This corresponds to the route from A to C.

Potential is also supplied from (+), through a circuit including front contact 27 of relay ANR, back contact 28 of relay 1R, wire 39, back contact 30 of relay 3AN, back contact 31 of relay 3BN, back contact 32 of relay DNL, to the left-hand terminal of the exit relay DXR. This corresponds to the route from A to D via the crossover 3.

Potential is also supplied from (+), through a circuit including front contact 27 of relay ANR, back contact 33 of relay 1AN, back contact 34 of relay 1BN, wire 40, back contact 35 of relay 2R, back contact 36 of relay 3R, upper winding of relay 3BN, to (-). This causes the picking up of the relay 3BN which opens at its back contact 31 the circuit corresponding to the route A to D via the cross-over 3 and closes front contact 31 of relay 3BN to pass energy on through back contact 32 of relay DNL, to the left-hand terminal of the exit relay DXR. This corresponds to the route from A to D via the crossover 1. Potential is also supplied from (+), through a circuit including front contact 27 of relay ANR, back contact 33 of relay 1AN, back contact 34 of relay 1BN, wire 40, back contact 37 of relay 2N, back contact 38 of relay ENL, to the left-hand terminal of the exit relay EXR. This corresponds to the route from A to E.

With positive potential supplied to the exit relay for the end of each of the possible routes emanating from the signal location A, then the operation of any given control button for a corresponding one of such exit relays to supply negative potential to that exit relay causes it to be picked up. This exit operation will presently be described in detail, but the effect of the non-availability of a route will first be mentioned.

For example, if a route from signal location B to signal location D is established or occupied by a train, the relays 1BN, 2N and 3BN are picked up (in a manner described later) opening back contacts 34, 37 and 31 respectively, thereby preventing the supply of positive potential to the exit relays DXR and EXR from the entrance signal location A.

Thus, it will be seen that positive potential is supplied to the exit relay at the end of each of the possible routes which are then available for use emanating from the signal location A, but in the case of optional routes eliminates the circuit portions for all such options except one. The manner in which this preselection of the optional routes is utilized will be discussed in detail later.

Exit operation.—When the operator actuates the button CPB, the closure of contact 19 of CPB cannot energize the relay CNL inasmuch as negative potential (-) is applied to the "entrance pick-up bus." However, with positive energy (+) applied to the left-hand terminal of the

relay CXR over the conditioning circuit network, the closure of the back contact 23 of button CPB connecting the right-hand terminal of relay CXR, to (-), causes such relay CXR to pick up and close its front contact 24 to complete a stick circuit over the conditioning network so that such relay remains energized irrespective of the release of the control button CPB.

The picking up of the relay CXR, while the control button CPB is still actuated, connects the "entrance pick-up bus" to the "cancel bus" which causes current to flow from (+), through a circuit including the lower winding of the cancel relay CAN, over the "cancel bus," back contact 21 of relay CXS, front contact 20 of relay CXR, contact 19 of button CPB in an actuated position, over the "entrance pick-up bus," front contact 5 of relay NPP, to (-).

The energization of the cancel relay CAN causes it to pick up and complete a stick circuit from (+), through the upper winding of relay CAN, front contact 17 of relay CAN, front contact 18 of relay NP, to (-).

Also, the picking up of relay CAN opens the back contact 12 in the stick circuit for relay NP which causes it to drop away.

The release of the relay NP opens its front contact 18 included in the stick circuit for the relay CAN. This allows the relay CAN to drop away immediately following the release of the particular control button then actuated for the exit end of a route, CPB in this instance. In other words, the continued operation of the control button CPB holds the relay CAN energized although the relay NP releases. This is made possible by reason of the closure of front contact 15 of relay CAN to maintain the relay NPP energized although the front contact 14 of relay NP is open.

Assuring that the operator actuates the control button CPB only momentarily for a sufficient time to pick up the exit relay CXR and the relay CAN, then the relay NP is released followed by the release of the relay CAN which in turn allows the relay NPP to drop away. With this sequence of operations, it will be noted that the last operation is the closure of the back contact 5 to apply positive potential (+) to the "entrance pick-up bus" ready for another entrance operation. This assures that any failure of the arrangement to completely follow through the proper sequence of operations following the designation of an available exit point, prevents further setting up of routes. However, the proper operation of a control button at the exit end of an available route following the operation of a control button at the entrance end of such route causes the picking up of the exit relay and the restoration of the "bus interlock arrangement" to normal.

Summary of bus interlock.—From the above description of the entrance and exit operations, it will be seen that the actuation of control button to designate an entrance point causes the entrance repeating relay NP to pick up in series with the entrance relay for the particular control button actuated. This entrance repeating relay NP in turn picks up a repeating relay NPP which removes positive potential (+) from the "entrance pick-up bus" so that the actuation of any other control button will not effect the energization of its entrance relay. However, the picking up of the relay NPP applies negative potential (-) to the "entrance pick-up bus" so that the actuation of a control button at the

exit end of an available route emanating from the entrance point corresponding to said particular control button causes the response of the exit relay for such exit end and the energization of the cancel relay CAN over the "cancel bus."

The cancel relay CAN opens the stick circuit of the entrance repeating relay NP at back contact 12 which in turn deenergizes the cancel relay CAN at front contact 18, and both such relays dropped away deenergize the relay NPP at front contacts 14 and 15 so that the "bus interlock arrangement" restores to normal. The indicator lamp NPK is illuminated only so long as the relay NP is picked up. Thus, the operator can definitely know that the exit point has been properly designated when the lamp NPK becomes dark.

If a control button is actuated for an exit operation at the end of some route which is not available for use, for reasons mentioned above, then the exit relay will not pick up, and the "bus interlock arrangement" does not restore to normal in the usual manner. The display of indications will be explained in detail in connection with Figs. 5A and 5B, but it is desired to point out at this time that the picked up condition of any entrance relay causes the flashing illumination of the indicator lamp within the corresponding control button. This continued flashing, when the operator fails to get a route upon the actuation of a button at the exit end of a possible route, taken in connection with the fact that the indicator lamp NPK is illuminated, causes the operator to be advised of this inability to obtain the route and he must act in accordance therewith to restore the system to normal.

The operator first cancels his entrance operation by pulling the particular control button having the flashing illumination. For example, the pulling of the button APB opens the contact 8 and deenergizes the stick circuit of the relay ANR so that its associated indicating lamp AGK is deenergized (see Fig. 5B). The operator must still restore the "bus interlock arrangement" to normal. To do this, he actuates the cancel button CANB which opens front contact 13 deenergizing the stick circuit of the entrance repeating relay NP and restoring the "bus interlock arrangement" to normal conditions.

Completion operation.—Having considered how the "bus interlock arrangement" of circuits cooperates with a conditioning network to provide that single buttons perform both entrance and exit operations, the manner in which the picking up of the exit relay at the exit end of an available route effects the completion operation will now be considered.

As previously mentioned, the route establishing circuit means includes two conditioning networks, one for each direction of route build-up. Each of these networks has feed points for the signal locations governing traffic in that direction corresponding to the direction of build-up for that network. As above explained, the entrance operation performed for a signal located at one end of the track layout causes the application of positive potential (+) to the conditioning network having a feed point for the corresponding signal location, and thereby conditions all of the possible routes emanating from such signal location. But if the entrance operation is performed for a signal located at the opposite end of the track layout, the other conditioning network is supplied with positive poten-

tial (+) at its feed point for the corresponding signal location, and similarly conditions all of the possible routes emanating from such signal in the opposite direction.

5 Not only are these conditioning networks used for conditioning or preselecting the possible routes which may be set up from any given entrance point, but they are also employed for in part completing any given one of such possible routes. The same circuit portions corresponding to the track layout in a conditioning network are used in its completing operation with respect to a particular one of the possible routes emanating from any given signal location, but only those circuit portions of the conditioning circuit network corresponding to that particular route are energized by reason of the preselection conditioning effected by the other conditioning network upon the entrance operation.

20 Simultaneously with the application of positive energy (+) to the conditioning network through a front contact of an exit relay for the completion operation, positive energy (+) is also supplied to the completion circuit network for energizing any reverse control relays R that may be required for the particular route designated. In other words, the remaining normal switch control relays to be energized to set up the particular defined route are energized over the conditioning network having a feed point for the exit signal location while the reverse switch control relays are energized for such route over a separate completion circuit network receiving energy from a feed point also corresponding to the designated exit signal location.

25 More specifically, the picking up of the exit relay CXR in response to the actuation of the button CPB following the entrance operation of the button APB, applies energy from (+) through a circuit including front contact 41 of relay CXR, back contact 42 of relay CNL, back contact 43 of relay 3R, upper winding of relay 3AN, to (-).

30 35 The picking up of the relay 3AN passes energy on through its front contact 44, wire 59, back contact 45 of relay 1R, upper winding of relay 1AN, to (-).

40 The picking up of contact 46 of the relay 1AN would pass energy on to any other switch which might be in the route, but in this particular embodiment there being no other switches energy cannot be passed on further by reason of the open condition of back contact 60 of entrance relay ANR.

45 Simultaneously with the application of energy through front contact 41 of relay CXR, positive potential (+) is applied through its front contact 47 to the completion network for the reverse relays. It will be noted that the route from A to C does not include any track switches to be operated to their reverse positions so that no reverse relay is energized by the closure of front contact 47 in this particular instance. An example of the completion network energizing a reverse relay will be pointed out in the consideration of the optional route selection.

50 55 *Switch execution.*—At the same time that energy is applied through front contact 47 of relay CXR for completing the route by operation of any reverse switch control relays that may be required for the designated route, the same completion network is in part used for executing the switch controls to the secondary switch control relays WZ. This execution for the switches can-

not occur until the particular route connecting the designated entrance signal location with the designated exit point has been predetermined or preselected by the conditioning operation so that the energy which feeds from the exit end passes over only the circuit portions of the completion circuit network corresponding to the particular route desired.

For example, the picking up of the relay 3AN closes an executing circuit for the switch control relay 3AWZ from (+), through a circuit including front contact 47 of relay CXR, front contact 48 of relay 3AN, asymmetric unit 49, wire 50, front contact 51 of relay 3AN, lower winding of relay 3AWZ, back contact 52 of relay 3R, to (-).

The picking up of the relay 3AWZ causes the operation of the track switches 3ATS and 3BTS to normal positions as will be typically described in connection with Fig. 2.

The picking up of the relay 3AN and closure of front contact 48 closes the completion circuit portions corresponding to the route so that the picked up condition of the relay 1AN completes an execution circuit for relay 1AWZ from (+), through a circuit including front contact 47 of exit relay CXR, front contact 48 of relay 3AN, wire 53, front contact 54 of relay 1AN, asymmetric unit 55, wire 56, front contact 57 of relay 1AN, lower winding of relay 1AWZ, back contact 58 of relay 1R, to (-). The picking up of the relay 1AWZ causes the operation of the track switches 1ATS and 1BTS to normal positions as will be typically described in connection with Fig. 2.

Typical switch control (Fig. 2).—Inasmuch as the switch controls for the various switches and crossovers of a track layout are substantially the same, the control for only the crossover 1 (having the switches 1ATS and 1BTS) has been shown in Fig. 2 as typical of the control for the remaining switches of the track layout. As will be explained more in detail in connection with the route locking, each of the track sections have associated therewith east and west directional stick relays ES and WS, a lock relay LR, and the usual detector track relay TR. Each lock relay LR has included in its energizing circuits front contacts of its associated directional stick relays ES and WS and its associated detector track relay TR. Its pick-up circuit includes a normally closed contact on the auxiliary switch control lever SML for each of the track switches included in its associated track section.

This has been typically illustrated in Fig. 2 by showing the lock relay 1ALR having an energizing circuit closed from (+), through a circuit including contact 119 of lever 1SML in a normal position, winding of relay 1ALR, front contact 118 of relay 1AWS, front contact 117 of relay 1ATR, front contact 116 of relay 1AES, to (-). The picking up of the relay 1ALR closes its front contact 120 which shunts out the lever contact 119.

Similar energizing circuits are provided for the relay 1BLR as will be obvious from the drawing, the only difference being that its front contact 275 applies positive energy (+) to shunt out the lever contact 276 of lever 2SML and lever contact 277 of lever 1SML.

The primary switch control relays 1AN, 1R and 1BN have been repeated from Fig. 1A and have been shown in their normally deenergized positions. Also associated with each track switch or crossover is a lock stick relay specifically shown as relay 1LS for the crossover 1 under consideration. This lock stick relay 1LS is normally energized from (+), through a circuit including front

contact 69 of lock relay 1BLR, front contact 70 of lock relay 1ALR, back contact 71 of relay 1BWZ, back contact 72 of relay 1AWZ, windings of relay 1LS, to (-). This normal energization of the lock stick relay 1LS permits the energization of a switch control relay, such as relay 1AWZ, to immediately operate the switch machines 1ASM and 1BSM if the track switches are not in corresponding positions.

10 During the establishment of a route the relay 1AWZ and/or relay 1BWZ is picked up opening the respective back contacts 71 and/or 72, but the relay 1LS is maintained energized by reason of its stick circuit including contacts 73, 74 and 75 which shunt out the contacts 71 and 72 when the relay 1LS is picked up. It will be seen that this stick circuit is maintained closed until the track switches 1ATS and 1BTS are operated into correspondence with the secondary switch control relays 1AWZ and 1BWZ at which time either the relay 1NCR or the relay 1RCR is picked up to open the stick circuit for the relay 1LS and cause it to be deenergized to open its front contacts 64, 65 and to close back contact 65 thereby opening and shunting the switch machine control circuits to protect them against further operation. This deenergization of the lock stick relay 1LS also effects the closing of the signal clearing circuits at its back contacts (see Fig. 3).

Having considered certain of the general aspects of the switch control circuits of Fig. 2, consideration will now be given to the manner in which the energization of the relay 1AWZ, described in connection with Figs. 1A and 1B, effects the operation of the track switches.

The energization of the relay 1AWZ causes energy to be applied from (+), through a circuit including polar contact 61 of relay 1AWZ in a right-hand position, front contact 62 of relay 1AWZ, back contact 63 of relay 1BWZ, front contact 64 of relay 1LS, operating windings of the switch machines 1ASM and 1BSM connected in multiple, front contact 65 of relay 1LS, back contact 66 of relay 1BWZ, front contact 67 of relay 1AWZ, polar contact 68 of relay 1AWZ in a right-hand position, to (-). The energy which flows in this circuit causes the switch machines 1ASM and 1BSM to unlock their respective track switches 1ATS and 1BTS and cause their operation to normal locked positions (assuming that such track switches were in the reverse position, but of course causing no operation if the track switches are already in normal locked positions, as shown).

55 It is, of course, understood that if some other route were being established than that being considered in connection with Figs. 1A and 1B, which required the operation of the track switches 1ATS and 1BTS to reverse positions, both of the secondary switch control relays 1AWZ and 1BWZ would be energized. In view of the fact that the energy supplied to the switch machines by relay 1AWZ includes back contacts 63 and 66 of relay 1BWZ, under such circumstances the relay 1BWZ would effect the control of the switch machines by applying the required polarity to their operating circuits.

Assuming the track switches 1ATS and 1BTS to have been operated to normal positions in correspondence with the relay 1AWZ energized to a normal controlling position, as above described, the relay 1NCR is energized by a circuit closed from (+), through a circuit including front contact 76 of relay 1AWZ, polar contact 77 of relay 1AWZ in a right-hand position, windings of re-

lay 1NCR, polar contact 78 of relay 1WP in a left-hand position, front contact 79 of relay 1WP, to (-).

When the track switches 1ATS and 1BTS have been operated to reverse positions in correspondence with the reverse energization of the both at the relays 1AWZ and 1BWZ, energy is applied to the left-hand terminal of the relay 1NCR from (+), through front contact 76 of relay 1AWZ, polar contact 77 of relay 1AWZ in a left-hand position, in multiple with energy from (+), through front contact 93 of relay 1BWZ, polar contact 94 of relay 1BWZ in a left-hand position, to the left-hand terminal of relay 1RCR; while the right-hand terminal of the relay 1RCR is connected to (-), through polar contact 78 of relay 1WP in a right-hand position and front contact 79 of relay 1WP.

It should also be noted that when the track switches 1ATS and 1BTS are operated to normal positions in correspondence with the normal energization of the relay 1BWZ, the relay 1NCR is energized from (+), through a circuit including front contact 93 of relay 1BWZ, polar contact 94 of relay 1BWZ, in a right-hand position, winding of relay 1NCR, polar contact 78 of relay 1WP in a left-hand position, front contact 79 of relay 1WP, to (-).

While the track switches 1ATS and 1BTS are being operated by their respective switch machines 1ASM and 1BSM upon the energization of relay 1AWZ and/or 1BWZ, such operation is assured of completion, irrespective of the deenergization of the primary switch control relays 1AN, 1R and 1BN, by reason of a stick circuit closed for the particular secondary switch control relay WZ then effecting the operation. For example, if the relay 1AWZ has been effecting the operation, it is maintained energized by a stick circuit closed from (+), through a circuit including back contact 80 of relay 1WP, front contact 81 of relay 1AWZ, polar contact 82 of relay 1AWZ in a right-hand position, upper winding of relay 1AWZ, polar contact 83 of relay 1AWZ in a right-hand position, to (-). It will of course be understood that if the relay 1AWZ is energized to a reverse position and the track switches are being operated to reverse positions, the polar contacts 82 and 83 will be in left-hand positions and pole change the direction of current in the upper winding 1AWZ and similarly maintain such relay energized until the track switches are operated to the reverse positions and locked causing the energization of the relay 1WP and the opening of back contact 80.

In a similar manner, if the operation of the switch machines is being effected by the energization of the relay 1BWZ, such operation is continued to completion irrespective of deenergization of the primary switch control relays 1AN, 1R and 1BN by reason of a stick circuit for the relay 1BWZ closed from (-), through a circuit including back contact 95 of relay 1WP, front contact 96 of relay 1BWZ, polar contact 97 of relay 1BWZ in a right-hand position, upper winding of relay 1BWZ, polar contact 98 of relay 1BWZ in a right-hand position, to (-). It will of course be understood that if the relay 1BWZ is energized to a reverse position and the track switches are being operated to reverse positions, the polar contacts 97 and 98 will be in left-hand positions to pole change the direction of current in the upper winding of relay 1BWZ and also maintain such relay energized until the track switches are operated to the reverse positions as

indicated by the energization of relay 1WP and the opening of back contact 95.

It should be pointed out at this time, however, that the execution circuit for the secondary switch control relays 1AWZ and 1BWZ is maintained energized upon the establishment of a route, so that the stick circuits including back contacts 80 and 95 of relay 1WP are required for the completion of a track switch operation only in the event that the route establishing means should be restored to normal inactive conditions before the operation of the track switches has become completed.

After a route has been set up and a signal cleared, as will presently be described, the relay 1ALR is deenergized closing back contact 99 which applies positive potential (+) to the stick circuit for the relay 1AWZ to maintain such relay energized so long as the track switch 1ATS is locked, that is, so long as a route is set up over such track switch and the signal cleared or so long as such route is occupied by a train. While the route is occupied by a train, the execution circuit for the relay 1AWZ is deenergized by the dropping of the exit relay, as will be presently explained, so that the continued energization of the relay 1AWZ is maintained through its stick circuit for the purpose of maintaining indications displayed on the track diagram in a manner which will be later explained in detail.

Various other features of the typical switch control will be considered in detail in connection with the auxiliary manual operation of the track switches.

Signal control circuits (Fig. 3).—Assuming that all of the track switches have properly responded to the energization of their switch control relays WZ, that their respective correspondence relays are energized, and that their respective lock stick relays are deenergized, a circuit is then closed for clearing the signal at that end of the route designated as the entrance end. The particular route A to C under consideration includes the track switches 1ATS and 3ATS in normal positions, so that the relays 1NCR and 3NCR (see Fig. 3) are energized while the relays 1LS and 3LS are deenergized. The entrance relay ANR is picked up as above pointed out so that a circuit is closed for the energization of the signal control relay AGR from (+), through a circuit including back contact 84 of relay CGR, back contact 85 of relay CNR, back contact 86 of relay 3RCR, front contact 87 of relay 3NCR, back contact 88 of relay 3LS, back contact 89 of relay 1RCR, front contact 90 of relay 1NCR, back contact 91 of relay 1LS, front contact 92 of relay ANR, windings of relay AGR, to (-). The picking up of contact 293 of signal control relay AGR causes the signal AG to change its indication from stop to clear so that a train may accept such signal and pass over the route established, as above explained in detail.

Route locking.—The route locking contemplated for use with the embodiment of the present invention is of the directional rear releasing type. That is, the clearing of a signal for a particular direction effects the locking of all the track switches in the route established, while the acceptance of such signal by a train entering that route continues to cause all of the track switches in advance of the train to remain locked irrespective of the return to stop of the governing signal, but as the train passes beyond the respective track sections of that route, such sections are released for use in other routes al-

though those sections in which the train is located and those sections in advance of the train remain locked. This type of route locking requires east and west directional stick relays ES and WS for each of the track sections as well as a lock relay LR for each of such sections. In some cases suitable selections may be made so as to eliminate some of the relays depending upon the track layout and the situations encountered in practice.

This type of release route locking has been disclosed in prior patents such as Patent No. 2,115,511 dated April 26, 1938 and in the Patent No. 2,125,242 dated July 26, 1938, however the relays and circuits employed to accomplish such locking for the present embodiment of the invention have been shown in Fig. 4 for the purpose of clarifying the complete operation of the system.

With reference to Fig. 4, it will be seen that the signal control relays GR, one for each of the signals of Fig. 3, are shown in block form at the right and left of Fig. 4 according to the location of their respective signals to the right or left ends of the track layout. The switch position repeating relays WP and also the track relays TR have been shown in block form. The circuits for the directional stick relays have been shown in detail and these relays are normally energized through circuits readily apparent from the drawings, but in order to make the description entirely clear, the operation of these directional stick relays will be pointed out in detail with regard to the route from A to C which has been given more specific consideration above.

The directional stick relay 1AES for track section 1AT, is normally energized by a circuit closed from (+), through a circuit including back contact 101 of signal control relay AG, front contact 102 of track relay 1ATR, and winding of relay 1AES, to (-). The front contact 103 of relay 1AES provides a shunting stick circuit around the track contact 102.

The directional stick relay 3AES for the track section 3AT, is normally energized by a circuit closed from (+), through a circuit including front contact 104 of relay 1AES, front contact 105 of relay 3ATR, and winding of relay 3AES, to (-). The front contact 106 of relay 3AES provides a shunting stick circuit around the track contact 105.

The directional stick relay 3AWS for the track section 3AT is normally energized from (+), through a circuit including front contact 107 of relay 3WP, polar contact 108 of relay 3WP in a left-hand normal position, back contact 109 of relay CG, front contact 110 of relay 3ATR, and winding of relay 3AWS, to (-). The front contact 114 of relay 3AWS provides a shunting stick circuit for the track contact 110. The front contact 115 of relay 3BWS also supplies positive potential (+) to the heel of contact 109 of relay CG, which provides that the relay 3AWS is dependent upon the directional stick relay 3BWS when the track switches 3ATS and 3BTS are reversed causing the polar contact 108 of relay 3WP to be in a right-hand position.

The directional stick relay 1AWS for track section 1AT is normally energized by a circuit closed from (+), through a circuit including front contact 111 of relay 3AWS, front contact 112 of relay 1ATR, and winding of relay 1AWS, to (-). The front contact 113 of relay 1AWS provides a shunting stick circuit for the track contact 112. It will be obvious from Fig. 4 that

the remaining directional stick relays have similar circuits.

Each of the lock relays is normally energized. For example, the lock relay 1ALR is normally energized from (-), through a circuit including front contact 116 of relay 1AES, front contact 117 of relay 1ATR, front contact 118 of relay 1AWS, winding of relay 1ALR, (see Fig. 2), and contact 119 of auxiliary switch control lever 1SML in a center position, (see Fig. 2) to (+). The front contact 120 of the relay 1ALR provides a shunting stick circuit for the auxiliary switch control lever contact 119.

Each of the lock relays has a similar energizing circuit including the directional stick relays for its track section, a track contact and a center contact of the auxiliary switch control lever for each track switch in the associated track section. These circuits have been shown in detail in Fig. 2 for the lock relays 1ALR and 1BLR, and have been shown in part for the remaining lock relays 3ALR and 3BLR. It is noted that the track switch 2TS is included in the same track section with the track switch 1BTS so that the conditions under which it should be locked are the same as for the track switch 1BTS. Thus, no separate lock relay has been shown for the track switch 2TS although it could be provided.

The clearing of a signal, such as the signal AG by reason of the energization of its controlling relay AG, causes the directional stick relays 1AES and 3AES to be successively deenergized by reason of the opening of contacts 101 and 104 in succession. However, the directional stick relays 1AWS and 3AWS are maintained energized.

This dropping of the lock relays for the several track switches in the route causes the secondary switch control relays WZ for such switches to be maintained energized. For example, with reference to Fig. 2 the relay 1AWZ has positive (+) energy applied to its stick circuit through back contact 99 of relay 1ALR. The direction of current flow in this stick circuit is of course determined by the position of polar contacts 82 and 83 of the relay 1AWZ as initially energized. A similar stick circuit is provided for the WZ relay of each of the remaining track switches.

The dropping of these lock relays upon the clearing of a signal for an established route also effects the locking of the primary switch control relays, as shown in Fig. 2. For example, the relay 1AN is energized by a stick circuit closed from (+), through a circuit including back contact 121 of relay 1ALR, front contact 122 of relay 1AN, lower winding of relay 1AN, back contact 123 of relay 1R, to (-). In a similar manner each of the remaining primary switch control relays for an established route is energized through a similar stick circuit including a back contact of its associated lock relay LR.

Passage of a train.—As a train accepts the signal AG, it enters the track section 1AT deenergizing its track relay 1ATR. This deenergizes the entrance relay ANR by opening contact 9 (see Fig. 1A). The deenergization of the entrance relay ANR in turn deenergizes the exit relay CXR by reason of the open condition of front contact 27. Although both the entrance and exit relays are deenergized, the primary switch control relays 1AN and 3AN are maintained energized by reason of their holding stick circuits energized through the back contacts of their respective lock relays as described in connection with the relay 1AN of Fig. 2. Also the respective

secondary switch control relays WZ are maintained energized by their respective stick circuits controlled by their associated lock relays.

The deenergization of the entrance relay ANR also causes the signal control relay AGR to be deenergized which returns the signal AG to stop (see Fig. 3). Although back contact 101 of relay AGR (see Fig. 4) is closed, the relay 1AES remains deenergized because contact 102 is opened by reason of the presence of the train. It may be noted here that front contact 112 is also opened but the relay 1AWS does not become deenergized but reason of its shunting stick circuit including front contact 113. Inasmuch as the relay 3AES is energized through a front contact 104 of relay 1AES it remains deenergized.

The passage of the train into the track section 3ATR opens front contact 105 maintaining the relay 3AES deenergized although the relay 1AES becomes energized as soon as the track relay 1ATR picks up closing front contact 102.

With the train entirely in the track section 3AT, the track switches 1ATS and 1BTS are released for operation as the contacts 116 and 117 included in the circuit of the lock relay 1ALR are now closed.

When the train entirely passes out of the route it is obvious that the closure of front contact 105 of relay 3ATR allows the directional stick relay 3AES to pick up and the track switches 3ATS and 3BTS are available for operation to provide any route including such switches.

Manual restoration.—It is readily apparent that the route establishing means is initially established by operation of a control button to designate an entrance signal location followed by the operation of a control button to designate an exit signal location, but the continued effectiveness of the route establishing means is thereafter wholly dependent upon the continued energization of the entrance relay for that route. With reference to Fig. 1A, it is seen that the stick energization of the entrance relay ANR is dependent upon the closed condition of track contact 9 and the control button contact 8. As above described, the entrance of a train opens track contact 9 and deenergizes the entrance relay, restoring the system to normal conditions in due course as the train passes through the route.

However, if a train should not accept the signal AG or if the operator desired to return the signal to stop and restore the route establishing means to normal conditions prior to the entrance of a train into an established route, he could do so by merely pulling the control button APB to open the normally closed contact 8 of this button. Such operation of the control button deenergizes the stick circuit of its associated entrance relay causing the system to restore to normal.

Although a system of this type should always provide that a clear signal may be returned to stop at any time by the operator, it is usually expedient to provide what is termed approach locking to prevent the release of the route which was governed by such clear signal until after a predetermined time if there is a train approaching such signal. These features of approach locking have not been shown, but may be applied to the present invention in any suitable way and have been disclosed in one form in the above mentioned Patent No. 2,125,242 dated July 26, 1938.

It is considered sufficient for an understanding of how such features may be applied to the

present invention, to state that means is provided which is effective upon the deenergization of the relay AGR, for example, (see Fig. 4), to prevent energy from being supplied to the pick-up circuit for the directional stick relays until after a predetermined time has elapsed, if there is a train approaching the signal AG. In other words, the approach of a train delays the restoration of the route locking after the manual return of a signal to stop for a time sufficient to allow the train to enter the route and cause the detector locking to become effective or to allow the train to come to a stop ahead of the signal location.

Display of indications (Figs. 5A and 5B).—For the purpose of making it easy to consider the display of indications, the control panel illustrated in Fig. 1A has also been illustrated in Fig. 5A. The control buttons, as above mentioned, include indicator lamps for displaying the condition of their associated signals, while each of the illuminated strips of the miniature track diagram includes two indicator lamps, namely, one white lamp and one red lamp. Associated with each of the auxiliary switch machine control levers SML is a correspondence lamp CRK. Normally all of these indicator lamps are deenergized, presenting what has been conveniently termed "a normally dark board" to the operator.

With reference to Fig. 5B, the operation of the button APB, as above described, to designate an entrance signal location effects the picking up of the entrance relay ANR which closes a circuit for the signal indicator lamp AGK from (BX), through a circuit including interrupter contact 124, back contact 125 of signal indication relay AGKR, front contact 126 of relay ANR, and indicator lamp AGK, to (CX). Inasmuch as the interrupter contact 124 is alternately opened and closed at a predetermined rate by the operation of the interrupter motor M, the signal indicator lamp AGK located in the button APB is intermittently flashed. This advises the operator that his actuation of the control button has designated an entrance signal location for which the entering signal has not yet been cleared.

Upon the clearing of the signal by the energization of the signal control relay AGR (see Fig. 3), the closure of front contact 127 energizes the signal indication relay AGKR which has been shown in block form in Fig. 5B. This shifts the control of the indicator lamp AGK from back point 125 of relay AGKR to front point 125 to connect the lamp to a continuous supply of alternating current (BX). Thus, the indicator lamp AGK is steadily illuminated advising the operator that the associated signal AG has been cleared.

It will be readily apparent that the entrance of a train into a route emanating from such signal location, or the restoration of the route to stop by the pulling out of the control button APB, results in the deenergization of the entrance relay ANR which in turn causes the indicator lamp AGK to be deenergized. The control of each of the signal indicator lamps for the remaining control buttons is similar to the control provided for lamp AGK.

When a route is established, it is desired that such route be indicated to the operator by illumination of the portions of the miniature track diagram corresponding to the actual route. For convenience in considering these different portions of the routes provided by the particular track layout chosen for the present embodiment, miniature track portion which is in a

facing position with regard to the track switch **1ATS** has been designated as miniature track portion **1AN/RK** to imply that the lamps associated with that portion are illuminated whenever that track switch is either normal or reverse in an established route. Similarly, the track portion which corresponds to the trailing portion or the normal position of the track switch **1ATS** has been designated as **1ANK**, while the reverse portion common to the track switches **1ATS** and **1BTS** has been designated as **1RK**. Each of these miniature track portions has two lamps associated therewith, namely, a white lamp **W** and a red lamp **R**. From this it will be seen that ready reference may be made to the various indicator lamps of Fig. 5A and know immediately by their particular reference characters what track portion they are associated with.

As above mentioned, the designation of an entrance signal location, such as signal **AG**, by the operation of the control button **APB**, effects the illumination of only the indicating lamp **AGK** and none of the miniature track portions are illuminated, but when the operator designates an exit signal location such as by the operation of the button **CPB** above considered, the primary switch control relays assume their proper positions and the secondary switch control relays are energized upon the execution of the switch controls as above described. These primary and secondary switch control relays are then used to select the energizing circuits for the several indicator lamps for the track portions in the particular route designated in a manner that only the indicator lamps for such route are energized.

More specifically, for a route from location **A** to location **C**, the relays **1AN**, **3AN**, **1AWZ** and **3AWZ** are energized, in a manner above described in detail. This illuminates the white lamp **W** of the track indicating portion **1AN/RK** by reason of a circuit closed from **(BX)**, through a circuit including front contact **128** of relay **1AWZ**, front contact **129** of relay **1AN**, front contact **130** of relay **1ATR**, and indicator lamp **W** of the indicator **1AN/RK**, to **(CX)**.

The circuit is closed for the indicator lamp **W** of the track indicating portion **1ANK** from **(BX)**, through a circuit including front contact **128** of relay **1AWZ**, front contact **131** of relay **1AN**, front contact **132** of relay **1ATR**, and white lamp **W** of track portion **1ANK**, to **(CX)**.

The white lamp **W** of the indicator track portion **3AN/RK** is energized by a circuit from **(BX)**, through a circuit including a front contact **133** of relay **3AWZ**, front contact **134** of relay **3AN**, front contact **135** of relay **3ATR**, and indicator lamp **W** of track portion **3AN/RK**, to **(CX)**.

A circuit is closed for the white lamp **W** of track indicating portion **3ANK** from **(BX)**, through a circuit including front contact **133** of relay **3AWZ**, front contact **136** of relay **3AN**, front contact **137** of relay **3ATR**, and indicator lamp **W** of track portion **3ANK**, to **(CX)**. Thus it is seen that the established route between **A** and **C** is indicated by the illumination of the miniature track portions corresponding to that route.

Upon the entrance of a train into the track section **1AT**, the entrance relay **ANR** is deenergized, as above explained, causing the indicator lamp **AGK** to be extinguished, but the illumination of the track portions **1AN/RK**,

1ANK, **3AN/RK** and **3ANK** is maintained by reason of the continued energization of the relays **1AWZ**, **1AN**, **3AWZ** and **3AN** through their stick circuits as controlled by the lock relays **5 ALR** and **3ALR** (see Fig. 2). The illumination of the track indicating portions **1AN/RK** and **1ANK** is shifted from white lamps **W** to red lamps **R** by the contacts **130** and **132** of the track relay **1ATR**. This will be obvious from a consideration of Fig. 5A.

When the train moves into the track section **3AT**, the illumination of the track portions **3AN/RK** and **3ANK** is shifted to their red indicator lamps **R** by reason of the closure of back contacts **135** and **137** of relay **3ATR**. When the train entirely moves out of the track section **1AT**, the lock relay **1ALR** is picked up deenergizing the relays **1AWZ** and **1AN** so that the indicator lamps of the miniature track portion **1AN/RK** and **1ANK** become extinguished, thus advising the operator that such track portions can be used for some other route such as from **A** to **B**, for example.

Similarly, when the train moves entirely out of the track section **3AT**, the miniature track portions **3AN/RK** and **3ANK** have their indicator lamps extinguished by reason of the deenergization of the relays **3AWZ** and **3AN**.

It may be well to again mention that the indicator lamp **NPK** of Fig. 1A is energized between the entrance operation and the exit operation of any pair of control buttons. This indicator lamp **NPK**, which is preferably included within the cancel button **CANB** shown in Figs. 1A and 5A, enables the operator to determine whether any particular operation of a button is to act as an entrance operation or an exit operation.

During the operation of a track switch from one position to another due to the energization of its **WZ** relay, such track switch is either unlocked or is out of correspondence with the **WZ** relay controlling it. This may happen either while a route is being established by the entrance-exit manipulation of the control buttons for the signal locations, or while the track switch is being operated from one position to another by its associated auxiliary control lever **SML**. In either case, the track switch may stall in mid-stroke thus failing to allow the completion of a route, and the operator may desire to know what particular switch is causing the trouble. Under such circumstances, all that is necessary to ascertain which particular track switch is still in mid-stroke is for the operator to actuate the correspondence indicating button **CRKB** (see Fig. 1A or Fig. 5A together with Fig. 2).

The actuation of this button **CRKB** applies energy to the correspondence circuits between the **WZ** and **WP** relays for the several track switches of the track layout so that the correspondence lamp **CRK** is illuminated for any one or more of those track switches which are still in mid-stroke or out of correspondence with their secondary control relays **WZ**. The control for such a correspondence lamp has been typically illustrated in Fig. 2 of the accompanying drawings. Let us assume that the track switches **1ATS** and **1BTS** are being operated to reverse positions by the energization of both the relays **1AWZ** and **1BWZ**, and that the operator depresses the button **CRKB**. An energizing circuit is closed for the indicator lamp **1CRK**, as soon as the relays **1AWZ** and **1BWZ**

are picked up and before the switches are unlocked dropping relay IWP , from (+), through a circuit including the back point of button CRKB , front contact 138 of relay IWP , polar contact 139 of relay IWP , polar contact 140 of relay IBWZ in a left-hand position and front contact 141 of relay IBWZ , indicator lamp ICRK , to (-). Also, polar contact 142 of relay IAWZ and front contact 143 of relay IAWZ provides a circuit in multiple with contacts 140 and 141 , respectively.

When the track switch IWP becomes unlocked and in mid-stroke as indicated by the deenergization of relay IWP , back contact 138 applies energy directly from the "correspondence indication bus" to the indicator lamp ICRK in an obvious manner.

On the other hand, assuming the track switches IATS and IBTS to be in reverse positions, either the energization of the relay IAWZ or the energization of relay IBWZ to normal positions, depending upon the particular end of the crossover to be included in a route, results in an out-of-correspondence condition with the relay IWP and provides an obvious energizing circuit for the indicator lamp ICRK upon the actuation of the button CRKB .

This organization of control for the correspondence lamps of the several track switches of a track layout has the advantage that the individual transit conditions of the track switches as they are being operated to set up routes are not indicated to the operator except at such times as such transit conditions are desirable or necessary. In other words, the illumination of the track indicating portions for the route being established is sufficient information for the operator, taken with the clearing of the signal, to advise him that such route can be accepted by a train except under those circumstances where the designated route fails to become established and in such cases provision is made in accordance with the present invention whereby he may ascertain which switch or switches are responsible for the failure of the route to become established. Although the button CRKB is preferably of the self-restoring type, it should be noted that it can be of the stay-where-put type if desired.

Individual control of track switches (Fig. 2).—There are times when it may be desirable for the operator to cause the individual operation of a particular track switch or several track switches of the track layout to free them from snow and ice, or from some other obstruction, or to allow the passage of a hand car or the like. Also, there may be occasions when it is desirable for the operator to set particular switches in particular positions and so act upon the primary switch control relays of the route establishing means that those positions may be maintained and predominate in the establishment of routes in the entrance-exit manipulation of the control buttons. This may be desirable for the selection of optional or alternative routes between common entrance and exit points. The present invention anticipates such conditions and provides that each of the track switches or crossovers is provided with an auxiliary control lever SML for operating it to the desired position through the energization of the primary switch control relays, such as relays IAN , IR and IBN , for example, as typically shown in connection with the track switches IATS and IBTS of Fig. 2. These auxiliary switch machine control levers SML are normally in center positions and are operated

to the right or to the left for normal and reverse operation of their respective track switches.

With reference to Fig. 2, the operation of lever ISML to the right closes an energizing circuit 5 for the relay IAN from (+), through a circuit including lever contact 144 in a left-hand position, lower winding of relay IAN , and back contact 123 of relay IR , to (-). At the same time a circuit is closed for the relay IBN from (+), through a circuit including lever contact 145 in a left-hand position, lower winding of relay IBN , back contact 123 of relay IR , to (-).

On the other hand, if the lever ISML is operated to the left, an energizing circuit is closed for the relay IR from (+), through a circuit including lever contact 144 in a right-hand position, back contact 146 of relay IAN , lower winding of relay IR , and back contact 147 of relay IBN , to (-).

20 The individual operation of a track switch occurs at a time when no energy is being supplied to the switch control execution circuits so that additional means must be provided to effect the energization of the secondary switch control relays WZ . For example, when the lever ISML is operated to a normal controlling position, energy is applied to the relay IAWZ by a circuit closed from (+), through a circuit including lever contact 149 in a left-hand position, front contact 51 of relay IAN , lower winding of relay IAWZ , and back contact 58 of relay IR , to (-). At the same time the relay IBWZ is energized by a circuit closed from (+), through a circuit including lever contact 148 in a left-hand position, front contact 149 of relay IBN , lower winding of relay IBWZ , and back contact 150 of relay IR , to (-). Inasmuch as the relay IBWZ has its controlling contacts for the switch machine ISM in a preferred position in the chain interlock between the 40 two relays, it is that relay which effects the normal operation of the switch machine ISM . However, this is immaterial as the chain interlock might just as well be reversed and the relay IAWZ be made the superior relay.

45 If on the other hand, the lever ISML is operated to a reverse controlling position then the relay IR is energized and the relays IAWZ and IBWZ both receive energy in the opposite direction by reason of the closure of front contacts 58 and 150 , while negative potential is applied through back contacts 57 and 149 . This operation will be readily apparent from the drawings. It may now be seen that the asymmetric units such as unit 55 are provided for the purpose of preventing energy which is applied to the relays WZ by the operation of an auxiliary switch control lever SML from flowing outward over the completion and execution circuit network. Although asymmetric units, such as rectifier unit 55 , adequately provide this feature, such units may have substituted therefor additional center contacts on the switch machine control levers which open the circuits connecting the completion network with the relays WZ at points corresponding to the location of the asymmetric units.

70 During the individual operation of each of the track switches, the operator can determine when such track switch has completed its operation by merely actuating the correspondence indicator button CRKB which illuminates the correspondence lamp ICRK for that switch only while it is in operation. It should be noted that the energization of the primary and secondary switch control relays by the actuation of a switch lever SML to a normal or a reverse position also causes

the corresponding track indicating portions on the miniature track diagram to be illuminated so that the operator readily knows the position to which the switches are being operated. Such lamps remain illuminated so long as the levers remain in their operated positions, thus advising the operator that the positions of such switches are predetermined by their individual control levers.

The restoration of the auxiliary switch control levers to normal positions of course causes the restoration of their respective primary and secondary switch control relays to normal unless the track switches are included in a route established and thereby have their lock relays maintained deenergized due to the presence of a train or the like. Also, if lever 1SML for example, is restored to its center position prior to the completion of the operation of the track switches 1ATS and 1BTS, the associated secondary switch control relays are maintained energized by reason of energy applied to their stick circuits by back contacts 80 and 95 so that the operation of such track switches is completed as initiated. Such is also true if one of the primary switch control relays 1AN, 1R or 1BN is dropped away prior to the complete operation of the associated track switches.

If there is no route established over a track switch and its lock relay is not deenergized, then the operator may move the associated individual control lever to normal and reverse positions and effect the reversal of such track switches in mid-stroke by reason of the fact that the application of energy to the lower windings of the relays WZ neutralizes the energization of such relays by their stick windings so that they may drop away and pick up in their opposite controlling positions, but when their stick circuits are energized by reason of the deenergized condition of a lock relay, such a reversal of energy cannot occur because the primary switch control relays are also locked by reason of the energization of their stick circuits.

Dual system control.—The switch and signal control system of the present invention may be considered a dual system, that is, routes may be established by the entrance-exit manipulation of the control buttons for the ends of the various routes afforded by the track layout, or such routes may be set up by the individual operation of the auxiliary levers SML for the track switches included in such routes followed by the actuation of the control button at the entrance end of such route alone. It is of course obvious that such individual lever control of the various switch and signals of the track layout would be desirable only in those cases where the system might fail to automatically establish routes by entrance-exit manipulation. This of course would only happen upon the failure of contacts and circuits in the conditioning and completion networks.

These dual methods of manipulation are made possible in the present invention by reason of the manner in which the signal control circuits are selected (see Fig. 3). For example, in establishing a route from A to C, the operator may actuate the control levers 1SML and 3SML to normal positions and cause the track switches 1ATS and 3ATS to be operated to their normal positions. The indicator lamps for the track portions corresponding to the route from A to C are illuminated and the correspondence relays assume proper positions upon the completion of

the operation of their respective track switches. The lock stick relays therefore are deenergized and all that remains for the clearing of the signal governing entrance to the route is to close 5 the entrance contact at front point 92 of the relay ANR which is effected by the actuation of the button APB. Thus, the signal control relay AGR is energized over the same circuit as previously pointed out when the route was assumed to be set up by entrance-exit manipulation. Under such circumstances no exit operation for the end of the route is required, but the operator must restore the bus interlock arrangement to normal before he again actuates a button for an entrance operation. To do this, he merely actuates the cancel button CANB.

Any route thus established by individual control of the track switches and signals can be restored to stop by the pulling of the control 20 button at the entering signal location to deenergize the corresponding entrance relay, the same as described for the entrance-exit type of control. The track switches of course remain in their last operated positions even though the individual switch machine control levers SML are restored to their center positions.

When a train passes into a route established by individual control of the switches and signal, the signal is automatically restored to stop by the deenergization of the stick circuit for the corresponding entrance relay. However, the route is maintained throughout unless the auxiliary levers SML have been restored to the center positions. In other words, the auxiliary levers SML 35 may be restored to their non-controlling positions as soon as the governing signal has been cleared because the route is held by the route locking, and thus permit the entrance and passage of a train through the route to effect the rear release of the track sections in some manner as previously described.

Semi-automatic signal control.—Each of the main track signals shown in Fig. 3 for governing traffic in the normal direction of train movement for its track is subject to control in accordance with traffic conditions in advance of such signal to provide so-called speed signalling and to give rear-end protection for train movements in such normal direction of traffic; while 45 each of the remaining signals are of the low speed dwarf type which indicate, when cleared, that a route governed thereby has been established and that the opposing signal for such route is at stop. Each of the high speed signals, 50 such as signal BG, for example, is under the control of two relays, namely, relay BGR which is manually controlled so as to be energized when a route originating at that signal is established and the opposing signal is at stop, and the relay BHR which is energized dependent upon a clear track up to the next succeeding signal governing traffic in the same direction and then energized with a polarity in accordance with the clear or stop indication of such succeeding signal. 55 Thus, this signal BG may give a high speed proceed indication when it governs an established route if the track sections are unoccupied to the next succeeding signal in advance providing that signal in advance also indicates proceed; and signal BG may give a caution indication when it governs an established route with the next succeeding signal at stop providing the intervening track sections are unoccupied, but gives a stop indication if the intervening track sections in advance of such signal BG are occupied by a train

irrespective of its manual control. It is of course understood that the signal BG may be manually put to stop at any time. A signal thus controlled is usually termed a semi-automatic signal, but with the automatic restoration of the entrance relays, such as relay ANR, for example, the signal is also a stick signal, so that the signal BG may be properly termed a semi-automatic stick signal in accordance with the usual signalling parlance.

To consider a typical example of how such semi-automatic control is provided, assume that an operator designates the respective entrance and exit ends of a route extending from C to A, and causes the establishment of that route in accordance with the principles of the route establishing means as heretofore set forth. After the route is completely established, the signal control relay CGR is picked up upon energization of a circuit closed from (+), including back contact 127 of relay AGR, back contact 92 of relay ANR, back contact 91 of relay 1LS, front contact 90 of relay 1NCR, back contact 89 of relay 1RCR, back contact 88 of relay 3LS, front contact 87 of relay 3NCR, back contact 86 of relay 3RCR, front contact 85 of relay CNR, and winding of relay CGR, to (-). The picking up of that relay by opening back contact 151 causes the extinguishing of the red lamp in signal CG which is normally energized by an obvious circuit providing of course that relay CHR is energized opening its back contact 159.

If the track sections 1AT and 3AT are unoccupied by a train, and if the signal next in advance such as signal AGL at signal location A indicates proceed as indicated by the energized condition of relay ALPC, the relay CHR is energized by a circuit closed from (B+), including front contact 152 of relay ALPC, front contact 153 of relay 1ATR, front contact 154 of relay 3ATR, and winding of relay CHR, to (CN). Upon the picking up of relay CGR, with relay CHR energized, a circuit is closed for the energization of the green lamp of signal CG, from (+), including front contact 155 of relay CNR, front contact 156 of relay CGR, front contact 157 of relay CHR, polar contact 158 of relay CHR in a right-hand position, and the green lamp of signal CG, to (-).

It is to be understood that relay ALPC is energized whenever the signal AGL indicates proceed, either for high speed or caution, and is deenergized whenever it indicates stop. The same relationships are also present between signal DGR and relay DRPC. These signals AGL and DGR are shown as being at locations A and D respectively, but they may be at more distant locations depending upon the requirements of practice. Also, these signals AGL and DGR may be automatic signals of automatic block territory or may be manual control as the situation may require.

To consider how a caution indication is selected for signal CG when a route is established under the above assumed conditions, assume that the signal AGL for governing west-bound traffic at location A is at stop, which causes the pole changing relay ALPC to be dropped away and relay CHR to be energized with the current of negative polarity. Such energization of relay CHR causes the illumination of the yellow lamp in signal CG for a caution indication by the energization of a circuit closed from (+), including front contact 155 of relay CNR, front contact 156 of relay CGR, front contact 157 of relay

CHR, polar contact 158 of relay CHR in a left-hand position, and the yellow lamp of signal CG for a caution indication, to (-).

If an operator causes the establishment of a route from C to A at a time when such route is occupied by a train, such occupancy causes the relay CHR to be deenergized and under such conditions causes the red lamp of signal CG to be maintained energized by an obvious circuit 10 closed at back contact 159.

Having thus described the automatic selecting of the indications for signal CG, it is to be understood that the indications of the signal BG are governed in a similar manner. It is also to be understood that numerous other means may be provided for displaying and for selecting the various indications in accordance with the occupied condition of the various track sections and in accordance with the requirements of practice, 20 all within the scope of the present invention.

Through route control.—As mentioned in the opening statements of the specification, the present invention is embodied in a system which provides for through route or end-to-end control 25 for track layouts having several adjoining interlocked groups located end-to-end. As typical of such a track layout, Fig. 7 illustrates a track layout having two interlocked groups, one being similar to the interlocked group of Fig. 3 and an 30 added interlocked group having a crossover 4. However, this track layout of Fig. 7 is assumed to be a portion of a large interlocking plant having high speed traffic in both directions on each 35 main track with provisions for switching train movements. The signals AGR, BGR, CGL, CGR, DGL, DGR, EGL, FGL, FGR and GGL are therefore shown as giving call-on signal indications as well as the usual high speed signal indications. The signal AGL may be another manually 40 controlled signal or may be an automatic signal at the entrance to automatic block signalling territory.

In view of the detailed disclosure of the typical route establishing means for a single interlocked 45 group, it is believed that the manner in which such route establishing means may be provided for each of a large number of interlocked groups and the adjoining route establishing means interconnected for through route operation will be sufficiently understood by typically illustrating 50 such interconnection for only one double intermediate signal location. Thus, the circuits and means employed with respect to only the upper track of the layout of Fig. 7 has been shown in 55 Figs. 6A, 6B and 6C, it being understood that these circuits are given merely as typical of all the circuits which would be employed in the track layout of Fig. 7 or in any other complex track layout having several double intermediate signal locations. A portion of the track diagram 60 for this track layout of Fig. 7 has been shown in Fig. 6B, and the control buttons for this form of the invention are constructed so as to be pushed to close contacts for controlling the high speed signals and to be turned to close contacts 65 for controlling the call-on signals. The buttons are of the self-restoring type both from the pushed and the turned operated positions, as well as from pulled positions provided for restoring cleared signals to stop.

It will of course be appreciated that portions of the disclosure in Figs. 6A, 6B and 6C are identical to corresponding portions and apparatus shown in Figs. 1A and 1B, and especially the bus interlock arrangement is applied to the system

in exactly the same way as disclosed in Figs. 1A and 1B. However, the entrance relays and their response to the control buttons as controlled by the bus interlock arrangement and the route establishing means is substantially the same as in Figs. 1A and 1B, but is slightly modified in view of the use of the turned positions of the buttons to control the call-on signals in a manner specifically described later.

It is also to be understood in connection with Figs. 6A, 6B and 6C that the route establishing means, which has been repeated from Figs. 1A and 1B merely for convenience in showing the relationships between the route establishing means of the adjoining interlocked groups, may be modified in accordance with the various forms and arrangements of the route establishing means shown in Figs. 8, 9A, 9B, 12 and 15.

Although train movements might be effected through a track layout having a number of interlocked groups by operating the control buttons for the individual interlocked groups, the present system in responding to through route manipulations where the operation of a control button at the entrance to a plant and the operation of a control button at the exit of the plant or any other intermediate point will effect the setting up of a route irrespective of the number of intervening interlocked groups, clearly facilitates the establishment of routes and through routes in a complex interlocking plant. The present invention not only provides this through route control but accomplishes such control through the medium of a single control button for each of the signal locations including the double intermediate signal locations even though such double intermediate signal locations may also include low speed or call-on signals as well as the usual high speed signals.

The through route control in general follows the principles of the route establishing means above described in connection with a single interlocked group. For example, the picking up of an entrance relay, such as entrance relay ANR (see Fig. 6A) acts on the conditioning network to prepare for energization the exit relay for the exit end of each route or through route originating at the entrance point A. Such conditioning is made possible for those exit points outside of the interlocked group including the entrance signal location A by reason of a through route connection between the conditioning circuits for the adjoining interlocked groups, or in other words, there are two through route connections for each double intermediate signal location.

Each of these through route connections for an intermediate signal location is normally closed, but is opened whenever that signal location is included in an established route either as an entrance point or as an exit point, or whenever a route locking directional stick relay, such as relays 3AES, 3AWS, 4AWS and 4AES, is deenergized for either direction of traffic for the track section on either or both sides of such intermediate signal location. Therefore, the conditioning of an exit relay, such as exit relay FXR (see Fig. 6C) for the establishment of a route responsive to the picking up of an entrance relay ANR (see Fig. 6A) can be effected only when there is no route established either terminating or originating at the signal location C nor can such exit relay FXR be conditioned for energization for a through route when a train is present in the through route connecting the sig-

nal locations A and F. The details of such operation will be considered specifically below.

Let us assume that an operator desires to establish a through route by through route manipulations from A to F (see Figs. 6A, 6B, 6C) at a time when such route is available. The designation of the location A as the entrance end of such route causes the picking up of relay ANR by a circuit which has been described but in addition includes back contacts 498 of AOR. The picking up of that relay ANR causes the conditioning of relays CXR and FXR, so that the depression of the control button for any one of such exit points would cause the corresponding relay to be picked up. The relay CXR is conditioned by energy feeding to the left-hand terminal of its winding from (+), front contact 27 of relay ANR (see Fig. 6A), back contact 499 of relay AOR, back contact 28 of relay 1R, back contact 29 of relay 3R, wire 160, back contact 161 of relay COL, and back contact 162 of relay CML, to the left terminal of relay CXR.

Energy is passed on from the left-hand terminal of relay CXR to energize the relay 4AN (see Fig. 6C), because it can be trialed in a normal position by a through route originating at A, over a circuit including back contact 163 of relay CXR, front contact 164 of relay 3AES, front contact 165 of relay 3AWS, front contact 166 of relay 4AWS, front contact 167 of relay 4AES, back contact 168 of relay CXL, back contact 169 of relay CNR, back contact 170 of relay COR, wire 171, back contact 172 of relay 4R, and upper winding of relay 4AN, to (-). Upon the picking up of relay 4AN energy is passed on over a conditioning circuit for relay FXR including front contact 173 of relay 4AN, front contact 173a of relay FOL, and back contact 174 of relay FNL.

Each of the exit relays CXR and FXR being so conditioned for energization provides that a route can be established from A to C if an operator designates an exit point at C, or a through route can be established from A to F if an operator designates an exit point at F. Inasmuch as the through route control is now under consideration, let us assume that an operator designates an exit point at F subsequent to the designation of an entrance point at A and that there is an available route extending from A to F.

The relay FXR has positive energy (+) applied to its left-hand terminal in a manner just described, so that the operation of the control button FPB applies negative energy (-) to its right-hand terminal through back contact 175 of button FPB. The picking up of relay FXR closes its front contact 176 to shunt out button contact 175 to create a stick circuit for holding the exit relay FXR when the operator releases the button FPB.

Responsive to the picking up of exit relay FXR, the execution of the switch controls to relay 4AWZ and 4BWZ becomes effective for the crossover 4 in accordance with the general principles of the system as heretofore described. The complete selection of the route through the right-hand interlocked group as indicated by the picked up position of relay 4AN jointly with the picked up position of relay FXR, causes the picking up of the exit repeater relay CXLP which is energized by a circuit closed from (+), including front contact 177 of relay FXR (see Fig. 6C), front contact 178 of relay 4AN, wire 179, back contact 180 of relay CXL, winding of relay CXLP, and back contact 181 of relay CNR, to

(-). The picking up of that relay CXLP causes a stick circuit to be established to maintain it energized only until the relay CXR is picked up, extending from (+), including front contact 177 of relay FXR (see Fig. 6C), front contact 178 of relay 4AN, wire 179, back contact 180 of relay CXL, winding of relay CXLP, front contact 182 of relay CXLP, and back contact 183 of relay CXR, to (-).

Upon the picking up of relay CXLP a circuit is closed to cause the picking up of the entrance relay CNR from (+), including contact 184 of button CPB closed in a normal position, front contact 185 of relay 4ATR, front contact 186 of relay CXLP, and upper winding of relay CNR, to (-). The picking up of that relay closes a stick circuit at front contact 187 to shunt contact 188 out of the circuit just described.

Upon the picking up of relay CNR the closing of front contact 169 applies energy to the conditioning circuit including relay FXR for the purpose of maintaining that exit relay energized, dependent for deenergization upon the dropping away of relay CNR. During the shifting of contact 169 from its back to its front point, the stick circuit for relay FXR is not interrupted because front contact 188 of relay CXLP shunts back contact 169.

When relay CNR is picked up, a circuit is closed to cause the picking up of the exit relay CXR for the left-hand track portion extending from (+), including front contact 27 of relay ANR (see Fig. 6A), back contact 499 of relay AOR, back contact 28 of relay 1R, back contact 29 of relay 3R, wire 168, back contact 161 of relay COL, back contact 162 of relay CNL, winding of relay CXR, back contact 189 of relay CXL, front contact 190 of relay CNR, and front contact 191 of relay CXLP, to (-). The picking up of that relay closes a stick circuit at front contact 192 to shunt contacts 189, 190 and 191 out of the circuit just described. When relay CXR is picked up, the relay CXLP is deenergized by the opening of the stick circuit for that relay at back contact 183 to cause such relay to be dropped away. This can happen because relay CNR is picked up opening contact 181. The relay CXLP is made slightly slow acting to insure the establishment of the stick circuit for relay CXR before it is dropped away to open the pick-up circuit for that relay.

Responsive to the picking up of relay CXR, the crossovers 1 and 3 have their track switches operated to normal positions in accordance with the energization of their secondary switch control relays WZ over execution circuits provided in accordance with the principles of execution as heretofore set forth.

After the track switches for each of the respective track portions or interlocked groups have been properly positioned in accordance with the normal controls selected for such track switches, signal control circuits are closed to cause the clearing of the signal governing entrance to each such track portion. With reference to Fig. 7, the operation of the track switches of crossover 4 to normal positions as required causes the picking up of a normal correspondence relay 4NCR and the dropping away of the relay 4LS to close a circuit for the signal control relay C1GRR extending from (+), including back contact 193 of relay FGL, back contact 194 of relay FNL, back contact 501 of relay FOL, back contact 195 of relay 4RCR, front contact 196 of relay 4NCR, back contact 197 of relay

4LS, back contact 198 of relay COR, front contact 200 of relay CNR, and winding of relay C1GRR, to (-).

Upon the picking up of relay C1GRR a circuit is closed to cause the illumination of the green lamp in the high signal CGR (if the next signal in advance for governing traffic in the same direction, such as FGR, indicates proceed, and if the route established from C to F is unoccupied by a train) by the energization of a circuit closed from (+), including front contact 201 of relay CRHR, front contact 202 of relay C1GRR, polar contact 203 of relay CRHR in a left-hand position, and the green lamp in signal CGR, to (-).

If the next signal in advance of signal CGR is at stop and the route from C to F is unoccupied by a train when relay C2GRR is picked up, the yellow lamp for the caution indication in signal CGR is illuminated by the energization of a circuit closed from (+), including front contact 201 of relay CRHR, front contact 202 of relay C1GRR, polar contact 203 of relay CRHR in a right-hand position (in accordance with the next signal in advance being at stop), through the yellow lamp in the high signal CGR, to (-).

It is to be understood that the relay CRHR is energized whenever the signal FGR indicates proceed, either its high speed signal or its low speed signal, and is deenergized whenever such signal FGR indicates stop. Thus, when the signal FGR is cleared, the relay CRHR is energized over a circuit closed from (B+), front contact 502 of relay FPPC, front contact 503 of relay 4ATR, windings of relay CRHR, to (CN). In this connection, it is noted that the relay CLHR is controlled in a similar manner in accordance with the condition of the signal AGL and the presence of traffic in the associated track sections.

Thus, if the route from C to F is occupied by a train, the track relay 4ATR is deenergized opening front contact 503 deenergizing the relay CRHR, which holds the high signal CGR at stop by energizing its red lamp *r* by an obvious circuit including back contact 231 of relay CRHR. Such red lamp *r* is normally illuminated while the relay CRHR is normally energized by the energization of a circuit closed from (+), including front contact 201 of relay CRHR, back contact 202 of relay C1GRR, red lamp *r* of the high signal CGR, to (-).

The clearing of the high signal CGR by the energization of the relay C1GRR, closes front contact 507 to energize the indication relay CGKR which in turn illuminates the signal indicator lamp within the associated control button CPB. It is, of course, understood that the miniature track diagram is illuminated between C and F in a manner similar to that explained in connection with Figs. 5A and 5B.

In a similar manner, the relay A1GR is energized to clear the high signal AGR when the track switches between A and C have properly positioned and have locked, by reason of a circuit closed from (+), including back contact 205 of relay C1GLR, back contact 206 of relay CNL, back contact 207 of relay COL, back contact 208 of relay 3RCR, front contact 209 of relay 3NCR, back contact 210 of relay 3LS, back contact 211 of relay 1RCR, front contact 212 of relay 1NCR, back contact 213 of relay 1LS, back contact 214 of relay AOR, front contact 504 of relay ANR, windings of relay A1GR, to (-). The picking up of the relay A1GR controls the indications of

the high signal AGR in a manner similar to that explained in connection with the signal CGR.

The relay A1GR also closes front contact 505 to apply energy (+) to the indication relay AGKR, which causes the illumination of the indicator within the button APB. It is, of course, understood that if the call-on signal of AGR were cleared by energizing the relay A2GR, it would also cause the relay AGKR to be energized by closing its front contact 506. In other words, the indicator lamps within the control buttons indicate whether the signal is clear or at stop irrespective of whether it is the high speed or the call-on signal which is cleared. In this connection, it may be noted that the indicator relay CGKR associated with the control button CPB is energized whenever any one of the signals, either high speed or call-on, is cleared at the signal location C.

With a through route established as above described, it is noted that the entrance relays ANR and CNR are maintained energized dependent upon their respective track relays, 1ATR and 4ATR as well as their respective control button contacts 8 and 184. In other words, the high signal CGR is maintained cleared and the route establishing means is held in an active condition by the relay CNR which is dependent upon the passage of a train into the associated track section or dependent upon the pulling of the button CPB to open contact 184.

Thus, the passage of a train past the signal location A causes the relay ANR to be deenergized and the signal control relay A1GR to in turn be deenergized which restores the high signal AGR to stop but this in no way effects the condition of the signal CGR. It is noted that the primary switch control relays of the route establishing means are maintained energized through stick circuits previously described in connection with Figs. 1A, 1B and 2. As the train passes through the through route thus established passing the signal location C, the relay CNR is deenergized when front contact 185 of track relay 4ATR is opened.

Either or both of the signals AGR and CGR may be manually restored to stop by pulling out their respective control buttons APB and CPB to open the respective contacts 8 and 184.

Having specifically shown and described how a through route may be established past a particular double intermediate signal location, it is believed that it will be readily apparent how a through route can be set up past a plurality of intermediate signal locations when there are more than two interlocked groups located end-to-end in succession. When a large number of interlocked groups are located end-to-end and the control buttons are manipulated for a through route including all of such interlocked groups, it will be understood that the route establishing means for the interlocked group nearest the exit end of the through route responds first and operates its switches and closes its signal followed by the next preceding interlocked group and so on, group by group, until all of the interlocked groups included within the through route have been properly controlled to establish and clear the signals for the through route.

The present disclosure contemplates that double intermediate signal locations may be present on adjacent parallel tracks such as the signal locations C and D of Fig. 7, and in such cases the system must automatically operate to pro-

vide proper selections to give the through route which is most direct.

For example, in designating the signals locations A and F as the entrance and exit ends of a through route, there are three alternative routes over which a train might pass to go from signal location A to signal location F. One route is over the main track past the signal location C as above described, while the two alternative and inferior routes are past the signal location D over either the crossover 1 or the crossover 3 reversed and also over crossover 4 reversed. With the route establishing means of the present invention, the main route past the signal location C is given the preference or superiority and will always be established unless some conflicting condition causes an inferior route to be established in accordance with the principles of optional route selection which will be explained in detail hereinafter. But it may be stated here for the sake of clarity that the reason the main route past the signal location C is selected is because the preselection operation with respect to any switch, such as the crossover 4, is for the normal position in preference to the reverse position.

In this connection, it may be well to consider in a general way the reasons for the contact selections in the through route connection between the route establishing means of adjoining interlocked groups. For example, the through route connection from the conditioning network for the left-hand interlocked group ending with the exit relay CXR, leads through back contact 163 of relay CXR, front contact 164 of relay 3AES, front contact 165 of relay 3AWS, front contact 166 of relay 4AWS, front contact 167 of relay 4AES, back contact 168 of relay CXL, back contact 169 of the relay CNR, to the conditioning network for the right-hand interlocked group.

It is noted that, if the signal location C is the end of an established route from either direction with its exit relay CXR or CXL picked up, this through route connection just pointed out is opened. Similarly, if the signal location C is an entrance point for traffic to the right, this through route connection is also open at back contact 169 of entrance relay CNR. It is noted that the corresponding through route connection at this signal location for the opposite conditioning network includes similar contacts so that if the signal location C is the entrance point for a route from C to A, for example, the corresponding through route connection is opened at back contact 222 of entrance relay CNL.

It is desired to particularly point out that each of these through route connections for this signal location C include front contacts of the directional stick for both directions relays for the track sections on both sides of the signal location C. Thus, if a train has entered a route leading up to the signal location C from the signal location A, for example, the relay 3AES is deenergized and front contact 164 is open and the corresponding contact in the other through route connection is also opened, which provides that through route conditioning energy cannot flow past the signal location C if an east-bound train is in a track section of a route leading up to that signal location. The same is true when the west directional stick relay 3AWS is deenergized opening its contact 165, which is the case when a train is in the track section 3AT and is receding to the left from the signal location C. It will be apparent that the directional stick

relays 4AWS and 4AES provide similar control but considering traffic conditions to the right of the signal location C. Thus, a through route can not be established past the signal location C if either of the track sections adjacent that signal location is occupied by a train receding from the signal, or an established route is occupied by a train approaching such signal location. This last point is true irrespective of the number of track sections included in any route because each directional stick relay is dependent upon the energized condition of the directional stick relay for the preceding track section of that route.

With this organization, if a train is approaching the signal location C or is standing on the track section 3AT, the through route connection is broken at front contact 164 so that the relay 4AN is not energized upon the designation of the signal location A as an entrance point, but if the crossover 1 is available for use then the conditioning energy may flow over the corresponding portions of the conditioning network past the signal location D and permit the inferior of the through routes to be established for reasons which will be more apparent after a detailed consideration of the optional route features of the present invention. It is desired to state that with a train on the track section 3AT, it appears undesirable to allow a through route to be established from A to F even though the high signal A would not clear and thus protect the train on the track section 3AT because under such circumstances there would be nothing to prevent the clearing of the signal at the signal location C which might be accepted by the train standing on the track section 3AT allowing it to proceed when the operator did not intend such train movement at all. In other words, the control provided by the inclusion of directional stick contacts in the through route connections enforces more stringent conformity between the traffic conditions in through routes and the manipulations for such through routes.

Another reason for preventing the setting up of a through route when a portion of that route is occupied by a train is that in some cases an optional or alternative route may be available by which a second approaching train can be run-around a first train which may be required to be held up at a particular signal location. That is, the presence of a train in track section 3AT in the approach to signal CGR (see Fig. 7) when that signal is at stop should not prevent an operator establishing a route for a train approaching signal A extending from A to F via cross-overs 1 and 4 and thus run-around the train occupying track section 3AT. When it is provided that the through route connection cannot be established for the signal location C by the inclusion of contacts of route locking relays as described in the through route connection, it is provided that an inferior one of the alternative routes available between the designated route ends will be established as from A to F via crossovers 1 and 4 in accordance with the principles of optional route selection as hereinafter described.

Although it is not required in all cases that an east and west stick relay be included in the through route connection for each of the two track sections adjacent at an intermediate signal location, such contacts have been shown in this disclosure in anticipation of conditions which would be encountered in practice in more complex track layouts. With reference to Fig. 7, for ex-

ample, a reason is provided for the use of such contacts in the through route connections different than the conditions which have been heretofore described in that such contacts are used to prevent the establishment of a route against an approaching train. Consider for example, that an east-bound train has entered track section 3AT approaching signal CGR, and has therefore released the track switches of the crossover 1 by leaving track section 1AT. Now consider under such conditions that an operator desires to cause a west-bound train approaching signal location F to run-around the train assumed to be in track section 3AT and leave the track layout at signal location A. Therefore, for the establishment of a route for that train the operator designates the respective entrance and exit ends at F and A for a through route. The opening of the through route connection past signal location C provided by the dropped away position of the route locking stick relay 3AES prevents the establishment of a through route on the upper track, and thus allows the inferior run-around route from F to A via crossovers 4 and which can be established in accordance with the principles of optional route selection as hereinafter described.

Single button for intermediate location.—In accordance with one of the primary objects of entrance-exit systems, namely, to simplify the manipulation by an operator in the setting up of the various routes extending through a track layout, the present invention provides a means for designation by actuation of a single control button of each of the entrance and exit controls required for a double intermediate signal location, thus eliminating the confusion of an operator having to select for actuation a proper one of several buttons for such a signal location. The depression and pulling out of such button in proper sequence defines ordinary entrance, exit and restoration controls, and the rotation of such button defines a call-on control. That is, for example, the button CPB (see Fig. 6B) when depressed subsequent to the designation of an entrance point at A causes the designation of an exit point at C. If, however, the button CPB is initially depressed, such button serves to designate an entrance point for a route to be established in a particular direction selected in accordance with the establishment of a route up to the signal location C. That is, if a route is established from A to C when an operator depresses button CPB for designation of an entrance point, it is automatically selected that the direction shall be for a route governed by a signal at location C for east-bound traffic, such signal being selected as a high speed signal rather than a call-on signal if both types of signals are provided as assumed for such signal location. If an operator wishes to cause the establishment of a route having an entrance point at signal C governed by a call-on signal, he designates the entrance point at such signal location by the rotation of the button CPB in a counterclockwise direction if the route governed by such call-on signal is to be for west-bound traffic, and in a clockwise direction if such route is to be governed by a call-on signal for east-bound traffic. Upon the manual release of the button CPB after having been actuated to an operating position by rotation, such button is automatically restored to its normal center position with respect to rotation. Thus the button CPB is not only biased to a normal position with respect to push and pull operation, but

it is biased to a normal position with respect to rotation.

To consider a typical example of how the single button CPB is used in the establishment of a route, assume that an operator desires to cause the establishment of a route from A to C at a time when such route is available. The designation of the entrance end of such route by the depression of button APB causes the picking up of relays ANR, NP and NPP (see Fig. 6A) by the energization of circuits which have been described, and the picking up of relay ANR conditions relay CXR for energization in accordance with the availability of the route.

Upon depression of the button CPB for designation of an exit point at C for a route from A to C, the exit relay CXR is picked up by the energization of a circuit closed from (+), including front contact 27 of relay ANR (see Fig. 6A), back contact 499 of relay AOR, back contact 28 of relay 1R, back contact 29 of relay 3R, wire 160, back contact 161 of relay COL, back contact 162 of relay CNL, winding of relay CXR, back contact 189 of relay CXL, and contact 215 of button CPB closed in a depressed position, to (-). The picking up of that relay closes a stick circuit at front contact 192 to shunt contacts 189 and 215 out of the circuit just described. When relay CXR is picked up a circuit is closed to cause the picking up of the relay CAN (see Fig. 6A) extending from (+), including the lower winding of relay CAN, cancel bus, back contact 216 of relay CXSR, front contact 217 of relay CXR, contact 218 of button CPB closed in a depressed position, entrance pick-up bus, and front contact 5 of relay NPP, to (-). The picking up of relay CAN causes the dropping away of relay NP by opening the stick circuit for that relay at back contact 12, and relay CAN maintains relay NPP picked up by the closing of an obvious circuit at front contact 14. Upon the restoration to normal of the button CPB following the designation of the exit point at C, the circuit just described for relay CAN is opened at contact 218, and the dropping away of that relay causes the release of relay NPP, and thus restores the bus interlock system to its normal conditions. The restoration of the button CPB with relay CXR picked up closes a circuit to cause the picking up of the relay CXSR extending from (+), including winding of relay CXSR, front contact 219 of relay CXR, and contact 215 of button CPB closed when that button is in a normal position, to (-). The picking up of relay CXSR closes a stick circuit for that relay at front contact 220 to shunt contact 215 out of the circuit just described. The relay CXSR when picked up opens back contact 216 to provide that the depression of button CPB with relay CXR picked up cannot apply energy to the cancel bus.

Responsive to the picking up of the exit relay CXR, the relay 3AN is picked up by the energization of a circuit closed from (+), including front contact 221 of relay CXR, back contact 222 of relay CNL, back contact 223 of relay COL, wire 224, back contact 43 of relay 3R, and upper winding of relay 3AN, to (-). The picking up of that relay closes a circuit to cause the picking up of relay 1AN extending from (+), including front contact 221 of relay CXR (see Fig. 6B), back contact 222 of relay CNL, back contact 223 of relay COL, wire 224, back contact 43 of relay 3R, front contact 44 of relay 3AN, back contact 45 of relay 1R, and upper winding of relay 1AN, to (-). The response of the relays 3AN and

1AN causes the operation of the track switches for the respective crossovers 3 and 1 to normal positions in accordance with the execution of the switch controls in a manner which has been described. After the track switches have been properly positioned to establish the route from A to G, the relay AGR (see Fig. 7) is picked up to cause the clearing of the signal AG in accordance with the energization of a circuit which has been described for that relay.

To consider as a typical example, of how an entrance point is designated by the actuation of the control button CPB for the intermediate signal location at C, assume, when the route is established as has been described from A to C that an operator desires such route to be extended to an exit point at F. Thus, to initiate the setting up of a route from C to F, the designation of an entrance point for such route is effected by the depression of the button CPB. Responsive to the depression of that button the entrance relay CNR is picked up by the energization of a circuit closed from (+), including upper winding of relay NP (see Fig. 6A), back contact 5 of relay NPP, entrance pick-up bus, contact 218 of button CPB closed in a depressed position, back contact 225 of relay CXL, back contact 226 of relay CNL, wire 227, front contact 228 of relay 3AN, wire 229, back contact 230 of relay 4AN, wire 231, back contact 232 of relay COR, and lower winding of relay CNR, to (-). The picking up of that relay closes a stick circuit extending from (+), including contact 184 of button CPB closed in both a normal and a depressed position, front contact 185 of relay 4ATR, front contact 187 of relay CNR, and upper winding of relay CNR, to (-). The establishment of such stick circuit provides that the relay CNR is maintained energized after the pick-up circuit is opened upon the restoration to normal of the button CPB, dependent for deenergization upon the entrance of a train into the track section 4AT to cause the release of the track relay 4ATR. The picking up of relay NP (see Fig. 6A) responsive to entrance designation of course causes the picking up of the repeater relay NPP upon the closing of an obvious circuit at front contact 15 and in picking up the relay NPP conditions the bus arrangement for the designation of an exit point.

It will be noted from the circuits just described that the picking up of relay CNR in preference to relay CNL is selected by the picked up position of relay 3AN which is significant of the establishment of a route up to signal location C for east-bound traffic. Of course, such relay 3AN would also be picked up if the track section 3AT were occupied by a west-bound train, and the entrance relay CNR may be energized by actuation of button CPB for a back-up move if desired. If a route F to C were established, the depression of button CPB for designation of an entrance point could not cause the picking up of relay CNR because of the opening of the pick-up circuit for that relay at back contact 230 of relay 4AN. Under such conditions the depression of button CPB could not even cause the picking up of the entrance relay CNL for west-bound traffic to the left as such relay can be picked up only if relays 3AN is dropped away. A route could be set up however under such conditions governed by a call-on signal in a manner to be hereinafter considered if a west-bound train is approaching signal location C.

It is believed, therefore, to be obvious that the

pick-up circuits for the relays CNR and CNL are so selected that either one or the other of such relays is selected in accordance with the establishment of a route up to that signal location and that neither one of such relays can be picked up if an operator should attempt to designate an entrance point when there is no route established extending to signal location C or when there is a route established extending through the track section at each side of signal location C. The stick circuit for each of the relays CNR and CNL of course provides that such relay can be restored upon passage of a train or upon manual designation by an operator.

Responsive to the picking up of relay CNR, the relay 4AN is picked up by the energization of a circuit which has been described, and the picking up of that relay causes energy to feed to the winding of relay FXR to condition that relay for energization responsive to the designation of an exit point at F in a manner corresponding to that which has been described. Responsive to the designation of an exit point at F, the relay FXR is picked up, and the picking up of that relay causes the execution of the switch controls for operating the track switches of crossover 4 to normal positions to correspond with the positions of the track switches required for the establishment of the route from C to F. After such route is established, the signal CGR is cleared for governing the entrance to such route in a manner which has previously been described in detail.

Call-on signals.—Inasmuch as a call-on or low speed signal without automatic control allows a train to proceed into an occupied block, it should be used with the greatest of care and when once used should not be again used unless required. In other words, the clearing of a call-on signal gives the engineer of a train the information that the track switches of a route are in proper positions and that he may proceed subject to stopping short of any obstruction that may be in the route. In accordance with the present invention, it is proposed that a call-on signal is cleared only when the track section immediately in advance of such signal is occupied by a train, and when once cleared, will automatically restore to stop when that track section becomes unoccupied, thus making it necessary that the operator manipulate the control buttons each time a call-on signal is initially cleared. However, it is to be understood that this automatic control of the call-on signal does not necessarily have to be employed in order to use call-on signals with the present invention, as will be explained more fully hereinafter.

To consider as a typical example of how a call-on signal may be cleared following the establishment of a route, let us assume that an east-bound train entered the route from A to C (see Fig. 7) and is still standing on the track section 1AT, and that the operator desires to connect another train with such first train, and to do this must clear the call-on signal AGR. The operator designates the signal location A as an entrance point by turning or rotating the button APB in a clockwise direction to close a pick-up circuit for the call-on entrance relay AOR from (+), through a circuit including upper winding of relay NP, back contact 5 of relay NPP, "entrance pick-up bus", front contact 6 of button APB in a non-operated position, button contact 508 in a right-hand position, back contact 509 of relay AXL, back contact 510 of relay ANR,

lower winding of relay AOR, to (-). As soon as this relay AOR picks up, it closes a stick circuit (+), including contact 8 of button APB, back contact 9 of relay 1ATR, front contact 511 of relay AOR, upper winding of relay AOR, to (-).

The bus interlock arrangement relays operate as previously described so that the release of the button APB permits the operation of the control button CPB to perform an exit operation to energize the exit relay CXR by a circuit closed from (+), including front contact 498 of relay AOR, back contact 28 of relay 1R, back contact 29 of relay 3R, wire 160, back contact 161 of relay COL, back contact 162 of relay CNL, windings of relay CXR, back contact 189 of relay CXL, operating contact 215 of relay CPB, to (-). As soon as the exit relay CXR picks up it closes front contact 192 to complete a stick circuit to hold the relay CXR dependent upon the relay ACR upon the release of the button CPB.

The picking up of the relay CXR while the button CPB is operated closes the cancellation circuit including front contact 217 of the relay CXR for restoring the interlock arrangement to normal by applying energy to the "cancel bus."

Inasmuch as the train on the track section 1AT has been assumed to have entered into a route established from A to C, the crossovers 1 and 3 are already in normal positions and their associated primary switch control relays 1AN and 3AN are of course energized over stick circuits typically shown in Fig. 2, and the associated lock stick relays LS are deenergized.

Thus, the picking up of the relay AOR completes an energizing circuit for the signal control relay A2GR (see Fig. 7) from (+), through a circuit including back contact 205 of relay C1GLR, back contact 206 of relay CNL, back contact 207 of relay COL, back contact 208 of relay 3RCR, front contact 209 of relay 3NCR, back contact 210 of relay 3LS, back contact 211 of relay 1RCR, front contact 212 of relay 1NCR, back contact 213 of relay 1LS, front contact 214 of relay AOR, windings of relay A2GR, to (-).

The energization of the relay A2GR causes the clearing of the call-on signal AGR by suitable circuits similar to those shown in connection with the control of the call-on signal of CGR.

In other words, the relay A1GR controls the main or high speed signal of AGR and the relay A2GR controls the call-on or low speed signal AGR. The energization of relay A2GR closes front contact 506 to energize the signal indication relay AGKR for illuminating the indicator within the control button APB as typically shown in Fig. 5B.

This call-on signal AGR is restored to stop whenever the train leaves the track section 1ATR by reason of the opening of the stick circuit for the relay AOR at back contact 9, or the operator may restore this call-on signal to stop by merely pulling the button APB to open contact 8.

It is noted that should it be desired to have the stick circuit for the call-on entrance stick relay AOR dependent upon the presence of a train in every track section included in any route originating at the signal location A, the track contacts for the various track sections could be included in this stick circuit by suitable selections which should be made dependent upon switch position as indicated by the WP relays of the track switches in the routes involved, but this has not been shown as such selections will be readily understood by those skilled in the art. Also,

the automatic restoration of the call-on signal is not desired, and if it is found expedient to be able to clear the call-on signal irrespective of the occupied condition of an adjacent track section, the track contacts may be omitted from the stick circuits of the call-on entrance stick relays, such as relay AOR. In this particular case it would merely mean connecting the wire leading to the back point of contact 9 to the wire leading from the heel of such contact 9. With this arrangement the call-on entrance stick relay would then be dependent wholly upon manual restoration. It is to be understood that such connections may be made for each of the call-on entrance stick relays shown in the embodiment of the invention and contemplated as used with the invention.

To consider as a typical example of how a route is established to be governed by a call-on signal at a double intermediate signal location, assume that an east-bound train occupies track section 3AT in approach to signal location C, and that an operator desires to establish a route from C to F for such train to be governed by a call-on signal, such call-on signal being either required because of the presence of a train in the route from C to F, or by reason of preference of the operator.

To designate an entrance point for a route to be governed by a call-on signal extending from C to F, the operator rotates the button CPB in a clockwise direction, and such rotation causes the operation of the contact 233 of that button to a right hand position to close a pick-up circuit for the call-on entrance relay COR extending from (+), including upper winding of relay NP (see Fig. 6A), back contact 5 of relay NPP, entrance pick-up bus, contact 218 of button CPB in a normal position with respect to push and pull operation, contact 233 of button CPB closed in a right-hand position, back contact 234 of relay CXL, back contact 235 of relay CNR, and lower winding of relay COR, to (-). The picking up of that relay causes the establishment of a stick circuit extending from (+), including contact 184 of button CPB closed in a normal position with respect to push and pull operation, back contact 236 of relay 3AT, front contact 270 of relay COR, and upper winding of relay COR, to (-). Such stick circuit provides that the relay COR is maintained picked up after the operator has allowed the button CPB to be restored to its normal position, dependent for restoration upon the picking up of relay 3AT after the train for which the route is to be established has left that track section.

Responsive to the picking up of relay COR energy is applied at front contact 170 to a pick-up circuit for relay 4AN which has been described, and the picking up of that relay closes a circuit to condition the relay FXR so that such relay can be picked up upon designation of an exit point at F.

In view of the description as heretofore set forth with reference to the establishment of routes, and more particularly with reference to the establishment of a route from C to F, it is believed obvious how such route is established upon designation of an exit point at F when an entrance point has been designated at C by the rotation of the button CPB for defining that such route is to be governed by a call-on signal. After that route is established, a call-on signal control relay C2GRR (see Fig. 7) is picked up by the energization of a circuit closed from (+), including back contact 193 of relay FGL, back contact 194 of relay FNL, back contact 501 of relay

FOL, back contact 195 of relay 4RCR, front contact 196 of relay 4NCR, back contact 197 of relay 4LS, front contact 198 of relay COR, and winding of relay C2GRR, to (-). The picking up of that relay opens an obvious circuit for the lower red lamp in relay CGR, at back contact 271, and closes an obvious circuit for the energization of the lower yellow lamp in that signal for a call-on indication at front contact 271. In view of the fact that the signal control relay C1GRR is dropped away at that time, it is believed obvious that the upper red lamp of signal CGR above the yellow call-on lamp is maintained energized. Thus, a distinctive call-on indication is displayed by the illumination of a yellow lamp of signal CGR in combination with the illumination of a red lamp above it. Such indication is distinguished from a caution indication, because a caution indication is provided by the illumination of an upper yellow lamp together with the illumination of a red lamp below it.

The restoration to normal of a route established having an entrance point at signal location C is effected in a general manner similar to that which has been described. That is, the pulling out of the button CPB can be effective to initiate the restoration of a route to normal in accordance with manual designation, or such route establishing means can be restored to normal automatically upon the passage of a train. If manual restoration is designated for a route having an entrance point at C for either direction of traffic, when such route is governed by either a call-on or a high speed signal, the pulling out of the button CPB for designation of the restoration desired causes the dropping away of the entrance relay energized for that signal location by the opening of the stick circuit for such relay at contact 184 of button CPB. The restoration of the route establishing means in accordance with the dropping away of an entrance relay is effected in a manner corresponding to that which has been described.

Having thus described in detail typical operating conditions in connection with the establishment of routes involving a double intermediate signal location at C for a particular direction of traffic, it is believed to be readily apparent from the circuits which have been described, inasmuch as the circuits are comparable for both directions of traffic, that a similar mode of operation is prevalent in the establishment of routes for west-bound traffic. It is also to be understood that certain modifications of the circuits described can be made to conform to conditions encountered in practice where there may be only a single intermediate signal.

Optional routes.—A primary requisite of an entrance-exit system is that such system provide a means for selecting a preferred one of a plurality of optional or alternative routes extending between an entrance and an exit point. That is, with reference to the track layout illustrated in Fig. 3, there are two alternative routes extending between signal locations A and D. In accordance with the circuits shown in Figs. 1A and 1B, it is provided that, when both of such alternative routes are available for use, the route diverging nearest the designated entrance point is established in preference to the other route. This rule also holds true in more complex track layouts where there are several optional or alternative routes extending between an entrance and an exit point, but it does not apply where a run-around route is involved as the principle

governing optional routes with reference to run-around routes is that the most direct route is given preference to all others.

The preselection of a preferred one of a plurality of alternative routes is provided in accordance with the selective energization of the relays AN, BN and N which are energized responsive to entrance designation as has been considered to some extent when considering the conditioning of the system responsive to the actuation of a control button for designation of an entrance point. To provide the selection of a preferred route in accordance with the principles as set forth above, it is provided that a normal switch control relay AN, BN or N is picked up responsive to entrance designation when its track switch can be trialed in a normal position in an available route extending from an entrance point which has been designated. The picking up of such primary normal switch control relay definitely selects that the position of that track switch shall be normal if such track switch is to be included in a route extending from the entrance point which has been designated, although execution of such normal control is delayed in a manner and for purposes which have been heretofore described.

It is therefore provided in accordance with such general principles that, for example, in setting up a route from A to D, the designation of an entrance point at A so conditions the track switches that the route between such points via crossover 1 will be established in preference to the alternative route via crossover 3 after the exit point at D has been designated. Although there is no reverse relay picked up responsive to entrance designation to select the reverse position of the track switches of crossover 1, the picking up of relay 3BN responsive to entrance designation at A, in accordance with the above described principles for the energization of such relay, provides that the track switches of crossover 3 must be operated to normal positions in the establishment of such route, and such being the case, provides that the only route remaining available to be established including the track switch at the B end of crossover 3 in a normal position is a route from A to D extending over crossover 1. If, for example, there were other crossovers to the right of crossover 3 which would also provide alternative routes, in accordance with the principles as heretofore set forth, relay BN would be picked up for the track switch at the lower end of each of such crossovers to render the optional route including such crossover unavailable, in view of the availability of the route from A to D over crossover 1.

From the above general description, and from the specific examples to be hereinafter described, it is believed to be obvious to those skilled in the art how the system of optional route selection can be applied to track layouts in which several optional routes are involved, and how these same principles of optional route selection can be applied where some or all of such alternative routes include one or more intermediate signals.

To consider as a specific example of how a particular one of several alternative routes is established, assume that an operator designates an entrance point at A at a time when a route is available from A to D via either crossover 1 or crossover 3. The depression of button A under such conditions causes the picking up of relay ANR in a manner which has been de-

scribed, and responsive to picking up of relay ANR energy feeds through the conditioning portions or branches of the conditioning circuit network corresponding to routes which are available. Such conditioning causes the picking up of relay 3BN by the energization of a circuit which has been described, and the depression of button DPB (subsequent to the picking up of relay 3BN) for designation of an exit point causes the picking up of relay DXR by the energization of a circuit closed from (+), including front contact 27 of relay ANR (see Fig. 1A), back contact 33 of relay 1AN, back contact 34 of relay 1BN, wire 40, back contact 35 of relay 2R, back contact 39 of relay 3R, front contact 31 of relay 3BN, back contact 32 of relay DNL, winding of relay DXR, and contact 237 of button DPB closed in a depressed position, to (-). The picking up of that relay closes a stick circuit at front contact 238 to shunt contact 237 out of the circuit just described. Responsive to the picking up of relay DXR, the relay 2N is picked up by the energization of a circuit closed from (+), including front contact 239 of relay DXR, back contact 240 of relay DNL, back contact 241 of relay 3R, back contact 242 of relay 2R, and upper winding of relay 2N, to (-). When relay 2N is picked up, the relay 1R is picked up because its energization is selected in accordance with the dropped away position of relay 1BN at that time, by the energization of a circuit closed from (+), including front contact 243 of relay DXR, front contact 244 of relay 3BN, front contact 245 of relay 2N, wire 246, back contact 247 of relay 1BN, upper winding of relay 1R, back contact 248 of relay 1BN, and back contact 249 of relay 1AN, to (-).

It will be noted from the circuit just described for relay 1R that each of the R relays is connected into a circuit network arrangement having feed points corresponding to the respective exit points for both directions of traffic, and having circuit portions correspond to the various routes through the track layout. Such circuit network, as has been heretofore pointed out, also provides for the execution of the switch controls. The use of such a circuit network for the control of the reverse switch control relays and for the execution of the switch controls provides that the reverse switch control relays and the WZ relays are energized only after an exit point has been designated for a route which has been conditioned, and thus insures before rendering the setting up of a route effective that such route has had both its entrance and exit ends properly designated by an operator.

The picking up of relay DXR subsequent to the picking up of relays 3BN causes the energization of relay 3BWZ and the picking up of relay 2N causes the energization of relay 2WZ in a manner corresponding to that which has been described for the execution of a normal switch control, and the picking up of relay 1R causes the picking up of relays 1AWZ and 1BWZ for the execution of the reverse switch control for the track switches of crossover 1. The relay 1BWZ is picked up under such conditions upon the closing of an obvious circuit at front contact 150 (see Fig. 1A), and relay 1AWZ is picked up responsive to the picking up of relay 1R upon the closing of an obvious circuit at front contact 58.

The picking up of the relays WZ for the respective track switches included in the route selected provide that the route is set up in accordance with the normal and reverse controls

selected by the route establishing means, and a signal control circuit is closed for governing entrance to such route in a manner which has been described when considering in detail the signal controls.

If for some reason, in the setting up of a route from A to D, the route via crossover 1 is not available, the relay 3BN cannot be picked up responsive to the designation of an entrance point at A, because the unavailability of the route via crossover 1 is defined by the picked up positions of relay 1BN and/or relay 2R. Such relays would of course be picked up if a conflicting route has been established, or if a conflicting route is occupied by a train. It is also provided that such conflict can be manually designated if an operator desires to cause the route to be set up from A to D via crossover 3 when the route via crossover 1 is apparently available for use, by the actuation of the lever 1SML, for example, to a normal operating position to cause the picking up of relay 1BN. The picking up of that relay of course prevents the energization of relay 3BN when an entrance point is subsequently designated at A by opening a circuit which has been described for relay 3BN at back contact 34.

Therefore, if it is assumed that there is not an available route from A to D via crossover 1, and a route is available via crossover 3 between such route ends, the designation of an entrance point at A causes the picking up of no normal switch control relays, because there are no available routes including any of the track switches trailed in their normal positions, but such entrance designation does of course condition the relay DXR for energization upon the designation of an exit point for such route end. Thus, upon designation of an exit point at D, the relay DXR is picked up because of the energization of a circuit closed from (+), including front contact 21 of relay ANR (see Fig. 1A), back contact 28 of relay 1R, wire 39, back contact 30 of relay 3AN, back contact 31 of relay 3BN, back contact 32 of relay DNL, winding of relay DXR, and contact 237 of button DPB closed in a depressed position, to (-). The picking up of relay DXR closes a stick circuit for that relay at front contact 238 to shunt contact 237 out of the circuit just described.

Responsive to the picking up of relay DXR, the relay 3R is picked up by the energization of a circuit closed from (+), including front contact 243 of relay DXR (see Fig. 1B), back contact 244 of relay 2BN, winding of relay 3R, back contact 251 of relay 3BN, and back contact 252 of relay 3AN, to (-). A circuit is also closed at the same time to cause the picking up of relay 1AN from (+), including front contact 239 of relay DXR, back contact 240 of relay DNL, back contact 253 of relay 3BN, back contact 44 of relay 3AN, wire 59, back contact 45 of relay 1R, and upper winding of relay 1AN, to (-). Responsive to the picking up of relays 3R and 1AN execution becomes effective respectively for the track switches of crossovers 3 and 1 to cause a route to be completely established from A to D via crossover 3. The establishment of such route of course causes the clearing of a signal governing entrance thereto in accordance with the energization of signal control circuits in a manner which has been described.

In accordance with some requirements of railroad practice, it may be required that a particular route of a plurality of optional routes to be established for either direction of traffic when

available in preference to the other alternative routes. Such preference can be required, for example, under a condition where it is desirable that a particular high speed track switch or crossover be used in preference to lower speed track switches and crossovers whenever possible. To consider an example of how such preference may be required, reference is made to the modification shown in Fig. 8 of the circuits which have been heretofore described for the route establishing means shown in Figs. 1A and 1B. In such modification, it is assumed that a route establishing means is provided for a track layout corresponding to the track layout shown in Fig. 3, and the circuits for such route establishing means are provided in such a manner that of the two alternative routes between A and D, the route including crossover 3 is established when available in preference to alternative routes between A and D for either east-bound or west-bound traffic.

In accordance with the general principles of optional route selection as they have been set forth, the route from D to A will be established via crossover 3 because such route diverges nearest the entrance point at D. Thus, for west-bound traffic, such route is given preference over the alternative route because of the picking up of relay 1AN responsive to entrance designation at D as such relay is energized whenever there is an available route extending from a designated entrance point over the track switch for the upper end of crossover 1 trailed in a normal position. The picking up of such relay 1AN definitely selects that the track switches of the crossover 1 shall be in their normal positions in a route established emanating from that entrance point, all of which being effective in a manner very similar to that which has been described.

A different situation exists however, with respect to establishing as a preferred route the route from A to D via crossover 3 for east-bound traffic in that such route is not established via the crossover diverging nearest the entrance point designated. To provide preference for that particular route over the alternative route via crossover 1, an extra conditioning relay 3BY is provided which is energized responsive to entrance designation at A only when there is an available route extending over crossover 3 from that entrance point. The picking up of that relay conditions the relay DXR for energization, and also selects that the position of the track switches of the crossover 3 shall be reverse if an exit point is designated at D.

To consider more specifically how such mode of operation is effective, assume that an operator designates an entrance point at A and causes the picking up of the entrance relay ANR in accordance with the general mode of operation of picking up such entrance relay as described with reference to Fig. 1A. The picking up of relay ANR responsive to entrance designation causes the picking up of relay 3BY by the energization of a circuit closed from (+), including front contact 254 of relay ANR, back contact 255 of relay 1R, back contact 256 of relay 3AN, back contact 257 of relay 3BN, and winding of relay 3BY, to (-). The picking up of relay 3BY conditions the relay DXR for energization so that the depression of button DPB for designation of an exit point at D causes the picking up of that relay by the energization of a circuit closed from (+), including front contact 254 of relay ANR, back contact 255 of relay

1R, back contact 256 of relay 3AN, back contact 257 of relay 3BN, front contact 258 of relay 3BY, back contact 259 of relay DNL, winding of relay DXR, and contact 260 of button DPB closed in a depressed position, to (-). The picking up of that relay closes a stick circuit at front contact 261 to shunt contact 260 out of the circuit just described.

Responsive to the picking up of relay DXR in the establishment of a route under the above assumed conditions, the relay 3R is picked up because that relay is selected in preference to relay 3BN by the picked up position of the preconditioning relay 3BY. The relay 3R is picked up by the energization of a circuit closed from (+), including front contact 515 of relay DXR, front contact 262 of relay 3BY, winding of relay 3R, back contact 263 of relay 3BN, and back contact 264 of relay 3AN, to (-).

The relay 1AN is picked up responsive to the picking up of relay DXR because the track switch which it controls would be trialed in a normal position if a train were to pass from D to A over an available route via crossover 3. Thus the relay 1AN is picked up by the energization of a circuit closed from (+), including front contact 265 of relay DXR, back contact 266 of relay DNL, back contact 267 of relay 3BN, back contact 268 of relay 3AN, back contact 269 of relay 1R, and winding of relay 1AN, to (-).

Responsive to the picking up of relays 3R and 1AN, the track switches of the crossovers 3 and 1 respectively are operated to corresponding positions in accordance with the closing of execution circuits (not shown in Fig. 8) which correspond to the execution circuits shown in Figs. 1A and 1B which have been heretofore described. The operation of the track switches to their proper positions to establish a route from A to D via crossover 3 causes the clearing of a signal for governing entrance to such route in a manner similar to that which has been described when considering the signal controls in detail.

If the preferred route is not available from A to D (see Fig. 8) via crossover 3, as is the case if relay 3AN is picked up, the inferior route extending from A to D via crossover 1 can be established if such route is available because the circuit for relay 3BY is open at back contact 258 to provide that such relay cannot be picked up responsive to the designation of an entrance point at A.

Responsive to the designation of an entrance point under the above assumed conditions, the relay DXR is conditioned for energization so that the designation of an exit point at D by the depression of button DPB will cause the picking up of relay DXR by the energization of a circuit closed from (+), including front contact 254 of relay ANR, back contact 271 of relay 1AN, back contact 272 of relay 1BN, back contact 273 of relay 2R, back contact 274 of relay 3R, back contact 258 of relay 3BY, back contact 259 of relay DNL, winding of relay DXR, and contact 260 of button DPB closed in a depressed position, to (-). The picking up of that relay closes a stick circuit at back contact 261 to shunt contact 260 out of the circuit just described.

Responsive to the picking up of relay DXR the relay 3BN is picked up (because that relay is selected in preference to relay 3R by the dropped away position of relay 3BY) by the energization of a circuit closed from (+), including front contact 515 of relay DXR, back contact 262 of

relay 3BY, upper winding of relay 3BN, and back contact 516 of relay 3R, to (-).

The relay 2N is picked up responsive to the picking up of relay DXR upon the energization of a circuit closed from (+), including front contact 265 of relay DXR, back contact 266 of relay DNL, back contact 517 of relay 3R, back contact 278 of relay 2R, and upper winding of relay 2N, to (-).

10 The picking up of relay 2N definitely determines that the route established is to include the track switch 3 in a normal position, and thus selects the control for the relay 1R which governs the operation of the track switches of crossover 1 to reverse positions. The relay 1R is picked up subsequent to the picking up of relay 2N upon the energization of a circuit extending from (+), including front contact 515 of relay DXR, back contact 262 of relay 3BY, front contact 279 of relay 2N, back contact 230 of relay 1BN, upper winding of relay 1R, back contact 231 of relay 1BN, and back contact 232 of relay 1AN, to (-).

25 The execution of the switch controls to establish the route in accordance with the switch positions selected by the energization of the relays 1R, 2N and 3BN is effected in a manner similar to that which has been described, and the signal governing entrance to such route at A is cleared after such track switches have been properly positioned.

30 Inasmuch as many different conditions may arise in which preference to a particular route such as the route from A to D via crossover 3 is required, it is to be understood that the circuits which have been described with reference to providing preference for a particular route in Fig. 8 is merely a typical condition that can be applied to other types of track layouts. It is 35 also to be understood that, for the track layout illustrated, the route from A to D via crossover 3 can be given preference even if other crossovers providing other optional or alternative routes between A and D are provided to the right 40 of crossover 3. If there are other crossovers, in order to maintain the preference from A to D via crossover 3, the circuits provided for such other crossovers would be arranged in a manner corresponding to the circuits provided for 45 crossover 1. Under such conditions, inasmuch as the route from D to A via crossover 3 would not be the first route diverging from an entrance point at D, the circuits for the relay 3AN would have to be provided comparable to the circuits 50 to relay 3BN, and a relay 3AY (not shown) would be provided for the upper end of crossover 3 responsive to entrance designation at D in a manner comparable to the response of the 55 relay 3BY as has been described to entrance designation at A.

SECOND FORM OF THE INVENTION

60 *General organization.*—To simplify the disclosure and description of the present invention, the modified or second form of the invention is assumed to be applied to the track layout of Fig. 3 (the same as used for the first form), although it is to be understood that the principles of operation of both forms of the invention may be universally applied to all types of track layouts encountered in practice. It is also arranged that those parts of the second form which are used in common with the parts of the first form, have 65 been given the same reference characters in order

to readily identify the common parts and to apply the description to these common portions.

More specifically, Figs. 9A and 9B show the same track diagram as shown in Figs. 1A and 1B for convenience in considering the route establishing means of this form. The bus interlock arrangement and its response to the control buttons to provide for single button operation is the same as shown in Figs. 1A and 1B. The novel features shown in Figs. 9A and 9B relate more particularly to the arrangement and operation of the route establishing means, and there are, of course, other features shown in other figures in connection with the control of the indicator lamps for the display of indications, and the like, hereinafter pointed out in detail.

The route establishing means of Figs. 9A and 9B includes two conditioning networks, one conditioning network having feed points for the signal locations at the right-hand end of the track layout and the other conditioning network having feed points for the signal locations at the left-hand end of the track layout. These conditioning networks effect the control of the normal switch control relays AN, BN and N in a manner similar to that described in connection with Figs. 1A and 1B, but in addition to providing this control for the normal primary switch control relays, these conditioning networks also effect the control of the reverse switch control relays R. In other words, the conditioning networks not only effect the conditioning or preselecting operation but also effect the completion operation.

Each of the primary switch control relays R is provided with three windings a, b and c. The windings a and b of any relay R must both be energized in order to cause the relay to be picked up, but the energization of the winding c by the operation of an associated auxiliary switch control lever SML will alone effect the picking up of this relay. In other words, these switch control relays R are of the marginal relay type. It is also noted that this form of the present invention requires only one polar neutral secondary switch control relay WZ for each track switch or crossover.

Route establishing means.—With reference to Figs. 9A and 9B, the actuation of any control button to designate a signal location as an entrance point, effects the energization of its associated entrance relay, such as relay ANR, for example, and the interlock bus arrangement is conditioned to cause the subsequent actuation of another control button to be effective to designate an exit point.

The picking up of an entrance relay energizes the associated conditioning network to condition for energization the exit relay for the exit end of each available route originating at such designated entrance signal location and also to energize the normal switch control relays AN, BN or N for each track switch that can be trailed in a normal position for any of such available routes. Also, the application of energy to such conditioning network also conditions the reverse switch control relay for each track switch that can be included in a reverse position in an available route extending from the entrance point designated. Such conditioning is effected by the energization of one of the marginal windings of such relay so that the energization of the other marginal winding of that relay in response to the designation of an exit point can cause such relay to be picked up.

The actuation of a control button such as the

button DPB, subsequent to the designation of an entrance point, causes the energization of the associated exit relay which applies energy to its associated conditioning network to perform a completion operation with respect to that particular route having its entrance and exit ends thus designated. This operation also restores the bus interlock arrangement to normal conditions.

More specifically, the actuation of the control button APB, for example, closes back contact 6 to energize the entrance relay ANR, which picks up and sticks dependent upon the track relay 1ATR as previously described.

The picking up of the entrance relay ANR closes front contact 460 to apply energy to the associated conditioning network to condition for energization the exit relays CXR, DXR and EXR, and to perform the preselection operation. For example, the relay CXR is conditioned by a circuit closed from (+), including front contact 460 of relay ANR, back contact 461 of relay 1R, wire 462, back contact 463 of relay 3R, back contact 464 of relay CNL to the left-hand terminal of relay CXR.

15 The marginal relay 1R is conditioned by the energization of its winding a over a circuit closed from (+), including front contact 460 of relay ANR, back contact 359 of relay 1AN, back contact 351 of relay 1BN, winding a of relay 1R, to (-). This relay 1R, however, will not pick up until and unless its other winding b is also energized.

20 The marginal relay 3R is also conditioned by the energization of its winding a over a circuit closed from (+), including front contact 460 of relay ANR, back contact 461 of relay 1R, wire 462, back contact 357 of relay 3AN, back contact 358 of relay 3BN, winding a of relay 3R, to (-). Energy cannot be passed on from the left-hand terminal of the winding a of relay 3R because the relay 3BN is energized and picked up.

25 The energizing circuit for the relay 3BN is closed from (+), including front contact 460 of relay ANR, back contact 350 of relay 1AN, back contact 351 of relay 1BN, back contact 352 of relay 2BN, wire 353, back contact 354 of relay 2R, back contact 355 of relay 3R, upper winding of relay 3BN, to (-).

30 When the relay 3BN picks up it closes front contact 359 to pass energy on to back contact 360 of relay DNL to the left-hand terminal of the exit relay DXR to condition it for energization.

35 The winding a of relay 2R is energized conditioning this relay for being picked up, by the connection of its left-hand terminal through contact 356 of relay 2N to the wire 353 receiving energy as above pointed out.

40 The relay EXR is conditioned for energization by supplying energy from the wire 353 through back contact 358 of relay 2N, back contact 465 of relay ENL, to the left-hand terminal of the relay EXR.

45 Thus, the operation of any one of the buttons CPB, DPB or EPB would effect the energization of the associated exit relay and cause a route to be established from the entrance point A in accordance with the preselection operation.

50 Let us assume, however, that the operator actuates the control button DPB closing back contact 237 which applies negative potential (-) to the right-hand terminal of the relay DXR causing it to be energized and pick up its contacts. The closure of its front contact 238 completes a stick circuit for this relay DXR to maintain it energized when the control button DPB is re-

leased. The response of the exit relay DXR while the button DPB is operated, restores the bus interlock arrangement to normal conditions by closing the associated cancellation circuit.

The releasing of the button DPB closes front contact 237 and with the front contact 466 of relay DXR closed energizes the relay DXS which closes its stick contact 467. The picking up of this relay DXS effects the opening of the cancellation circuit as above described in connection with the relay CXS of Fig. 1B.

Upon the picking up of relay DXR, a circuit is closed to cause the picking up of relay 2N from (+), including front contact 363 of relay DXR, back contact 364 of relay DNL, back contact 365 of relay 3R, back contact 366 of relay 2R, and upper winding of relay 2N, to (—). The relay 1AN is not picked up responsive to the picking up of relay DXR because the circuit for that relay is opened at back contact 367 of relay 3BN. The picking up of relay 2N opens the circuit for the upper winding *a* of relay 2R at back contact 356.

Responsive to the picking up of relay 2N, a circuit is closed to cause the picking up of relay 1R by the energization of its marginal winding *b* from (+), including front contact 363 of relay DXR, back contact 364 of relay DNL, back contact 365 of relay 3R, back contact 366 of relay 2R, front contact 368 of relay 2N, wire 369, back contact 370 of relay 1BN, back contact 371 of relay 1AN, winding *b* of relay 1R, to (—). The energization of both windings *a* and *b* for that relay 1R causes the relay 1R to be picked up, and thus completes the selection of the positions for the various track switches included in the route from A to D via crossover 1.

The picking up of an exit relay, such as exit relay DXR, for example, not only applies energy to its associated conditioning network to perform a completion operation, but also simultaneously applies energy to the execution network so as to position the secondary switch control relays WZ for only those track switches included in a designated route as determined by the pre-selection and completion operations. In other words, there may be normal primary switch control relays energized for available routes originating at a designated entrance point which are not used but are dropped out during the completion operation, but these relays cannot cause the control of their associated secondary switch control relays due to the arrangement of circuit selections in the execution network.

More specifically, the picking up of the exit relay DXR applies energy to a switch execution circuit network having circuits similar to the circuits which have been described for completion and execution with reference to Figs. 1A and 1B, except that only one secondary switch control relay WZ is provided per crossover, and such circuit network does not govern the energization of the reverse switch control relays R. Thus, the picking up of relay DXR in setting up a route from A to D via crossover 1 causes the picking up of the relay 3WZ by the energization of a circuit selected by the picked up position of relay 3BN closed from (+), including front contact 372 of relay DXR, asymmetric device 373, front contact 374 of relay 3BN, lower winding of relay 3WZ, and back contact 375 of relay 3R, to (—). The picking up of relay 3WZ due to such energization causes the operation of the track switches of crossover 3 to normal positions in accordance with switch control circuits similar to the typical

switch control circuits shown in Fig. 10 and hereinafter described.

The track switch 2 is operated to a normal position when relay 2WZ is picked up in response to the picking up of relay 2N upon the energization of a circuit closed from (+), including front contact 372 of relay DXR, front contact 376 of relay 3BN, front contact 371 of relay 2N, asymmetric device 378, front contact 379 of relay 2N, lower winding of relay 2WZ, and back contact 380 of relay 2R, to (—).

The picking up of relay 1R causes the picking up of relay 1WZ for the operation of the track switches of crossover 1 to reverse positions in accordance with the closing of an obvious circuit for the lower winding of relay 1WZ, at front contact 381 of relay 1R, (see Fig. 9A).

Typical switch control (Fig. 10).—The control for the various track switches and crossovers of a track layout governed by the route establishing means of Figs. 9A and 9B has been typically shown in Fig. 10, certain of those relays and controls which are the same as Fig. 2 being repeated and given the same reference characters so that corresponding parts of the description with respect to Fig. 2 also applies to this Fig. 10.

It will be noted, however, that a single secondary switch control relay 1WZ controls the opposite ends of a crossover so that the relay 1LS is normally energized by a circuit closed from (+) including front contact 468 of relay 1BLR, front contact 489 of relay 1ALR, back contact of relay 470, winding of relay 1LS, to (—). A stick circuit for shunting out the back contact 470 of relay 1WZ is closed by a front contact 471 of relay 1LS, back contact 472 of relay 1NCR and back contact 473 of 1RCR.

The correspondence relays 1NCR and 1RCR are each provided with their own circuits. More specifically, relay 1NCR is energized, when the relay 1WZ is energized to a normal controlling position if the track switches are in correspondence therewith, by a circuit closed from (+), including front contact 481, polar contact 482 of relay 1WZ in a right-hand position, winding of relay 1NCR, polar contact 480 of relay 1WP in a left-hand position, front contact 478 of relay 1WP, to (—).

The relay 1RCR is energized when the relay 1WZ is energized to a reverse controlling position and the track switches are in correspondence therewith by a circuit closed from (+) including front contact 481 of relay 1WZ, polar contact 482 of relay 1WZ in a left-hand position, windings of relay 1RCR, polar contact 480 of relay 1WP in a right-hand position, front contact 479 of relay 1WP, to (—).

The energization of the relay 1WZ to a reverse controlling position, as above described, calls for the track switches 1ATS and 1BTS of the crossover 1 to be operated to its reverse positions which is effected by the closure of a reverse operating circuit for the switch machines closed from (+) through a circuit including polar contact 383 of relay 1WZ in a left-hand position, front contact 483 of relay 1WZ, front contact 484 of relay 1LS, through the switch machines 1ASM and 1BSM in multiple, front contact 485 of relay 1LS, front contact 486 of relay 1WZ, polar contact 382 in a left-hand position, to (—). It will be obvious that the switch machines 1ASM and 1BSM may be operated to normal positions by the application of the opposite polarity applied to their operating circuits when the relay 1WZ is energized to its nor-

mal controlling position with polar contact 382 and 383 in right-hand positions.

During the operation of the track switches 1ATS and 1BTS the relay 1WP is deenergized closing back contact 478 and applying positive potential (+) to the stick circuit for the relay 1WZ including front contact 475 of relay 1WZ, and polar contacts 476 and 477 in right or left-hand positions depending upon whether the relay 1WZ is in a normal controlling position or in a reverse controlling position. This stick circuit insures that the track switches will be fully operated to normal or reverse positions, irrespective of the deenergization of the primary switch control relays before the switch machines have completed their operating strokes.

While a route is cleared over one, or the other, or both of these track switches 1ATS and 1BTS, the respective lock relays 1ALR and 1BLR are controlled as above described in connection with the route locking provided in Fig. 4. Thus, potential (+) is applied through either or both of the back contacts 468 and 469 to the stick circuit of the relay 1WZ just pointed out as having energy applied during operation of the switch machine at front contact 478 when one or more routes are set up over the track switches 1ATS and 1BTS.

It will, of course, be understood that when the track switches have been operated into correspondence with the relay 1WZ, the proper correspondence relay 1NCR or 1RCR will be energized opening the stick circuit for the lock stick relay 1LS which is then deenergized and shunts the control circuits for the switch machines at back contact 484.

The individual control of the crossover 1 may be effected by its auxiliary lever 1SML operated to either normal or reverse controlling position from its neutral position as described in connection with Fig. 2.

Signal control circuits.—When the entrance and exit ends of a desired route have been designated and the switches have operated into correspondence with the controls effected by the route establishing means, the correspondence relays for the track switches of that route are energized and the respective lock stick relays are deenergized, thus completing a signal clearing circuit for the signal at the entrance end of such route as shown in Fig. 3 of the accompanying drawings. In other words, the track layout and signal circuits of Fig. 3 are also associated with this form of the invention shown in Figs. 9A and 9B.

More specifically, the signal AG is cleared by reason of the energization of the signal control relay AGR, over a circuit closed from (+), including front contact 487 of relay DGR, back contact 488 of relay DNR, back contact 489 of relay 3RCR, front contact 490 of relay 3NCR, back contact 491 of relay 3LS, back contact 492 of relay 2RCR, front contact 493 of relay 2NCR, back contact 494 of relay 2LS, front contact 495 of relay 1RCR, back contact 90 of relay 1NCR, back contact 91 of relay 1LS, front contact 92 of relay ANR, windings of relay AGR, to (-).

It is of course to be understood that other types of signal control circuits as well as other types of signals than those shown in Fig. 3 can be used in accordance with the requirements of practice with the route establishing means as shown in Figs. 9A and 9B.

Restoration to normal.—The restoration to

normal of the system as provided in the form of the present invention shown in Figs. 9A and 9B can be effected responsive either to manual designation of such restoration or automatically upon passage of a train in a manner similar to that which has been described in connection with Figs. 1A and 1B, and thus reference for the restoration of the system is provided by the second form of the present invention can be made 10 to the description as heretofore set forth with reference to the first form of the present invention relative to manual restoration to normal and to automatic restoration upon passage of a train. When restoration is effective in an automatic manner upon passage of a train, the primary switch control relays AN, BN, N and R are maintained energized by their stick circuits provided for their lower windings as long as their respective track switches are electrically locked 20 by the route locking for the respective detector track sections for such track switches.

Route locking.—It is assumed that the route locking of the rear release type is provided for use with the system embodying the route establishing means as shown in Figs. 9A and 9B in which normally energized directional stick route locking relays ES and WS are provided in a manner corresponding to that shown in Fig. 4 of the accompanying drawings. It is to be understood, however, that other types of route locking can as well be used with the route establishing means shown in Figs. 9A and 9B, and that approaching locking can be applied if such is the requirements of practice by the use of a 30 time element relay to delay the picking up of the directional stick route locking relays at such times as is required in practice to provide approach locking or time locking. That is, the circuits for the east and west stick route locking relays can be provided in accordance with the circuit shown, for example, in the patent to C. F. Stoltz, Patent No. 2,115,511, dated April 26, 1938 in which it is provided that a time element is inserted in the pick-up circuit under certain 35 conditions of the route locking relays to provide approach locking.

End-to-end control.—Having considered in detail a system of end-to-end control which is applicable to the route establishing means provided 50 in the first form of the present invention, it is believed to be readily apparent to those familiar with the art how such system of end-to-end control can be applied to the route establishing means for the second form of the present invention as illustrated in Figs. 9A and 9B inasmuch as the end-to-end control is primarily concerned with the picking up of the entrance and exit relays for respective entrance and exit points at intermediate signal locations included in a 55 through route as well as at the extreme ends of such route, and the entrance and exit relays illustrated in Figs. 9A and 9B are controlled in a manner comparable to the control of similar relays as shown and described with reference to the 60 first form of the present invention.

Optional routes.—The second form of the present invention is not unlike the first form in that the picking up of a reverse switch control relay does not take place until it is definitely determined that the associated track switch must be in a reverse position in a route being established. That is, normal switch control relays are picked up for the various routes emanating from a designated entrance point, but the picking up of reverse switch control relays is delayed until after

the designation of an exit point for the particular route to be established.

Inasmuch as the normal and reverse switch control relays are interlocked so that only one may be picked up at a time, and the normal relays may be energized prior to the reverse relays, any track switch that can be in either of its positions to establish a route connecting the designated entrance and exit points is operated to its normal position in preference to its reverse position. Thus, with reference to Figs. 9A and 9B, the designation of an entrance point at signal location A causes the picking up of the relay 3BN which opens the contact 358 preventing the continued energization of the winding *a* of relay 3R. Also, the opening of contact 367 prevents the energization of the winding *b* of the relay 3R upon the picking up of the exit relay DXR. Such being the case, if there is an available route over the crossover 1 reversed, that route will be established in preference to the alternative route between signal locations A and B via the crossover 3.

It is therefore provided that of several optional or alternative routes between designated entrance and exit points, the available route diverging nearest the designated entrance points will be set up in preference to any other of the alternative routes. In the case of run-around routes, the most direct route is established in preference to indirect routes by reason of preselection operation being actively performed for the normal position only of the trailed switches. These rules hold true even if some of the alternative routes include intermediate signals, and end-to-end or through route control is provided.

Having considered how a route is established from A to D via crossover 1 in accordance with the route establishing means shown in Figs. 9A and 9B, consideration will now be given as to how the route is established from A to D via crossover 3 when the route via crossover 1 is not available, or when an operator selects by the actuation of the auxiliary control lever 1SML to a normal position that the route from A to D via cross over 3 will be established in preference to the route via crossover 1. Thus, to consider a typical example, assume that the relay 1BN is picked up as would be the case if a route were established from B to E or if the operator had actuated the auxiliary control lever 2SML to a normal operating position.

Under such conditions the designation of an entrance point at A cannot cause the picking up of relay 3BN because the circuit for that relay is open at back contact 352 of relay 1BN. However, the upper winding *a* of relay 3R is energized by a circuit which has been described to condition the relay 3R so that it can be picked up responsive to exit designation. The relay 1R cannot have its upper winding *a* energized because the circuit for that winding is open at back contact 351 of relay 1BN at that time, and the opening of that contact also prevents the energization of the upper winding *a* of relay 2R by energy from front contact 460.

Upon designation of an exit point at D, after the system has been thus conditioned responsive to entrance designation at A, the relay 3R becomes picked up due to the energization of its center winding *b* by a circuit closed from (+), including front contact 363 of relay DXR, back contact 364 of relay DNL, back contact 367 of relay 3BN, back contact 384 of relay 3AN, and center winding *b* of relay 3R, to (-). At the 75

same time a circuit is closed to cause the picking up of relay 1AN extending from (+), including front contact 363 of relay DXR, back contact 364 of relay DNL, back contact 367 of relay 3BN, back contact 384 of relay 3AN, back contact 385 of relay 3AN, wire 386, back contact 327 of relay 1R, and upper winding of relay 1AN, to (-). The execution of the switch controls, and the clearing of the signal governing entrance to the route at 10 A is effected subsequent to the selection of the route by the picking up of relays 1AN and 1R in a manner similar to that which has been described with reference to Fig. 10.

Having thus described how optional routes are selected for one direction of traffic, it is to be understood that a similar mode of operation is effective for the opposite direction of traffic. That is, with reference to Figs. 9A and 9B, the preferred route from D to A is via crossover 3 because such route diverges nearest the designated entrance point, and if such route is not available, the next diverging route which is the route via crossover 1 is established.

Modified optional route selection (Fig. 12).—As 25 has been heretofore pointed out, it is sometimes desirable to provide that a particular one of several optional or alternative routes is to be used when available in preference to any other routes for railway operating reasons, such, for 30 example, as for the purpose of using a high speed track switch to be used when available in preference to lower speed track switches. Under such conditions, preference for such track switch can be provided as illustrated in Fig. 12 in which it is 35 provided that the route from A to D via crossover 3 is set up when available in preference to alternative routes. In such figure, it is provided that the reverse switch control relays for the crossover 3 are given preference over the normal switch control relays for that crossover in order 40 that a route may be established over such crossover with its track switches reverse, if there is an alternative route available between the respective entrance and exit points at A and D which 45 will include the track switch at the lower end of crossover 3 in a normal position and one that will include such track switch in a reverse position.

To provide reverse preference for the track 50 switches of crossover 3, a reverse switch control relay is provided for the track switch at each end of the crossover, and such relay is picked up responsive to entrance designation if that track switch can be trailed in an available route emanating from the entrance point designated. Thus, responsive to the designation of an entrance point A, the relay 3BR is picked up by the energization of a circuit closed from (+), including front contact 460 of relay ANR, back contact 461 of relay 1R, back contact 357 of relay 3AN, back contact 358 of relay 3BN, and upper winding of relay 3BR, to (-).

The upper winding of relay 3BN is only momentarily energized responsive to entrance designation at A when a circuit is closed for that relay extending from (+), including front contact 460 of relay ANR, back contact 359 of relay 1AN, back contact 351 of relay 1BN, back contact 352 of relay 1BN, back contact 354 of relay 2R, back contact 355 of relay 3BR, and upper winding *a* of relay 3BN, to (-). The energization of that winding does not cause the picking up of relay 3BN because the picking up of that relay is dependent upon the joint energization of the upper and center windings *a* and *b* respectively.

Thus, in view of the fact that relay 3BN cannot be picked up responsive to the energization of the circuit extending from front contact 460 of relay ANR, the circuit just described for relay 3BR remains established, and the picking up of relay 3BR opens the circuit just described for the upper winding of relay 3BN at back contact 355.

The upper winding *a* of the relay 1R is energized responsive to the picking up of relay ANR, by a circuit which has been described, but such energization does not cause the picking up of relay 1R because such relay can be picked up only if the upper and center winding *a* and *b* respectively for that relay are energized. A similar condition obviously exists with reference to the energization of the upper winding *a* of relay 2R.

Having thus considered the conditioning of the system responsive to entrance designation, assume that an operator designates an exit point at D subsequent to such conditioning. The picking up of relay DXR responsive to such exit designation causes the picking up of the relay 3AR by the energization of a circuit closed from (+), including front contact 363 of relay DXR, back contact 364 of relay DNL, back contact 367 of relay 3BN, back contact 368 of relay 3AN, and winding of relay 3AR, to (-).

Such relay is picked up because the track switch at the upper end of crossover 3 for which it is provided could be trailed in a reverse position if a train were to pass over the available route extending from D to A via crossover 1. The route from D to A via crossover 1 is not available at this time because the relay 3BR is picked up to define that the establishment of a route including the track switches over crossover 3 can be effected only if such track switches are to be operated to reverse positions.

The picking up of relay 3AR closes a circuit to cause the picking up of relay 1AN extending from (+), including front contact 363 of relay DXR, back contact 364 of relay DNL, back contact 367 of relay 3BN, back contact 368 of relay 3AN, front contact 388 of relay 3AR, back contact 385 of relay 3AN, back contact 387 of relay 1R, and upper winding of relay 1AN, to (-). The picking up of relay 1AN completes the selection of the route extending from A to D via crossover 3, and the execution of the switch control circuits to cause the energization of the relays 1WZ and 3WZ respectively is effected in a manner corresponding to that described with reference to Figs. 9A and 9B. Such execution differs from the circuits shown for the control of relay 3WZ in Fig. 9B only in the fact that such relay is picked up dependent upon the closing of front contacts of the two reverse relays for crossovers 3, 3AR and 3BR connected in series. After the track switches have completed their operation to the positions called for, the signal AG governing entrance to such route is cleared in a manner which has been described with reference to Fig. 3.

It is believed to be obvious that the route from D to A would be set up via crossover 3, even if there were one or more alternative routes diverging to the right of crossover 3, because of the energization of circuits comparable to those just described in detail for the setting up of the same route for the opposite direction of traffic.

It has been pointed out above how the route establishing means of Figs. 9A and 9B selects alternative routes with a predetermined preference, and how this predetermined preference may be changed in accordance with Fig. 12 as

applied to the track layout of Fig. 3. It is to be understood, however, that the route establishing means thus disclosed may be applied to various other track layouts in accordance with the principles of the invention disclosed herein. Also, it is to be understood that this form of the invention may have associated therewith through route or end-to-end control. In other words, several interlocked groups such as shown in Fig. 10 may be located end-to-end and inter-connections provided at each of the intermediate signal locations as disclosed in connection with Figs. 6A, 6B and 6C which specifically shows through route connections applied to the form of the invention disclosed in Figs. 1A and 1B. This may be explained another way by stating that the route establishing means included in Figs. 6A, 6B and 6C may have substituted therefor route establishing means as disclosed in Figs. 9A and 9B (or in Fig. 12) without in any way changing the features of operation of the through route control provided.

The through route control and interlock between the control buttons disclosed in Figs. 6A, 6B and 6C may also be used with other types of route establishing means employing the pre-selection principle, such, for example, as disclosed in the prior application of A. Langdon, Ser. No. 119,641, filed January 8, 1937.

30 Indications.—With reference to Figs. 11 and 5B, circuits are provided for the indicator lamps shown for various light sections along the track diagram illustrated in Fig. 9A. Although the types of indications displayed correspond to the types of indications displayed when circuits are provided as shown in Figs. 5A and 5B, the circuits shown in Fig. 11 are particularly adapted for use with the route establishing means of Figs. 9A and 9B having switch control means shown in Fig. 10.

To consider a specific example of how the indications are provided in accordance with the energization of circuits shown in Figs. 11 and 5B, assume that an operator causes the establishment of a route in accordance with the route establishing means as illustrated in Figs. 9A and 9B extending from A to D via crossover 1. The depression of the button for designation of the entrance point at A causes the flashing of the indicator lamp AGK in that button in accordance with the circuits shown in Fig. 5B, and the picking up of the exit relay DXR responsive to the designation of an exit point at D causes the immediate energization of the white lamp W in light section 3BN/RK. Such indicator lamp is illuminated upon the picking up of relay DXR by a circuit closed from (+), including front contact 389 of relay DXR, front contact 390 of relay 3BLR, front contact 391 of relay 3BTRP, and the white lamp W of light section 3BN/RK, to (-). The white lamp W in light section 3BNK is also illuminated at the same time by a circuit closed from (+), including front contact 389 of relay DXR, front contact 390 of relay 3BLR, center contact 392 of lever 3SML, front contact 393 of relay 3BN, front contact 394 of relay 3BTRP, and the white lamp W of light section 3BNK, to (-). After the relay 2N is picked up responsive to the picking up of relay DXR in a manner which has been described, the white lamp of light section 2NK is illuminated upon the energization of a circuit closed from (+), including front contact 389 of relay DXR, front contact 395 of relay 3BN, front contact 396 of relay 2N, front contact 397 of relay 1BLR, cen-

ter contact 398 of lever 2SML, front contact 399 of relay 2N, front contact 400 of relay 1BTRP, and the white lamp W of light section 2NK, to (—). At the same time a circuit is closed to cause the illumination of the white lamp of light section 1BN/RK by the energization of a circuit closed from (+), including front contact 389 of relay DXR, front contact 395 of relay 3BN, front contact 396 of relay 2N, front contact 401 of relay 1BLR, front contact 402 of relay 1BTRP, and the white lamp W of light section 1BN/RK, to (—).

When the relay 1R is picked up subsequent to the picking up of the relay 2N, a circuit is closed to cause the illumination of the white lamp in light section 1RK extending from (+), including front contact 389 of relay DXR, front contact 395 of relay 3BN, front contact 396 of relay 2N, front contact 403 of relay 1BLR, front contact 404 of relay 1ALR, center contact 405 of lever 1SML, front contact 406 of relay 1R, front contact 407 of relay 1ATRP, front contact 408 of relay 1BTRP, and the white lamp W of light section 1RK, to (—). At the same time a circuit is closed to cause the illumination of the white lamp of light section 1AN/RK extending from (+), including front contact 389 of relay DXR, front contact 395 of relay 3BN, front contact 396 of relay 2N, front contact 409 of relay 1R, front contact 410 of relay 1ALR, front contact 411 of relay 1ATRP, and the white lamp W of light section 1AN/RK, to (—). The energization of that lamp therefore, completes the illumination along the miniature track diagram of the portion which corresponds to the route established from A to D via crossover 1, and, upon the clearing of the signal governing entrance to such route, the indicator lamp in the button APB for the entrance point at A becomes steadily illuminated in accordance with the energization of an obvious circuit as shown in Fig. 5B.

The clearing of the signal governing entrance at A causes the dropping away of relays 1ALR, 1BLR and 3BLR, and the dropping away of relay 3BLR opens the circuit connecting the white lamp of light section 3BN/RK to the circuit network at front contact 390 and closes a circuit at back contact 398 to maintain such lamp energized as long as the lock relay 3BLR remains dropped away. In a similar manner, the dropping away of relay 1BLR disconnects the lamps of light sections 2NK and 1BN/RK from the circuit network and provides for energization of the lamps of such light sections upon the closing of respective back contacts 397 and 401. The closing of back contact 403 of relay 1BLR applies energy to the circuit described for the white indicator lamp in light section 1RK, and the closing of back contact 404 of relay 1ALR also supplies energy to that circuit, thus providing that the light section 1RK is maintained illuminated until after both of the lock relays 1ALR and 1BLR are picked up. The light section 1AN/RK is maintained illuminated in accordance with the closing of back contact 410 of relay 1ALR, but is independent of the lock relay 1BLR, thus providing that such light section becomes dark when the relay 1ALR is allowed to be picked up in the rear of a passing train.

It will be understood from the above consideration of Figs. 11 and 5B, and especially in view of the similarity of this form of the invention to the form shown in Fig. 5A, that the passage of a train into any track section of an established route causes an appropriate indication to

be displayed by deenergizing the white lamp W and energizing the red lamp R for the corresponding indicator section or portion on the track diagram. This operation with respect to 5 any indicator portion of the track diagram is effected through the track relay and its associated track repeating relay for the corresponding section, such as track relays 1ATR and its repeating relay 1ATRP for the track section 1AT (see 10 Fig. 3). Each track repeating relay is of the slow acting type. In brief, when any given route is established, the dropping of the lock relays for the track sections of such route isolates the control circuits for the lamps of the indication portions 15 on the track diagram from the indication network (see Fig. 11), so that the only thing that happens upon the automatic restoration of the entrance and exit relays by the entrance of a train into such route is to extinguish the indicator lamp for the corresponding entering signal and cause the indicator section for the first track section of such route to be illuminated red.

Similarly, the entrance of a train into any 20 succeeding section of the route deenergizes the associated track and track repeating relays for such section to cause the associated indicator sections of the track diagram to be illuminated red. Then, as the train passes through the route and the track relays for the successive sections 25 pick up in the rear of the train, the lock relays for such sections of course pick up in turn to deenergize the indicator lamps for the corresponding sections. Inasmuch as the track repeating relay for each section is slow acting, there is sufficient time for the lock relay of any 30 section to assume its proper position to deenergize the indication lamps for such section before the track repeating relay assumes its new position. Thus, as a train passes through a route and the lock relays for the sections in the rear of such train are successively picked up, the lamps for the corresponding indicator sections on the miniature track diagram become successively 35 deenergized.

45 *Cascading of switch operation.*—Inasmuch as the system provided by the present invention is contemplated for use in the control of complex track layouts, it may happen in accordance with the system as above described, that more switch machines will be operated at the same time than the source of power can conveniently handle, and it may become necessary in such cases to organize the system to provide for a more even distribution of the power load. In some cases, sufficient power distribution can be provided by allowing only one switch machine motor to be started at a time, while in other cases it may even be desirable to delay the operation of some of the track switches until others have completed their operation.

60 With reference to Fig. 13, it is provided by the present invention that even though some of the switch control relays WZ respond to route establishment at the same time, and others respond in quick succession because of the use of quick acting relays for the route establishing means, the track switches will be operated one at a time in a cascade manner, there being a predetermined time interval between the starting of each 65 of the switch machine motors.

70 Although the features of cascade operation shown in Fig. 13 may be applied to various types of route establishing means, it is assumed for convenience in the disclosure this cascade operation 75 is applied to the route establishing means

and switch control shown in Figs. 9A, 9B and 10. The track layout of Fig. 13 is exactly the same as shown in Fig. 3 and as considered for Figs. 9A and 9B, but in order to indicate how any other switch for the same interlocked group (or if desired some other interlocked group) might be connected in the cascade circuit arrangement, the relays and circuit connections for some other such switch has been shown. It should be noted, however, that these relays are preferably considered to be associated with some other switch in the same interlocked group, with a similar group of relays as shown in Fig. 13 associated with each of the different interlocked groups of a large track layout. This is because there is a certain time period of delay between the execution of the switch controls to the WZ relays of one interlocked group and the next interlocked group included in any through route, by reason of the successive operations involved in the through route connections for adjoining interlocked groups.

The apparatus provided for each track switch includes a WZP relay of the slow pick-up type associated with each of the secondary switch control relays WZ and the corresponding switch indication relay WP. These three relays for each track switch or crossover included within the particular group to have cascade operation provided therefor, have associated therewith a single normally energized relay WZL of the slow release type. This relay WZL is made sufficiently slow in dropping away to provide that it will be maintained picked up during the period required for the execution of the switch controls from the primary switch control relays to the secondary switch control relays WZ for any particular route being established. Its pick-up circuit is opened upon the picking up of the first WZ relay to be energized in the establishment of a route, and if the track switch or track switches governed by such WZ relay are out of correspondence with the position of such track switch or track switches, then the relay is dropped away. The time interval between the successive operations of the track switches, can be varied in accordance with the requirements of practice by varying the pick-up time characteristics of the relays WZP without in any way delaying the automatic selection of a route by the route establishing means as heretofore described. If desired, the pick up time of the relays WZP can be prolonged by the use of thermal relays or the like, so that each switch machine (or pair of machines) will complete its operation, before the next switch machine is initiated. Such arrangement has not been shown, as it is well understood how a thermal relay may be energized to close a pick-up circuit for a relay, which relay when picked up deenergized the thermal relay but maintains itself stuck up.

To consider specifically how such mode of operation is effective, assume, for example, that a route has been established in a manner heretofore described from A to D via crossover 1 to cause the picking up of the relays 1WZ, 2WZ and 3WZ, in accordance with the circuits as heretofore described with reference to the second form of the present invention. Also assume that each of the track switches included in that route is out of correspondence with the position called for by the energized condition of the relay WZ for that track switch. The picking up of any one of the relays WZ for the establishment of such route opens the normally energized circuit for

relay WZL in an obvious manner, the relay WZL being normally energized by a circuit closed from (+), including back contact 412 of relay 1WZ, back contact 413 of relay 1WZP, back contact 5 414 of relay 2WZ, back contact 415 of relay 2WZP, back contact 416 of relay 3WZ, back contact 417 of relay 3WZP, back contact 418 of relay 4WZ, back contact 419 of relay 4WZP, and winding of relay WZL, to (-). The picking up 10 of the first of the WZ relays in the establishment of the route opens the circuit for the relay WZL, but, by the slow action of that relay, it is not dropped away until sufficient time has been provided for the response of each of the other WZ relays included in the route being set up.

After relay WZL has dropped away, with relay 1WZ picked up, a circuit is closed to cause the picking up of relay 1WZP extending from (+), including front contact 420 of relay 1WZ, winding of relay 1WZP, bus 421, and back contact 20 422 of relay WZL, to (-). The picking up of that relay establishes an obvious stick circuit at front contact 496 through front contact 497 for the energization of its lower winding to maintain that relay energized until restoration becomes effective to cause the dropping away of relay 1WZ and the opening of front contact 497. The picking up of that relay also applies energy to the switch machines 1ASM and 1BSM upon the closing of front contact 423 through the polar and neutral contacts 382 and 383 of relay 1WZ as shown in Fig. 10 to determine the normal or reverse position to which such switch machine is to be operated.

35 The picking up of relay 1WZP closes a circuit for the energization of relay 2WZP extending from (+), including front contact 412 of relay 1WZ, front contact 413 of relay 1WZP, front contact 424 of relay 2WZ, winding of relay 2WZP, bus 421 and back contact 422 of relay WZL, to (-). Although such circuit is closed immediately upon the picking up of relay 1WZP, the relay 2WZP is not picked up, because of its slow action, until after a time interval, thus providing that the circuit for the switch machine 2SM will be energized only after sufficient time has been provided for the starting of the motors of the switch machines 1ASM and 1BSM, or for the switch machine 1SM to have completed or partially completed its operation, depending upon the desired time for use in practice.

Upon the picking up of relay 2WZP, a circuit is closed to cause the picking up of relay 3WZP extending from (+), including front contact 412 of relay 1WZ, front contact 413 of relay 1WZP, front contact 414 of relay 2WZ, front contact 415 of relay 2WZP, front contact 425 of relay 3WZ, winding of relay 3WZP, bus 421, and back contact 422 of relay WZL, to (-). The picking up of that relay causes the operation of the switch machines 3ASM and 3BSM to a normal position in accordance with the position required for the establishment of the route from A to D via crossover 1.

65 The picking up of relay 3WZP closes an obvious circuit for relay WZL at front contact 417 to cause that relay to be picked up, and the picking up of that relay opens the pick-up circuits for the relays WZP, but each of the relays 70 WZP is maintained picked up by an obvious stick circuit as long as the relay WZ for that track switch or crossover remains energized.

In order to prevent unnecessary delay in the operation of the track switches, it is provided that the relay WZP is picked up only for each

track switch that is out of correspondence with the position called for by its associated relay WZ in the establishment of a route. That is, for example, if in the setting up of a route from A to D via crossover 1, the track switch 2 is already in a proper normal position as required for that route, the picking up of relay 1WZP closes a circuit for immediately picking up the relay 3WZP, such circuit extending from (+), including front contact 412 of relay 1WZ, front contact 413 of relay 1WZP, front contact 426 of relay 2WP, polar contact 427 of relay 2WP in a left-hand position, polar contact 428 of relay 2WZ in a right-hand position, front contact 425 of relay 3WZ, winding of relay 3WZP, bus 421, and back contact 422 of relay WZL, to (-).

With this arrangement, the operation of the switches is initiated in a predetermined fixed order as determined by the electrical connections, irrespective of the order in which the secondary switch control relays WZ are energized.

It is to be understood, and it is believed to be readily obvious to those skilled in the art, that the system shown in Fig. 13 to provide for the more even distribution of the switch machine power load can be applied to practically any NX system of the character described, as, for example, the route establishing means shown in the above mentioned prior application of A. Langdon, Ser. No. 119,641, filed January 8, 1937.

Modified cascade of switch operation (Figs. 14 and 15).—This form of cascade operation is arranged to be applied to the execution circuits of Figs. 9A and 9B so as to cause the execution of the switch controls from the primary switch control relays to the secondary switch control relays in succession upon the designation of the entrance and exit ends of a desired route, instead of causing the delay after the positioning of the secondary switch control relays as in Fig. 13. This form of execution circuit network arrangement, applied to the route establishing means of Figs. 9A and 9B requires that the auxiliary switch machine control lever for each track switch have slightly different circuits than shown in Fig. 10, and for this reason Fig. 15 discloses a typical switch machine control circuit for the arrangement shown in Fig. 14.

This form of cascade arrangement shown in Fig. 14 provides for the distribution of the power load for the switch machines by initiating only one switch machine into operation at a time, although several may be in operation contemporaneously. In other words, the starting current of a motor is a relatively high surge compared to the operating current, and if the starting surges are time spaced the source and power line may be adequate to allow proper operation.

In other words, the execution circuit network for the relays WZ is arranged in such a manner as to cause the relays WZ to be energized in succession or in a cascade manner when a route is established, such cascade always starting with the WZ relay for the track switch nearest a predetermined end of the track layout. For this embodiment of the present invention such point at which the initiation of the cascade of the relays WZ is effected is the WZ relay for the track switch nearest the right-hand end of the track layout. That is, in the establishment of a route from A to D via crossover 1, it is provided that the relay 3WZ is the first to be energized, and the WZ relays for the other track switches included in that route follow successively from the right-hand end of such route. Such is true even

if the route is set up from D to A via crossover 1 for a west-bound traffic.

To consider a specific example of how such mode of operation is effective when a route is established, assume that an operator designates respective entrance and exit points for a route to be established from A to D via crossover 1. Responsive to the designation of such route ends, the position of the track switches required is selected by the route establishing means in accordance with the energization of circuits corresponding to circuits which have been described with reference to Figs. 9A and 9B, and the picking up of the relay DXR causes the picking up of the relay 3WZ in accordance with the energization of a circuit closed from (+), including front contact 440 of relay DXR, front contact 441 of relay 3BN, asymmetric device 442, and upper winding of relay 3WZ, to (-). The picking up of relay 3WZ due to such energization causes the operation of the track switches of crossover 3 to normal positions in accordance with the mode of operation which has been described as typical with reference to Fig. 10 and which is also shown in Fig. 15.

Responsive to the picking up of relay 3WZ a circuit is closed to cause the picking up of relay 2WZ extending from (+), including front contact 440 of relay DXR, front contact 443 of relay 3BN, front contact 444 of relay 2N, front contact 445 of relay 2N, front contact 446 of relay 3WZ, asymmetric device 447, and upper winding of relay 2WZ, to (-). The picking up of that relay causes the operation of the track switch 2 to a normal position, and it also closes a circuit to cause the energization of relay 1WZ extending from (+), including front contact 440 of relay DXR, front contact 443 of relay 3BN, front contact 444 of relay 2N, back contact 448 of relay 1BN, front contact 449 of relay 1R, front contact 450 of relay 2WZ, asymmetric device 451, and lower winding of relay 1WZ, to (-). The energization of that winding causes the relay 1WZ to be picked up with its polar contacts operated to such a position as to cause the operation of the track switches of crossover 1 to reverse positions in accordance with the energization of circuits as shown in Fig. 15.

With reference to Fig. 15, the picking up of relay 1WZ with its polar contacts operated to a left-hand position in accordance with the reverse control selected by the route establishing means, causes energy to be applied to the control circuit for the switch machines 1ASM and 1BSM to cause its operation to a reverse position in accordance with the closing of an obvious circuit at front contacts 483 and 496. The completion of the operation of such switch machines to reverse positions causes the picking up of the relay 1RCR and the dropping away of relay 1LS in a manner similar to that which has been described with reference to Fig. 10. The dropping away of relay 1LS under such conditions closes a branch of the signal control circuit network as shown, for example, in Fig. 3, and after each of the track switches included in the route assumed to be designated has been properly positioned, the signal AG governing entrance thereto is cleared in a manner which has been heretofore described when considering in detail the signal control circuits.

In order to insure the complete operation of the switch machines 1ASM and 1BSM to reverse positions in accordance with the energization of relay 1WZ, a stick circuit is established upon

the picking up of relay 1WZ, when the initiation of the switch machine operation has caused the dropping away of relay 1WP, extending from (+), including back contact 478 of relay 1WP, front contact 452 of relay 1WZ, polar contact 453 of relay 1WZ in a left-hand position, and lower winding of relay 1WZ, to (—). The asymmetric device 451 prevents energy from such stick circuit from feeding back onto the execution circuit network provided for the energization of the relays WZ in accordance with the route establishment. After the switch machines 1ASM and 1BSM have completed their operation and the relay 1WP has been picked up, the stick circuit just described for relay 1WZ is opened at back contact 478, but another stick circuit is established when the route locking becomes effective upon the clearing of the signal governing entrance to the route extending from back contact 468 of relay 1BLR.

It is provided in accordance with the system as shown in Fig. 14, that each of the track switches can also be positioned by auxiliary control means in accordance with the energization of circuits shown in Fig. 15 in a manner very similar to that which has been described when considering in detail the switch control circuits as shown in Fig. 10. That is, the actuation of the lever 1SML for example, to a reverse operating position for causing the operation of the switch machine 1SM to a reverse position causes the picking up of the relay 1R by the energization of a circuit which has been described, and the picking up of that relay causes the picking up of relay 1WZ by the energization of a circuit closed from (+), including contact 454 of lever 1SML in a right-hand position, front contact 455 of relay 1R, and lower winding of relay 1WZ, to (—). The picking up of relay 1WZ due to such energization causes the operation of the switch machines to a reverse position. The asymmetric device 451 prevents the feeding of energy from the contact 454 of the lever 1SML back onto the circuit network shown in Fig. 14. A similar circuit is provided to energize relay 1WZ to a normal controlling position, which will be readily apparent to those familiar with the art.

To consider how the same sequence of operation of the switch machines is effective in establishing the route from D to A for west-bound traffic via crossover 1, assume that the ends of such route have been properly designated, and the relay AXL has been picked up for the exit end of such route. The picking up of that relay causes the energization of relay 3BN (see Fig. 14) in accordance with the general principles of the route establishing means as they have been heretofore set forth in connection with Figs. 9A and 9B, and the picking up of that relay closes a circuit for the upper winding of relay 3WZ, extending from (+), including front contact 456 of relay AXL, back contact 457 of relay 1AN, back contact 448 of relay 1BN, front contact 444 of relay 2N, front contact 443 of relay 3BN, front contact 441 of relay 3BN, asymmetric device 442, and upper winding of relay 3WZ, to (—). Upon the picking up of relay 3WZ a circuit is closed for relay 2WZ extending from (+), including front contact 458 of relay AXL, back contact 457 of relay 1AN, back contact 448 of relay 1BN, front contact 445 of relay 2N, front contact 446 of relay 3WZ, asymmetric device 447, and upper winding of relay 2WZ, to (—). The picking up of relay 2WZ closes a circuit for the energization of the lower winding of relay 1WZ extend-

ing from (+), including front contact 456 of relay AXL, back contact 457 of relay 1AN, front contact 449 of relay 1R, front contact 450 of relay 2WZ, asymmetric device 451, and lower winding of relay 1WZ, to (—). The picking up of relay 1WZ due to such energization completes the selection of the route extending from D to A via crossover 1, and each of the track switches included in such route is operated to its proper position in accordance with the typical switch control circuits as shown in Fig. 15. The complete operation of each of the track switches to the position required for the establishment of that route causes the clearing of the signal DG (see Fig. 3) in accordance with the energization of signal control circuits in a manner which has been described.

It will be noted from the typical circuits which have been described, that the relays WZ are energized by a circuit network which can readily be adapted by a person skilled in the art to any particular track layout encountered in practice, each relay WZ being energized for the particular position of its track switch required responsive to the energization of the relay WZ for the next adjacent track switch in a predetermined direction (such as to the right as shown in Fig. 14), such next track switch being the next track switch included in the route being set up. That is, if a route is selected extending from A to C, or from A to D via crossover 1, the relay 1WZ is energized responsive to the picking up of relay 3WZ, because that relay is provided for the next track switch to the right included in the route being established. However, if the route is established as has been described from A to D via crossover 1, the energization of relay 1WZ is dependent upon the picking up of the relay 2WZ which is, in that case, provided for the next track switch in the route being established.

Inasmuch as a high starting current is required only momentarily in the starting of each of the switch machines SM, sufficient time may be provided between the picking up of the relays WZ for proper distribution of the power load without requiring that those relays be provided with special slow pick-up characteristics, however, it is to be understood that such relays can be made sufficiently slow in picking up to satisfy any power load distribution condition of the character described which may be encountered in practice.

Having described two forms of the present invention together with certain modifications as specific embodiments of the present invention, it is desired to be understood that such forms have been selected to facilitate in the disclosure of the present invention rather than to limit the number of forms which the present invention may assume; and it is to be further understood that various adaptations, alterations and modifications may be applied to the specific forms shown to meet the requirements of practice without in any manner departing from the spirit or scope of the present invention, except as limited by the appending claims.

What we claim is:

1. In a switch and signal control system of the entrance-exit type, a track layout having a plurality of power operated switches for setting up different routes between signal locations constituting entrance and exit points, manually operable contact means associated with said signal locations and operable to designate each signal location as an entrance or an exit point, route

establishing means responsive to the actuation of a manually operable contact means to designate a signal location as an entrance point for energizing relay means to preselect the position of the trailed switches included in all available routes originating at that signal location and responsive to the subsequent actuation of a manually operable contact means to designate the exit point of any desired one of such available routes for causing the operation of the track switches to establish that route and for rendering ineffective the preselection with respect to the other routes, circuit means responsive to the actuation of a manually operable contact means to designate a signal location as an entrance point for preventing the subsequent operation of any other manually operable contact means from being effective to designate an entrance point until said circuit means is released, and means rendered effective by the response of said route establishing means to the actuation of a manually operable contact means to designate an exit point for releasing said circuit means.

2. In a switch and signal control system of the entrance-exit type, a track layout having a plurality of power operated track switches for setting up different routes between signal locations constituting entrance and exit points, a control panel having a miniature track diagram of said track layout and having control buttons on the track diagram at points corresponding to the signal location, said buttons being manually operable to designate the signal locations as entrance and exit points, conditioning circuit means responsive to the actuation of a control button to designate a signal location as an entrance point for energizing relay means to preselect the position of the trailed switches included in all available routes originating at that signal location and for conditioning the control buttons for the exit ends of such available routes so as to render the actuation of any given one of such buttons effective to designate its associated signal location as an exit point, means responsive to the actuation of a control button to effectively designate an exit point for a given one of the available routes for causing the operation of the track switches to establish that given route and for releasing the preselection of said conditioning circuit means with respect to the remaining routes, circuit means responsive to the operation of a control button to designate a signal location as an entrance point for preventing the subsequent operation of any other manually operable contact means from being effective to designate an entrance point until a control button has been effectively operated to designate an exit point, and other manually operable means effective to release said circuit means.

3. In a switch and signal control system of the entrance-exit type, a track layout having a plurality of power operated track switches for setting up different routes between signal locations constituting entrance and exit points, a control panel having a miniature track diagram of said track layout and having a single control button at each point on the track diagram corresponding to a signal location, circuit means effective, upon the actuation of any control button, to designate the corresponding signal location as an entrance point and thereafter preventing the actuation of any other control button from being effective to designate an entrance point until an exit point has been effectively designated, conditioning circuit means responsive to the designation of an entrance point for energizing relay means to preselect the position of the trailed switches included in all available routes originating at the corresponding signal location and to condition the control buttons for the exit ends of such available routes so as to render the actuation of any given one of such buttons effective to designate its associated signal location as an exit point, and means responsive to the actuation of a control button to effectively designate an exit point for causing the operation of the track switches to establish that route in accordance with its preselection and release the preselection of said conditioning circuit means with respect to the remaining routes, whereby each of said control buttons may act to designate an entrance or an exit point depending upon its relative order of actuation, and whereby a preselection operation can be performed with respect to only one entrance point at a time.

4. In a switch control system of the character described, a track layout including a plurality of power operated track switches for setting up different routes between route determining points at the opposite ends of the track layout, manually operable contact means for said route determining points, normal and reverse switch control relays for each of said track switches for governing the normal and reverse power operation of such track switch, one conditioning circuit network responsive to the operation of a manually operable contact means for any given route determining point at one end of the track layout for energizing the normal switch control relay for each track switch which would be trailed in a normal position by a train moving over any possible route emanating from such point, another conditioning circuit network responsive to the operation of a manually operable contact means for any given route determining point at the other end of the track layout for energizing the normal switch control relay for each track switch which would be trailed in a normal position by a train moving over any possible route emanating from such point, and a completion circuit network for both direction of traffic controlled by said normal switch control relays as energized by both of said conditioning circuit networks and rendered effective, upon the operation of a manually operable contact means for a route determining point at one end of a given route following the operation of a manually operable contact means for a route determining point at the other end of that given route, for energizing the reverse switch control relay for each switch required to be in a reverse position to set up said given route.

5. In a switch control system of the character described, a track layout including a plurality of track switches for setting up different routes between entrance and exit points at the opposite ends of the track layout, power operating means for each of said track switches, a control panel having a track diagram corresponding to said track layout manually operable contact means on said control panel at points corresponding to said entrance and exit points, normal and reverse switch control relays for each of said track switches, one conditioning circuit network responsive to the operation of a manually operable contact means for an entrance or exit point at one end of the track layout for energizing the normal switch control relay for each track switch which would be trailed in a normal position by a

train moving over any possible route emanating from such point, another conditions circuit network responsive to the operation of a manually operable contact means for any entrance or exit point at the other end of the track layout for energizing the normal switch control relay for each track switch which would be trailed in a normal position by a train moving over any possible route emanating from such point, a completion circuit network for both directions of traffic rendered active when a manually operable contact means is operated for an exit point at one end of a given route following the operation of a manually operable contact means for an entrance point at the other end of that route for energizing said reverse switch control relay for any switch required to be in a reverse position to set up said given route as preselected by the energization of normal relays by both of said conditioning circuit networks, and means energized by said completion circuit network for controlling said power operating means for each track switch in accordance with the energized condition of its normal and reverse switch control relays.

6. In a switch control system of the character described; a track layout including a plurality of power operated track switches for setting up different routes between route determining points at the opposite ends of the track layout; manually operable contact means for each of said route determining points; normal and reverse switch control relays for each of said track switches for governing the normal and reverse power operation of such track switch; one conditioning circuit network having feed points for those route determining points at the left end of the track layout and having circuit portions conforming to said track layout and including in each of the circuit portions corresponding to the normal and reverse positions of each switch, back contacts of the reverse and normal switch control relays respectively for that switch, said circuit portions for the normal position of each of those switches which would be trailed in the normal position by a train moving from left to right being normally connected to the corresponding normal switch control relay for that switch but being connected to the next circuit portion to the right only when such normal switch control relay is picked up and said reverse circuit portion for each switch being normally connected to the next circuit portion to the right but being disconnected from such next circuit portion when the associated normal switch control relay is picked up; another conditioning circuit network having feed points for those route determining points at the right end of the track layout and having circuit portions conforming to said track layout and including in each of the circuit portions corresponding to the normal and reverse positions of each switch, back contacts of the reverse and normal switch control relays respectively for that switch, said circuit portions for the normal position of each of those switches which would be trailed in the normal position by a train moving from right to left being normally connected to the corresponding normal switch control relay for that switch but being connected to the next circuit portion to the left only when such normal switch control relay is picked up and said reverse circuit portion for each switch being normally connected to the next circuit portion to the left but disconnected from such next circuit portion when the associated normal

switch control relay is picked up; and a completion circuit network controlled by the normal switch control relays as conditioned by said one and said another conditioning circuit networks and rendered effective upon the operation of a manually operable contact means for a route determining point at the leaving end of a given route following the operation of a manually operable contact means for the entering end of that given route for energizing the reverse switch control relays for each switch required to be in a reverse position to set up said given route; whereby the operation of a manually operable contact means for an entering route determining point at one end of the track layout conditions over a conditioning network a normal switch control relay for the switches trailed in the normal positions for all routes emanating from that point and thereby preselects which normal and reverse relays are to be energized by the other conditioning network and the completion network upon the operation of the manually operable contact means for the leaving end of a given one of said routes emanating from such entering route determining point.

7. In a switch and signal control system of the character described, a track layout including a plurality of power operated track switches for setting up different routes between signal locations at the opposite ends of the track layout, normal and reverse switch control relays for each of said track switches for governing its power operation to corresponding normal and reverse positions, one conditioning circuit network having circuit portions conforming to said track layout and a feed point for each signal location at one end of the track layout, said circuit portions for the normal and reverse positions of each track switch including back contacts of the reverse and normal switch control relays respectively for such switch, and said conditioning circuit network being effective upon the application of energizing potential to a given feed point to energize the normal switch control relay for each switch which would be trailed in a normal position by a train moving over any possible route emanating from the corresponding signal location, another conditioning circuit network having circuit portions conforming to said track layout and a feed point for each signal location at the other end of the track layout, said circuit portions for the normal and reverse positions of each track switch including back contacts of the reverse and normal switch control relays respectively for such switch, and said conditioning circuit network being effective upon the application of energizing potential to a given feed point to energize the normal switch control relay for each switch which would be trailed in a normal position by a train moving over any possible route emanating from the corresponding signal location, manually operable contact means for each of said signal locations for controlling the application of energizing potential to the conditioning circuit network having a feed point corresponding to that signal location, a completion circuit network for both directions of traffic controlled by both said conditioning circuit networks and rendered effective by the operation of a manually operable contact means for a signal location at the exit end of a route following the operation of a manually operable contact means for an entrance end of that route for energizing the reverse switch control relay for each switch required to be in a

reverse position to set up that given route, and circuit means for clearing the signal at the entrance end of any given route when that route has been set up to correspond with the energized condition of the normal and reverse switch control relays for the switches in that route.

8. In a switch and signal control system of the entrance-exit type, a track layout having power operated track switches for establishing different routes between entrance and exit points of the track layout, a control panel having a track diagram of said track layout and a single control button for each of said entrance and/or exit points, entrance storing means initially rendered active in response to the actuation of any button for designating an entrance point, circuit means preventing the actuation of any other button from designating an entrance point until some other button has been actuated to effectively designate the exit point for a route originating at that entrance point, route establishing means including relays initially energized in response to the actuation of a button rendering active its associated entrance storage means, said route establishing means being responsive to the subsequent actuation of a button for the exit end of an available route originating at said designated entrance point having its entrance storage means rendered active for operating the track switches to establish that route and for releasing said circuit means, and means for visually indicating when said circuit means is effective to prevent the actuation of a control button from acting upon its associated entrance storage means.

9. In a switch and signal control system for governing the power operation of the track switches in a track layout to set up different routes for train movement between signal locations, a miniature track diagram of said track layout having manually operable contact means located thereon at points corresponding to the signal locations for designating such signal locations as the entrance or exit ends of the various routes, normal and reverse primary switch control relays for each of the track switches except in the case of crossovers where a single reverse relay is common to both the track switches of the crossover, a secondary switch control relay for each of the track switches, two conditioning circuit networks, one network having feed points corresponding to the signal locations at one end of the track layout, and the other network having feed points corresponding to the signal locations at the opposite end of the track layout, and each network acting, when supplied with energy at a feed point corresponding to a designated entrance signal location, to energize the normal primary switch control relays for the track switches which are in the various available routes originating at such entrance signal location and which can be trailed in normal positions for such routes, but acting, when supplied with energy at a feed point corresponding to a signal location designated at the exit end of a particular available route following the energization of the other network at a feed point corresponding to the entrance end of such route, to energize the normal primary switch control relay for each of the remaining switches required to be in normal positions for such particular route, circuit means responsive to the actuation of any given manually operable contact means to designate an entrance signal location for supplying energy to the conditioning

circuit network having a feed point for such signal location, other circuit means responsive to the operation of any given manually operable contact means to designate an exit signal location for supplying energy to the conditioning circuit network having a feed point for such signal location, a completion circuit network selected by contacts of said normal primary switch control relays and supplied with energy at a feed point corresponding to the designated exit signal location for any particular route, said completion circuit network acting to energize the reverse switch control relays required to establish that particular route selected by the normal switch control relays as energized by both said conditioning circuit networks, and execution circuit means controlled by said primary switch control relays and rendered effective upon the designation of the exit signal location for the exit end of any particular route to energize the secondary switch control relays for only the track switches included in such particular route to effect the power operation of those track switches to proper positions for that route.

10. In a switch and signal control system of the character described, a track layout including a plurality of power operated track switches for setting up different routes between signal locations constituting entrance and exit points for such routes, manually operable contact means for each of said signal locations and operable to designate that location as an entrance or an exit point, normal and reverse switch control relays for each of said track switches except in the case of a crossover where a single reverse relay is common to the two track switches for the opposite ends of such crossover, one conditioning circuit network responsive to the operation of a manually operable contact means for any given signal location at the left end of the track layout designated as an entrance point for energizing the normal switch control relay for each track switch which would be trailed in a normal position by a train moving to the right from such entrance point over any possible route emanating from that entrance point, another conditioning circuit network responsive to the operation of a manually operable contact means for any given signal location at the right end of said track layout designated as an entrance point for energizing the normal switch control relay for each track switch which would be trailed in a normal position by a train moving to the left from such entrance point over any possible route emanating from that entrance point, an exit relay for each of said signal locations constituting an exit point, circuit means associated with each of said exit relays for causing that exit relay to be energized upon the operation of its associated manually operable contact means designating that location as an exit point only if there is an available route emanating to that exit point from a signal location designated as an entrance point, circuit means controlled by each exit relay for applying energy to that conditioning circuit network which is responsive to the operation of the manually operable contact means for such signal location to cause such conditioning network to energize the normal switch control relay for each track switch which would be trailed in a normal position by a train moving from such exit point over a route toward the designated entrance point as preselected by the other conditioning network responsive to the

manually operable contact means at the designated entrance point, a completion circuit network responsive to the energization of an exit relay at the exit end of an available route and controlled by the normal switch control relays for energizing the reverse switch control relay for each track switch in the route between said given entrance and exit points which does not have its normal switch control relays energized by either of said conditioning circuit networks, execution circuit means controlled by said normal and reverse switch control relays for causing the operation of those track switches in any selected route in accordance with the energized condition of their switch control relays only after such switch control relays for the switches of that route have been acted upon by both said conditioning circuit networks and said completion circuit networks, and circuit means for clearing the signal at the location designated as the entrance point only after the track switches between that point and the designated exit point have operated into correspondence with the route selected by the energization of said normal and reverse switch control relays.

11. In a switch and signal control system of the entrance-exit type for controlling the power operation of track switches in a track layout to establish different routes between the signal locations of the track layout, a miniature track diagram of the track layout having manually operable control buttons at points thereon corresponding to the location of the signals and having linear indicator portions associated with the different positions of the track switches and the intervening portions of track, a single switch control relay for each switch or end of a crossover for governing the power operation thereof to either position, route establishing means responsive to the operation of the control buttons for the opposite ends of any route to initiate the operation of the track switches to establish that route and for clearing the signal at the entrance end of such route, indicating means associated with each linear indicator portion and adapted to steadily illuminate its portion when rendered effective, circuit means responsive to the operation of said route establishing means to initiate switch operation for a route for rendering effective the indicating means for all the indicator portions of that route independently of the response of the track switches in such route, to thereby outline the route to be established by a substantially continuous and steady line of light through its length, and circuit means for maintaining said indicating means effective for each indicator portion of an established route corresponding to an occupied section of track and the sections of track in advance of a train in such route.

12. In a switch and signal control system of the entrance-exit type for controlling the power operation of the track switches in a track layout to establish the various routes through a track layout between the governing signal locations, a miniature track diagram of the track layout having manually operable control buttons at points corresponding to the location of the signals and having linear indicator portions associated with the different positions of the track switches and the intervening portions of track, route establishing means responsive to the actuation of the control buttons for the entrance and exit ends of any desired route to cause the power operation of the track switches to establish that route

and to clear the signal at the entrance end thereof, indicating means associated with each linear indicator portion and adapted to steadily illuminate its portion when rendered effective, circuit

- 5 means responsive to the operation of said route establishing means to initiate the establishment of any desired route for rendering effective the indicating means for all of the indicator portions of that route independently of the response of the track switches, an individual correspondence lamp associated with each of the track switches, correspondence circuit means associated with each of said track switches for illuminating its respective correspondence lamp while such switch is in operation or is unlocked only if such circuit means is supplied with energy, and manually operable contact means for at times supplying energy to said correspondence circuit means.
- 10 20 13. In a switch and signal control system of the type described for governing the power operation of track switches in a track layout to establish different routes between the signal locations provided for governing traffic thereover; a control panel having thereon a miniature track diagram of said track layout, manually operable control buttons at points corresponding to the location of the various signals, and linear indicator portions respectively associated with the
- 15 25 30 35 40 45 50 55 60 65 70 75 different positions of the track switches and the intervening sections of track; route establishing means responsive to the manipulation of the control buttons for the entrance and exit ends of any desired route for initiating the power operation of the track switches to establish that particular route and for causing the clearing of the signal at the entrance to that route after it has been established, circuit means responsive to the operation of the route establishing means to initiate the establishment of any given route for causing the steady illumination of the indicator portions for the proper positions of the switches and the intervening sections of track associated with that route independently of the operated condition of the various switches to thereby outline the route to be established by a substantially continuous line of light as soon as it has been selected by said route establishing means, normally inactive auxiliary switch control levers associated with each of the track switches and operable to normal and reverse controlling positions, circuit means responsive to the operation of any auxiliary switch control lever to a normal or reverse controlling position for effecting the corresponding operation of its associated track switch only provided it is not included in an established route for rendering said route establishing means ineffective with respect to all routes over that switch in its other position, and circuit means rendered effective while any given auxiliary switch control lever is in a normal or reverse controlling position for illuminating only the linear portion for the normal or reverse position of the corresponding track switch to thereby indicate the position to which such switch is being operated without illuminating the indicator portions for any intervening sections of track.

14. In a switch and signal control system of the type described for governing the power operation of track switches in a track layout to establish different routes between the signal locations provided for governing traffic thereover, a control panel having thereon a miniature track diagram of said track layout, manually operable control buttons at points corresponding to the

location of the various signals, and linear indicator portions associated with the different positions of the track switches and the intervening portions of track, route establishing means responsive to the manipulation of the control buttons for the entrance and exit ends of any desired route for initiating the power operation of the track switches to establish that particular route and for causing the clearing of the signal at the entrance to that route after it has been established, circuit means responsive to the operation of the route establishing means to initiate the establishment of any given route for causing the illumination of all the indicator portions of that route independently of the position of the various switches to thereby outline the route to be established by a substantially continuous line of light, normally inactive auxiliary switch control levers associated with each of the track switches and operable to normal and reverse controlling positions, circuit means interlocked with said route establishing means to provide that the operation of any auxiliary switch control lever to a normal or reverse controlling position will cause the corresponding operation of its associated track switch only provided it is not included in an established route, circuit means rendered effective while any given auxiliary switch control lever is in a normal or reverse controlling position for illuminating the linear portion for the normal or reverse position of the corresponding track switch to thereby indicate the controlled position for such switch, a correspondence lamp associated with each of said auxiliary switch machine control levers, a supplemental button associated with said auxiliary switch control levers, and circuit means for illuminating any given correspondence lamp when its associated track switch is out of correspondence with its control only provided said supplemental button is actuated, to thereby advise the operator of the position to which the track switch is being operated and to also advise him as to when such operation has been completed.

15. In a switch and signal control system of the type described for track layouts including a plurality of interlocked groups and affording one or more optional through routes past one or more intermediate signals for both directions of traffic, manually operable buttons for designating any given signal location of said track layout as an entrance or exit point, route establishing means responsive to the operation of said buttons to designate the entrance and exit ends of any given route or through route for establishing that route over one or more interlocked groups and for controlling the clearing of one or more signals in said route, said route establishing means including relay means associated with the various switches and initiating circuits for governing the selective energization of said relay means so that the operation of a button to designate any given signal location as an entrance point effects the energization of the initiating circuits for all available routes and through routes originating at that signal location and to cause the energization of the relay means associated with certain trailed switches in such available routes or through routes, and means for interrupting the initiating circuits relating to all through routes for both directions of traffic past an intermediate signal location when any route terminating at that signal location is established or occupied by a train travelling toward that intermediate signal location or whenever a track section

adjacent said intermediate signal is occupied by a train travelling away from that intermediate signal location.

16. In a switch and signal control system of the entrance-exit type, at track layout having a plurality of interlocked groups of power-operated track switches with governing signals constituting entrance and exit points for the various routes and affording one or more through routes past one or more intermediate signals, a control panel having a miniature track diagram of said track layout with a single control button located thereon at points corresponding to each of said signal locations, said control buttons for the signal locations which are intermediate signal locations for one or more through routes for governing traffic at such points in both directions being of the self-restoring push button type, and also being operable to right and left hand rotated positions from biased to normal positions, route establishing means responsive to the pushing of a control button to designate an entrance signal location followed by the pushing of a control button to designate an exit signal location for establishing the route or through route thus designated and to clear one or more signals for controlling traffic over such route, said route establishing means responding to the pushing of the control button for any given intermediate signal location to designate that signal location as an exit point of a route having its entrance point already designated, but responding to the pushing of such control button to designate an entrance point only providing a route terminating at that point is already established or occupied by a train, unless said control button is operated to a right or left hand rotated position corresponding to the direction of traffic desired to be established at that point.
17. In a switch and signal control system of the entrance-exit type, a track layout including a plurality of interlocked groups of power-operated track switches and affording one or more through routes past one or more intermediate signal locations as well as different routes between the signal locations of any one interlocked group, said signal locations constituting entrance and exit points, manually operable contact means associated with said signal locations operable to designate each location as an entrance or an exit point, route establishing means responsive to the actuation of a manually operable contact means to designate a signal location as an entrance point for preselecting the position of the trailed switches included in all available routes and through routes originating at that signal location and responsive to the subsequent actuation of a manually operable contact means to designate the exit point of any desired one of such available routes or through routes for causing the operation of the track switches to establish that route or through route and at the same time rendering ineffective the preselection with respect to all other routes and also for clearing one or more signals to govern traffic thereover, circuit means responsive to the actuation of a manually operable contact means to designate a signal location as an entrance point for preventing the subsequent operation of any other manually operable contact means from being effective to designate an entrance point until said circuit means is released, and means rendered effective by the response of said route establishing means to the actuation of a manually operable contact means to desig-

uate an exit point for releasing said circuit means, said means acting irrespective of whether such exit point is designated as the end of a route or a through route.

18. In a switch and signal control system of the type described for track layouts including a plurality of interlocked groups of power-operated track switches with governing signals constituting entrance and exit points for the various routes and affording one or more through routes past one or more intermediate signals, each of the interlocked groups also having its track divided into different track circuit sections, control buttons for said signal locations being operable to designate any given signal location of the track layout as an entrance or an exit point, route establishing means responsive to the operation of said buttons to designate the entrance and exit ends of any given route or through route for establishing that route over one or more interlocked groups and for controlling the clearing of one or more signals in such route, said route establishing means including relay means associated with the various switches and initiating circuits for governing the selective energization of said relay means so that the operation of a control button to designate any given signal location as an entrance point effects the energization of the initiating circuits for all available routes and through routes originating at that signal location to cause the energization of the relay means associated with certain trailed switches in such available routes or through routes, route locking means associated with the power-operated track switches of the track layout and acting when rendered effective upon the establishment of any given route or through route to prevent the operation of the track switches in that route until the governing signal or signals are restored to stop and such route is unoccupied by a train, said route locking means including a directional stick relay for each direction of traffic for each track circuit section and associated controlling circuit means so that the establishment of any given route for a particular direction of traffic causes the deenergization of the directional stick relays for the corresponding direction of traffic for all of the track circuit sections in that route or through route, and means including the directional stick relays for the track sections adjacent any given intermediate signal location for interrupting the initiating circuits relating to all through routes for both directions of traffic past that intermediate signal location when any route terminating at that signal location is established or occupied by a train travelling toward that intermediate signal location or whenever a track section adjacent said intermediate signal location is occupied by a train travelling away from that intermediate signal location.

19. In a switch and signal control system of the entrance-exit type, a track layout having a plurality of interlocked groups of power-operated track switches with governing signals constituting entrance and exit points for the various routes and affording one or more through routes past one or more intermediate signals, certain of such intermediate signal locations having both high signals and call-on signals for both directions of traffic, a control panel having a miniature track diagram of said track layout with a single control button located thereon at each of the points corresponding to a signal location, each of said control buttons for the intermediate sig-

nal locations being of the self-restoring push button type and also being operable to right and left-hand rotated positions from a biased normal position, route establishing means responsive to the pushing of a control button to designate an entrance signal location followed by the pushing of the control button to designate an exit signal location for establishing the route or through route thus designated and for clearing one or more high signals for controlling traffic over such route, said route establishing means responding to the pushing of the control button for any given intermediate signal location to designate that signal location as an exit point of a route having its entrance point already designated, and responding to the pushing of such control button to designate an entrance point only providing a route terminating at that point is already established or occupied by a train, and means for causing said route establishing means to respond to the rotation of the control button for any given intermediate signal location to right or left-hand rotated positions to designate that location as an entrance point of a route for a corresponding direction of traffic followed by the pushing of a control button to designate an exit point for such route for effecting the establishing of such route and the clearing of the call-on signal at the intermediate signal location thus designated as an entrance point.

20. In a switch control system as described for governing the power operation of the track switches in a track layout to establish the various possible routes, a control button for each point constituting the entering or leaving end of one or more routes, normal and reverse switch control relays for each of the track switches except in the case of crossovers where a single reverse relay is common to both track switches, two conditioning circuit networks, one having feed points for the ends of the routes at one end of the track layout and the other having feed points for the ends of the routes at the other end of the track layout, and each network acting when supplied with energy at a feed point in response to the actuation of its corresponding control button, to energize the normal switch control relays for the track switches which are in the various available routes originating at the corresponding point of the track layout and which can be trailed in normal positions for such routes, and also to partially energize the reverse control relays for the track switches that can be trailed in reverse positions in said available routes originating at said point, but acting when supplied with energy at a feed point for the leaving end of a particular route upon the actuation of the control button for that point following the energization of the other network at a feed point for the opposite end of such route, to energize the normal switch control relay for each of the remaining switches required to be in normal positions for such a particular route and to also complete the energization of the reverse switch control relays for the track switches of that particular route required to be operated to reverse positions, and circuit means responsive to the actuation of any given manually operable control button to supply energy to the conditioning circuit network having a feed point associated with that control button.

21. In a switch and signal control system of the entrance-exit type for governing the power operation of track switches to establish various routes through a track layout between signal lo-

cations, a control panel having thereon a miniature track diagram of the track layout, freely movable manual control devices located at points on said track diagram corresponding to the signal locations and operable to designate said signal locations as the entrance or exit ends of routes, two conditioning circuit means, one for each direction of traffic, means responsive to the operation of a manual control device to designate an entrance signal location for energizing one of said conditioning circuit means to effect the preselection of the position of all the trailed switches included in all of the establishable routes originating at that entrance signal location, means responsive to the operation of a manual control device to designate an exit signal location at the end of a particular one of the routes originating at the designated entrance signal location to energize the opposite conditioning circuit means to effect the selection of the position of the remaining track switches of that particular preselected route and to render ineffective the preselection for the other routes originating at the designated entrance signal location, and execution circuit means initially rendered effective by the designation of the exit signal location of any particular route and governed in accordance with the energized condition of both conditioning circuit means for that particular route to operate the track switches to positions selected by the energization of said two conditioning circuit means to establish such particular route.

22. In a switch control system as described for governing the power operation of the track switches in a track layout to establish the various routes, a control button for each point constituting the entering or leaving end of one or more routes, normal and reverse switch control relays for each of the track switches except in the case of crossovers where a single reverse relay is common to both track switches, two conditioning circuit means, one having feed points for the ends of the routes at one end of the track layout and the other having feed points for the ends of the routes at the other end of the track layout, entrance control means responsive to the actuation of a control button to designate the entrance end of one or more routes for energizing the conditioning circuit means having a corresponding feed point to preselect the positions of all of the trailed switches included in all of the available routes originating at that entrance point by energizing the normal or reverse switch control relays for energizing the normal or reverse switch control relays for the corresponding switches, exit control means responsive to the actuation of a control button to designate the exit end of a particular available route having its entrance end already designated for energizing the other conditioning circuit means to effect the selection of the positions of the remaining track switches of that particular route by energizing the normal or reverse control relays for the positions required and at the same time deenergizing said one conditioning circuit means with respect to the remaining routes originating at said entering point, execution circuit means having feed points for the entering and leaving points at both ends of the track layout and initially rendered effective with respect to any particular route upon the response of the exit control means for the leaving end of that route to cause the power operation of the track switches to positions selected by the energization of the normal and reverse control relays for the corresponding

track switches only after both of said conditioning circuit means have been energized with respect to that particular route.

23. In a switch and signal control system as described for governing the power operation of the track switches in a track layout to establish the various routes, a control button for each point constituting the entering or leaving end of one or more routes, normal and reverse switch control relays for each of the track switches except in the case of crossovers where a single reverse relay is common to both track switches, two conditioning circuit means, one having feed points for the ends of the routes at one end of the track layout and the other having feed points for the ends of the routes at the other end of the track layout, entrance control means responsive to the actuation of a control button to designate the entrance end of one or more routes for energizing the conditioning circuit means having a corresponding feed point to preselect the positions of all the trailed switches included in all of the available routes originating at that entrance point by energizing the normal or reverse switch control relays for the corresponding switches, exit control means responsive to the actuation of a control button to designate the exit end of a particular available route having its entrance end already designated for energizing the other conditioning circuit means to effect the selection of the positions of the remaining track switches of that particular route by energizing the normal or reverse control relays for the positions required and at the same time deenergizing said one conditioning circuit means with respect to the remaining routes originating at said entering point, execution circuit means having feed points corresponding to the ends of the various routes at both ends of the track layout and initially rendered effective by the response of the exit control means for the leaving end of any particular route to initiate the power operation of the track switches one at a time to establish said particular route as selected by the energization of the normal and reverse switch control relays, said execution circuit means being effective only if both said conditioning circuit means for that particular route have been energized.
24. In a switch and signal control system of the entrance-exit type for governing the power operation of track switches in a track layout to set up the various establishable routes between the signal locations at the opposite ends of the track layout, a control panel having thereon a miniature track diagram of the track layout and control buttons located thereon at points corresponding to the locations of the various signals and operable to designate their respective locations as entrance or exit points, initiating circuit means energized in response to the operation of a control button to designate its associated signal location as an entrance point for preselecting the position of certain switches included in all of the establishable routes originating at that entrance signal location, completion circuit means responsive to the subsequent actuation of a control button to designate the exit signal location of a particular one of said establishable routes for selecting the positions of the remaining track switches of that particular route and deenergizing the initiating circuits for all other routes originating at the designated entrance signal, and execution circuit means initially rendered effective upon the designation of the exit point for

any particular establishable route for causing the sequential initiation of the power operation of the track switches in that route subsequent to and dependent upon the selection of the positions of such switches by said initiation and completion circuit means.

25. In a switch control system of the type described, a track layout having power operated track switches for setting up different routes between entrance and exit points, a control panel having a miniature track diagram of the track layout, freely movable manual control devices associated with the entrance and exit points on said track diagram, route selecting means rendered effective in response to the actuation of the manual control devices for the opposite ends of any particular route to select the positions required for the various switches in that route, and means rendered effective upon the actuation of the manual control device for the leaving end of any particular route to sequentially initiate the power operation of the track switches in that route to positions selected by said route selecting means in a fixed predetermined order and independently of the sequence in which said route selecting means determines the positions of such switches.

26. In a switch and signal control system, a track layout having a plurality of track switches and crossovers for setting up different routes between signal locations at the opposite ends of the track layout, such track layout affording at least two alternative routes between common signal locations at the opposite ends of such track layout, control buttons for the signal locations constituting the entering or leaving end of one or more routes, normal and reverse switch control relays for each of the track switches except in the case of crossovers where a single reverse relay is common to both track switches, which reverse relays are of the marginal type having two control windings both of which are required to be energized in order to pick up the contacts of such relay, two conditioning circuit networks, one having feed points for the ends of the routes at one end of the track layout and the other having feed points for the ends of the routes at the other end of the track layout, and each network acting when supplied with energy at a feed point in response to the actuation of its corresponding control button, to energize the normal switch control relays of the track switches which are in the various available routes originating at the corresponding point of the track layout and which can be trailed in normal positions for such routes, and also to energize one winding of the reverse control relay for each of the track switches that can be trailed in reverse positions in said available routes originating at said point, but acting when supplied with energy at a feed point for the leaving end of a particular route upon the actuation of the control button for that point following the energization of the other network at a feed point for the opposite end of such route, to energize the normal switch control relay for each of the remaining switches required to be in normal positions for such particular route and to also energize the other winding of the reverse switch control relays for the track switches of that particular route required to be operated to reverse positions, said normal and reverse relays being interlocked so that in the case of the track switch which may be in either of its positions to establish one or the other of said alternative routes, the energization of the

normal relay prevents the energization of the reverse relay.

27. In a switch and signal control system of the type described, a track layout having power operated track switches to set up the various routes between signal locations constituting entrance and exit points, manually operable control devices associated with the signal locations for designating such locations as the entrance or exit ends of routes, normal and reverse switch control relays for each of the track switches, route establishing means responsive to the actuation of a manually operable control device to designate an entrance signal location followed by the actuation of a manual control device to designate an exit signal location for causing the power operation of the track switches to establish a route between such entrance and exit signal locations by energizing the proper normal and reverse switch control relays for the track switches in that route, an auxiliary switch control lever associated with each of the track switches in the track layout, circuit means controlled by each of said auxiliary switch control levers for energizing the normal or reverse switch control relay in response to the operation of its lever to a normal or reverse controlling position providing the opposite control relay is not already energized by said route establishing means, normally deenergized normal and reverse correspondence relays associated with each switch and energized respectively only if the switch has operated to the normal or reverse position to correspond with the normal or reverse switch control relay then energized, and circuit means for clearing a signal at the location designated at the entrance end of a route if all of the track switches in that given route are in correspondence with the control exercised by their respective normal and reverse switch control relays, said means acting independently of the designation of an exit end of a route, whereby any given route in the track layout and its governing signal may be cleared either by manipulations of the entrance-exit type or by individual manual control of the respective track switches in that route followed by actuation of the manually operable control devices for the entrance end of the route only.

28. In a switch control system of the type described for setting up different routes between entrance and exit points of a track layout by the power operation of the various track switches in the layout, a control panel having a miniature track diagram of the track layout, freely movable manual control devices associated with the entrance and exit points on said track diagram, route selecting means including a plurality of switch position selecting relays for each of the track switches in said track layout, said route selecting means being rendered effective to control the energization of the switch position selecting relays so as to select the positions required for the various switches to establish any given route through the track layout upon the actuation of the manual control devices for the entrance and exit points of such given route, slow acting electro-responsive means set into operation upon the actuation of the manual control device for the exit end of any particular route for measuring a predetermined time, and circuit means controlled by said switch position selecting relays for causing the sequential initiation of the power operation of the track switches in any selected route after a predetermined time has been measured by such slow acting electro-

responsive means, whereby the complete selection of a route is effected by said route selecting means upon the actuation of the manual control devices for the opposite ends of that route before the power operation of the track switches in such route is initiated.

29. In a switch control system of the entrance-exit type, a track layout having power-operated track switches for setting up different routes between entrance and exit points, a control panel having a miniature track diagram of the track layout, freely movable manual control devices associated with the entrance and exit points on said track diagram for designating the entrance and exit ends of any desired route through the track layout, primary switch control relays associated with each of said track switches in the track layout, a secondary switch control relay of the polar-neutral type associated with each of the track switches, route selecting means rendered effective in response to the actuation of the manual control devices for the entrance and exit ends of any particular route to select the positions required for the various switches in that route by automatically energizing the proper primary switch control relays for such switches, and circuit means rendered effective upon the actuation of the manual control device for the exit end of any particular route to sequentially energize the secondary switch control relays for the track switches in that route in accordance with the positions selected by the energization of said primary switch control relays irrespective of the sequence in which said primary switch control relays are energized by said route selecting means.

30. In a switch control system of the entrance-exit type for governing the power operation of track switches to establish various routes through a track layout between entrance and exit points, a control panel having thereon a miniature track diagram of the track layout, freely movable manual control devices located at points on said track diagram corresponding to said entrance and exit points and operable to designate the entrance and exit ends of the various routes, two conditioning circuit means, one having feed points for the ends of the routes at one end of the track layout and the other having feed points for the ends of the routes at the other end of the track layout, means responsive to the operation of a manual control device to designate the entrance end of one or more routes for applying energy to the corresponding feed point of one of said conditioning circuit means to effect the preselection of the position of all the trailed switches included in all of the establishable routes originating at that entrance point, means responsive to the operation of a manual control device to designate the exit end of a particular one of the routes originating at the designated entrance point to apply energy to the corresponding feed point of the other conditioning circuit means to effect the selection of the position of the remaining track switches of that particular preselected route and to render ineffective the preselection for the other routes originating at the designated entrance point, secondary switch control relays of the polar-neutral type associated with each of the track switches in the track layout, and execution circuit means including contacts of said polar-neutral relays and controlled by said two conditioning circuit means to effect the sequential energization of said secondary switch con-

trol relays for the track switches in any particular route following the designation of the exit end of that particular route, whereby the switches of any particular route having its entrance and exit ends designated by said manual control devices have their power operation initiated in cascade order irrespective of the sequence of the selection of their positions by said two conditioning circuit means.

10 31. In a switch and signal control system of the type described, a track layout having power-operated switches for setting up different routes between the signal locations, a single control button for each of the signal locations, two conditioning networks for selecting the positions of the track switches required to establish any particular route upon the operation of the control buttons to designate the entrance and exit ends of that route, one of said conditioning circuit networks being controlled by the buttons for the signal locations at one end of the track layout irrespective of whether such buttons designate the entrance or exit ends of routes, and the other conditioning circuit network being controlled by the buttons for the signal locations at the other end of the track layout irrespective of whether they are employed to designate the entrance or exit ends of routes, an execution circuit means controlled by said two conditioning circuit networks for causing the sequential initiation of the power operation of the track switches to establish any particular route.

32. In a switch and signal control system of the entrance-exit type; a track layout having a plurality of power-operated track switches for setting up different routes between entrance and exit points; a control panel having a miniature track diagram of said track layout and a single control button on the track diagram for each entrance and/or exit point of the track layout; an entrance relay for each entrance point; an exit relay for each exit point; entrance lock-out means; circuit means effective upon the actuation of the control button for any given entrance point to energize the entrance relay for that point and at the same time condition said entrance lock-out means to render all other control buttons for entrance points ineffective to energize their respective entrance relays until said entrance lock-out means is released; conditioning circuit means responsive to the picking up of an entrance relay to preselect the positions of the trailed switches included in all available routes originating at the corresponding entrance point and to condition for energization the exit relays for the exit points of all such available routes; circuit means responsive to the actuation of a control button for any given exit point having its exit relay conditioned for energizing that exit relay; circuit means rendered effective by the picking up of an exit relay only while its control button is actuated for releasing said entrance lock-out circuit means; and route establishing means controlled by the picking up of the exit relay for the exit point of any given route to cause the power operation of the track switches in that route in accordance with the preselection provided by said conditioning circuit means to establish that route and at the same time to release the preselection of said conditioning circuit means with respect to all remaining routes originating at the entrance to said given route.

33. In a switch control system of the type

described, a track layout having a plurality of power-operated track switches for setting up different routes between entrance and exit points, a control panel having a miniature track diagram of said track layout, a single control button on the track diagram for each of the entrance and/or exit points of the track layout, an entrance relay for each entrance point, an exit relay for each exit point, entrance lock-out means, circuit means effective upon the actuation of the control button for any given entrance point to energize the entrance relay for that designated entrance point and at the same time condition said entrance lock-out means to render all other control buttons ineffective to energize their respective entrance relays until said entrance lock-out means is released, pick-up circuit means responsive to the actuation of the control button for any given exit point of an available route originating at the designated entrance point for energizing the corresponding exit relay, releasing circuit means rendered effective by the picking up of an exit relay while its control button is actuated for releasing said entrance lock-out means, circuit means effective upon the release of a control button while its exit relay is picked up for thereafter rendering said releasing circuit means ineffective until the entrance relay for the route terminating at that point is again dropped away, and route establishing means controlled by the entrance and exit relays so as to cause the operation of the track switches to establish any given route when the entrance and exit relays at the opposite ends of that route are picked up.

34. In a switch control system, a track layout having power-operated track switches for establishing the various routes between entrance and exit points at the opposite ends of the track layout, manually operable contact means for each of said entrance and exit points, normal and reverse switch control relays for governing the power operation of the track switches, one circuit network responsive to the operation of a manually operable contact means to designate any given entrance point for energizing the normal switch control relay for each track switch which would be trailed in a normal position by a train moving over any available route originating at such designated entrance point, another circuit network responsive to the subsequent operation of a manually operable contact means to designate the exit point of any particular available route originating at a designated entrance point at the other end of the track layout for energizing the normal switch control relay for each of the remaining track switches required to be in normal positions for that particular route, a completion

- circuit network controlled by said normal switch control relays and initially rendered effective upon said actuation of the manually operable contact means to designate said exit point for energizing the reverse switch control relays for all the switches required to be in reverse positions to set up said particular route, and contacts of said normal and reverse switch control relays included in said one circuit network and effective, when 5 said completion circuit network is effective, to de-energize the normal switch control relays for all track switches not in said particular route as initially energized by the designation of the entrance point of such particular route.
- 15 35. In a switch control system of the entrance-exit type, a track layout having a plurality of power-operated track switches for setting up different routes between entrance and exit points, a single control button for each entrance and/or exit point of the track layout, an entrance relay for each entrance point, an exit relay for each exit point, normal and reverse primary switch control relays for each of the track switches, circuit means effective upon the actuation of the 20 control button for any given entrance point to energize the entrance relay for that point, conditioning circuit means responsive to the picking up of an entrance relay to preselect the positions of the trailed switches included in all available 25 routes originating at the corresponding entrance point by energizing selected primary switch control relays and to condition for energization the exit relays for the exit points of all such available routes, circuit means responsive to the actuation of a control button for any given exit point having its exit relay conditioned for energizing that exit relay, completion circuit means effective upon the picking up of an exit relay for the exit point of a particular route having its 30 entrance relay energized for causing the energization of the remaining primary switch control relays required to establish that particular route, secondary switch control relays associated with each of the track switches for causing the power 35 operation of such track switches, and circuit means including contacts of said primary switch control relays and contacts of said secondary switch control relays and initially rendered effective upon the picking up of the exit relay for any particular route for sequentially energizing said 40 secondary switch control relays for the switches of that particular route in a predetermined order irrespective of the order of energization of the primary switch control relays of the switches for 45 that route.
